UNITED STATES PATENT OFFICE

1,945,468

TELEPHONE SYSTEM

Herbert M. Friendly, Portland, Oreg.; Milton S. Friendly and Central Republic Trust Company executors of said Herbert M. Friendly, deceased

Application August 25, 1923. Serial No. 659,283

90 Claims. (Cl. 179—27)

The present invention is directed to automatic or machine switching telephone systems; more particularly to systems of the stated general type which contemplate directively progressing a call 5 from a calling station through the agency of a so-called finger-hole calling device or dial to a called station wherein mechanism is interposed the purpose of which is to receive and store the directive impulses sent from the calling station 10 and re-send them or otherwise re-direct them, as by revertive control, for example, self-controlled, effective to link the connection from the calling line to the called station.

a. In carrying out the present invention in the 15 exampled organization chosen to elucidate it, the calling line leads to a lineswitch of well known primary type. The latter switch, in common with other similar switches, has access to a plurality of secondary lineswitches of the same type 20 as the primary lineswitches, though the employment of the secondary lineswitch, as well as its type, is optional. The secondary lineswitch has access, in common with other secondary line switches to coordinate movement first selectors 25 of the present invention.

b. The first selectors are arranged in groups or units wherein a plurality of first selectors are companion to one coordinate movement so-called auxiliary selector or storing device selector. The 30 said auxiliary selector is directively responsive from the calling line consequent to any one of its companion first selectors being seized by a secondary lineswitch responsive to the initiation of a call. When any one of the first selectors of 35 a group is seized the other idle selectors of the group are falsely barred against seizure, so that a hunting secondary lineswitch will seize an idle first selector of another group, provided it, too, is not falsely barred. That is, if a said auxiliary 40 selector is busy, all its companion, embraced, first selectors will be barred from seizure, having in mind that one or more of the first selectors may be in actual service and therefore normally barred against seizure, due to the service condition. The 45 auxiliary selector of an accessible group of first selectors is thus seized consequent to the initiation of a call by a subscriber, there then being the seized one of the first selectors of its companion group operatively interlinked with the auxiliary selector. When the calling party starts the sending 50 of directive impulses from his calling finger-hole dial by way of extending the call to a called line, the auxiliary selector will operate responsive to the first directive series, effective to raising its shaft into alignment with the level of bank

contacts thereof numerically corresponding to the number of impulses in the series sent. The auxiliary selector will automatically rotate its shaft at the said attained level, and operate selectively to find an idle storing device in the manner 60 of the auxiliary selector AS3 shown in my pending application for U. S. patent, Serial No. 655,851, filed August 6, 1923.

c. The storing device referred to has for its object the receiving of directive impulses from 65 the calling telephone and re-sending them through the seized first selector, as interpreted by the storing device, to operate the said first selector and succeeding switches to extend the calling to the called line and thereupon disconnect or 70 eject the auxiliary selector and storing device from the connection, leaving the connection essentially as if the first selector and succeeding switches had been primarily operated from the calling telephone without relation to the auxiliary selector and storing device. The said storing device has the same general object as the storing device disclosed in the said cited pending application for patent, though it will appear presently, that the present invention contemplates new and 75 additional objects from that of the said application. It will also appear presently, that the storing device will not be employed to directly re-send stored directive series, or such series which have been interpreted into predetermined series 80 or trains of series, under all conditions of calling since, as disclosed in the said cited pending application, certain calls will be progressed through the first selector and succeeding switches directly 85 from the calling telephone. 90

d. A function of the present invention is that which provides for progressing a call over an alternative one of a first or a second preferred alternative inter-office trunk route to the office containing the line called, as disclosed in the said 95 cited pending application, and the additional function of the present invention of forthwith initially progressing the call over the said first preferred or second preferred alternative route if the first trunk group of the primary or normal 100 trunk route is busy. That is, if all the trunks of the inter-office trunk group containing the trunks normally intended for a first link of the primary trunk route to the office containing the called line are busy, the call will be thereupon forthwith 105 routed over the first preferred alternative trunk route, and if the said first alternative trunk route includes a group wherein all trunks thereof are busy when a selector has successively tested same, the progressed extension of the call will be de- 110

- stroyed by revertive control and the call will then be progressed over the second preferred alternative trunk route. In this connection, attention is called to a modification which may be employed 5 in connection with the trunk groups accessible at certain levels of an inter-office selector, or at all levels thereof, using a chained circuit path adapted to become closed when all trunks of the concerned level are busy which will operate a re-lay in the selector attaining the level in readiness to selectively test the trunks of same, wherein the trunk leading-in to the selector will become forth-with reversed with respect to the selector line relay. This reversal of the trunk will be effective 10 to cause the progressed extension of the call to be destroyed by revertive control and the call to then be extended over the first or the second preferred alternative inter-office trunk route, as will appear, in the direction of the office containing 15 the called line.
- e. Another function of the present invention is that which enables alternative calling numbers involving a fewer number of "pulls" or operations of the dial calling device, and therefore requiring less effort, time and attention on the part of the calling party in directly extending a call. For example, the present system contemplates that three letters as a prefix (equivalent to three corresponding digits) and four digits representing 20 the local office numerical position of the called line will be sent, although alternative calling numbers will be provided for a certain plurality of the offices entailing the calling of but one prefix name (equivalent to one corresponding digit) and the said four local digits. That is, for those 25 offices arranged for the alternative name prefix calling in lieu of the three-letter prefix, either method of prefixing may be used by the calling party. Where the alternative name prefixes are employed it will usually, but not necessarily, be most expedient to employ the "7", "8", "9" and "0" holes in the finger-hole dial used at the calling telephone. The latter said four holes will therefore have name designations in addition to 30 the numerical, and possibly letter designations also. Where the name corresponding to either of holes "7" and "8" is pulled as a complete prefix, a relay in the storing device selected will operate corresponding to the said hole employed which 35 will set-up the equivalent stored condition as when the corresponding three-letter prefix is employed. When the hole "9" is pulled, the first selector concerned will be caused to rotate-in on the normal level and seize a trunk of the group 40 therein and self-eject the auxiliary selector concerned, so that the next return of the dial on the calling telephone will operate to directly directly progress the call through the succeeding selector. When the hole "0" is pulled, the first 45 selector concerned will be caused to step-up one level and rotate-in on the first off-normal level and seize a trunk of the group therein and self-eject the auxiliary selector concerned, so that the next return of the dial on the calling telephone 50 will operate to directly directly progress the call through the succeeding selector. The foregoing in this paragraph relates as well to the said cited pending application. However, the present invention contemplates that when "9" or "0" is pulled as a complete prefix and the group of 55 trunks of the corresponding level (normal level or first off-normal level), is then busy so the call cannot be progressed over the first link of the primary or normal inter-office trunk route under 60 direct directive control of the calling party, the auxiliary selector will rotate past the first bank position and select the first idle storing device. Then upon the next return of the dial on the calling telephone, the storing device seized will be set-up in correspondence therewith. That is to say, if the sending of "9" or "0" does not cause the connection to be progressed over the first link of a primary or normal inter-office trunk route it will cause the auxiliary selector to select a storing 65 device which will forthwith automatically operate to extend the call over a first preferred alternative trunk route to the office containing the called line, the last four digits pertaining to the numerical location of the called line in its terminating office being effective to setting up a corresponding stored condition in the storing device effective to cause the storing device to re-send the same digits effective to the local selectors and connector of the office containing the called line. If the call cannot be completed over the first preferred alternative inter-office trunk route to the office containing the called line, due to a busy inter-office trunk condition being encountered, the progressed portion of the call will be destroyed and the call forthwith automatically progressed in the direction of the office containing the called line over a second preferred alternative inter-office trunk route. Then, if a busy trunk group in the second preferred alternative inter-office trunk route is encountered, the call will be automatically extended to a predetermined telephone, or to a switchboard jack at which an attendant or an operator respectively, will inform the calling party that the call cannot be completed at that time due to all available inter-office trunk routes being 70 busy, or perhaps being falsely busied due to cable failure affecting one or more of the routes. Moreover, the latter said connection may involve an audible tone on a talking conductor thereof, so that the calling party will be automatically apprised of the busy trunk condition without awaiting the response of an employe of the operating concern to orally inform him.
- f. Another function of the present invention is that which when the busy inter-office trunk condition occurs in a group designed to be a second or following inter-office trunk link of the inter-office connection, and therefore wherein the first trunk link of the primary or normal inter-office route was normally seized, the extended 75 connection will be destroyed and then extended over the first preferred alternative inter-office trunk route, wherein the first link will belong to the same trunk group as which formerly contained the trunk forming the first link in the futile extension involved in the primary or normal route destroyed. Of course, the identical trunk may possibly become the first link of the primary or normal inter-office trunk route, as well as the first link of the first or succeeding preferred alternative trunk route, though usually, if the call 80 cannot be completed to the office containing the called line at the second progression of the connection (over the first preferred alternative trunk route) a generally new inter-office trunk route will be chosen for the second preferred alternative inter-office trunk route. The routes are pre-determined, and may therefore be deliberately chosen at the time of installation (and moreover, changed from time to time if desired), with 85 all traffic and geographical factors bearing taken into consideration, so that the same group of trunks may contain the first link in the primary or normal and also in the said first and the said second preferred alternative routes, where condi- 90

tions and location make such desirable or necessary. In the latter assumed routing, if the first group is busy, the connection will be forthwith extended to the attendant or switchboard referred to, since the call is thus futile.

5 *g.* Another function of the present invention is that which will cause the storing device to forthwith annex the succeeding stored series of impulses of a train by revertive control consequent upon the last operated selector seizing, though a maximum period, which will not be exceeded, is optionally provided for the spacing of the series of a train. This function depends upon transiently attenuating the strength of current 10 over the leading-in trunk consequent to the seizure of the selector terminating the call extension. It also refers to the connector wherein as soon as the connector has operated in a primary (vertical) movement and its series relay deactuates 15 preparatory for the last digit series to operate the connector in a secondary (rotary) movement a resistance will be transiently included in the leading-in path including the line relay of the connector to cause the storing device to initiate 20 the sending of the last digit series to operate the connector in its secondary movement. The resistance is again transiently included by the connector following the setting of its wipers on the terminals of the called line to forthwith eject the 25 storing device from the connection and to enable the busy-tone to be thereupon audible to the calling party if the called line is found busy-guarded. This introduction of series resistance at the remote end of a connection serves to retract a marginal relay in the auxiliary selector which will, in 30 turn, close a circuit path including a source of alternating current to destroy the slow-releasing property of a relay or relays controlling the spacing of the series comprising the train sent from the storing device. This would not hold, of course, 35 where a call is progressed over the normal level or the first off-normal level of the first selector directly directly progressed from the finger-hole dial on the calling telephone, but in a commercial system the trunks of the said two levels 40 will not generally be universal inter-office trunks subject to seizure in general routing, but on the other hand, these trunks will be specific to the calling and the called office, possibly being local 45 trunks in the originating office or trunks to a contiguous office, perhaps under the same roof, and therefore not extending outside of the office 50 premises. These trunks being local to the calling office or a contiguous called office enough may be provided to preclude possibility of encountering 55 a busy condition. In carrying out this feature of the invention the trunk repeaters employed to obviate the carrying of the private conductor where the length of the trunk is great 60 enough to make the employment of the repeater preferable, the trunk repeater (or repeaters) used provides means for repeating the attenuated condition of current applied back over the trunk (re-applied through perhaps a plurality of successive repeaters) from the selector or connector seizing. This general feature insures that no delay 65 in transmitting the next directive series from the storing device will occur after the antecedent series sent has become effective to completing its 70 contemplated extension. This arrangement thus admits of normally timing the spaces between digit series re-sent from the storing device to allow for secondary selection where desired and insuring at the same time that upon the circuits 75 being in readiness to receive the succeeding se-

ries from the storing device that same will be forthwith transmitted, due to the revertive control effected. The object of the latter function is to shorten the re-sending time to the minimum actually required, rather than to the maximum 80 possibly required.

80 *h.* Another object of the invention is that which provides that if a prefix train is sent which has no office significance, and therefore is an idle call, the call will be forthwith progressed to an attendant's telephone or switchboard jack specific to the condition occurring.

85 *i.* Another object of the invention is that which provides for applying a false busy to the trunk leading to a secondary non-numerical switch if all the trunks accessible to the said switch are busy.

90 Other objects and the invention itself will be understood from the following description thereof.

95 Referring to the accompanying drawings:—

Fig. 1 shows a well known automatic telephone CT leading to a well known primary lineswitch PL. The said lineswitch, in common with others (not shown) having access to a plurality of well known secondary lineswitches of which switch SL 100 is one.

Fig. 2 shows a first selector FS2 of the present invention accessible from the group of secondary lineswitches of which switch SL is one.

Fig. 3 shows a well known automatic telephone T3 leading to a well known primary lineswitch PL3, the said lineswitch, in common with others (not shown) having access to a plurality of well known secondary lineswitches of which SL3 is one.

Fig. 4 shows a first selector FS4 of the present invention accessible from the group of secondary lineswitches of which switch SL3 is one.

Fig. 5 is a so-called auxiliary selector AS5 of the present invention which is companion to and embraces selectors FS and FS4 of the present invention as well as other selectors (not shown), each selector preferably accessible from secondary lineswitches of a different group.

Fig. 6 shows the numerical order distributor element ND6, digit distributor element DS6, and other cooperative elements of the storing device of the invention.

Fig. 7 shows the local digit setting elements A7, B7, C7 and D7 of the storing device.

Fig. 8 shows the digit finder element DF8, impulse device ID8, and other cooperative elements of the storing device.

Fig. 9 shows prefix setting relays of the storing device concerned in the 7th, 8th, 9th and 10th off-normal levels of the auxiliary selector AS5.

Fig. 10 shows relays for causing certain futile calls to be automatically routed to specific trunks or telephones and connections of the storing device.

Fig. 11 shows alternatively inter-office trunk routing relays and connections of the storing device.

Fig. 12 shows connections of the storing device.

Fig. 13 shows the prefix setting elements A13, B13 and C13 of the storing device, concerned in the 3rd off-normal level of the auxiliary selector AS5.

Fig. 14 shows so-called chain relays with reference to the "normal" and "1" levels.

Fig. 15 shows the manner of assembling certain figures to display an organization of the system, the lines extending to adjacent joining margins of the containing sheets registering.

Fig. 16 shows an operator's service trunk.

Fig. 17 shows the manner of assembling cer-

tain figures to display an organization of the system, the lines extending to the joining margins of the containing sheets registering.

Fig. 18 shows a trunk leading from the 6th level 5 of auxiliary selector AS5 to a repeater R18 of the invention and an inter-office trunk leading therefrom to selector S18 of the invention.

Fig. 19 shows a trunk leading from the 5th level 10 of selector R18 to a repeater R19 of the invention and an inter-office trunk leading therefrom to selector S19 of the invention.

Fig. 20 shows a trunk leading from the 6th level 15 of selector R19 to a repeater R20 of the invention and an inter-office trunk leading therefrom to selector S20 of the invention.

Fig. 21 shows a secondary trunking switch SL21 20 of the invention leading from the 7th level of selector S20, together with so-called chain relays for five of the trunks accessible from the said switch SL21, also an inter-office trunk accessible from switch SL21 leading to selector S21 of the invention.

Fig. 22 shows a selector S22 of the invention 25 terminating the trunk leading from the 7th level of selector S21. The selector S22 has access over a local trunk to connector C22 of the invention. The connector C22 has access to the line leading to subscriber's telephone TA.

Fig. 23 shows the finger-hole subscriber's calling 30 automatic dial, and the finger-hole designations thereof, adapted to be employed in conjunction with the present invention.

Fig. 24 shows so-called chain relays relating to the 6th level of selector S19.

Fig. 25 shows a system plan organizing the calling telephones, primary lineswitches, first selectors and auxiliary selectors.

Fig. 26 shows a system plan organizing the equipments of the present invention with reference to outgoing traffic from an office.

The various equipment elements will be comprehended in view of the following references to the third edition of "Automatic Telephone Practice", by Harry E. Hershey. The subscribers' telephones or substations are the usual common battery series type including a finger-hole dial calling device as described on pages 16 to 19; the primary lineswitches PL and PL3 and the secondary lineswitches SL and SL3 are as described on pages 53 to 55; the secondary non-numerical trunking switch SL21 is of the general type as the switch PL, for example, but modified to operate in accordance with the present invention; the various selectors for linking talking connections and the auxiliary selector AS5 are as described on pages 59 to 62 but modified to operate in accordance with the present invention; the connector C22 is as described on pages 36 to 40, but modified in accordance with the present invention; the rotary switches or elements of the impulse storing device, wherein a stepping magnet is employed, are of the general type as switch PL as to mechanical structure, having in mind that the said elements in the storing device operate both step-by-step directly and non-directively in accordance with the present invention; the mechanical structure of the elements A13, B13 and C13 in Fig. 13 are each generally similar to those of the cited connector C22, but modified to operate in accordance with the present invention.

In Fig. 26, selectors A, B; F, G, H; N, O, P; are like selectors S18, S19 and S20, respectively. Selectors D, E; I, L, M; Q, T, U; Y, b, c; d, b, i; 75 are like selector S21. Selectors V and X are

like selector S19. Selector W is like selector S20. Selectors J, R, Z and e are like selector S22. Connectors C, E, S, a and g are like connector C22. The repeaters shown in Fig. 26 indexed by "26" are like repeater R18.

The detailed operation of the elements of the system and the system itself will be comprehended in view of the calls which will be exemplified. Only enough of the system contemplated in the invention is shown and described as has been thought necessary to a full and complete disclosure of its operating principles and organizations.

Referring to Figs. 15, 25 and 26, it will be noted that the first selectors FS2 and FS4 have their bank contacts connected in multiple and that groups of trunks lead from the levels (certain levels only being shown connected) over inter-office trunks to terminating selectors at inter-office trunk switching centers or in offices in which subscribers' lines terminate. Trunk repeaters are indicated in Fig. 26 by small circles, as R18, for example, which is also shown in detail in R18 of Fig. 18. However, it will be understood that other expedients well known in the art may be employed in lieu of the repeaters.

The four circles at the left in Fig. 25 and the five circles at the right in Fig. 26 represent a subscriber's telephone respectively. These, in the latter figure, are designated by their calling numbers and also by their routing digits, as well as arbitrary index letters, having in mind that four of the said telephones can be reached by calling alternatively a prefix of three letters or corresponding digits, and by calling a single prefix name or corresponding digit.

The Fig. 26 also indicates that when calling from the originating or calling office containing selectors FS2 and FS4, the call can be routed over any one of three inter-office trunk routes, having in mind that in routing a primary inter-office trunk route will be normally employed; supplemented by a first and then by a second preferred alternative inter-office trunk route. The first preferred said alternative route will be automatically employed in case the primary route is barred against use by reason of the trunks of one of the trunk groups thereof being all busy or is falsely busied due to an out-of-order condition. The second preferred said alternative route will be automatically employed in case the primary said route and the first preferred said alternative route involves a busy or falsely barred trunk group. However, attention is called that in the event of the primary route to telephone TB involving the 5th level of selector FS2 (or FS4 or any commonly connected selector), 3rd level of selector F, 4th level of selector G, 5th level of selector H to incoming local selector I involves a busy or otherwise barred inter-office trunk group, the first selector FS2 (or other first selector having operated with relation to the inter-office trunk F') will automatically restore and re-operate with relation to the same level (5th) and perhaps seize the same trunk F' as before seized terminating in selector F, or will then operate with relation to the 4th level and seize a trunk N' leading to selector N, depending upon whether the group of trunks containing trunk F' (being the first trunk link) was not busy or was busy, respectively. That is, if the trunk F' was seized and the busy condition was subsequently encountered the re-operation of the first selector to progress the call over an alternative route will be with relation to the same level (5th) as

- before, but this time operating selector F with relation to its 2nd level to extend the call through the indicated levels of selectors V, W, L to selector J and through the 7th level of the latter said 5 selector and connector K to the telephone TB. And if the first selector FS2 failed to find an idle trunk when operating with relation to the 5th level and therefore rotated off all the trunk terminals of the level, the selector FS2 will be 10 forthwith restored and then operated with relation to the 4th level and select one of the trunks N' thereof leading to selector N, from whence the call will be progressed through its 2nd level to selector M and through the indicated levels of 15 the latter said selector and selector J, and connector K to the telephone TB. However, if the first selector FS2 operates to alternatively progress the call over the 5th level a second time and a busy inter-office trunk group is again encountered, the first selector FS2 will again automatically restore and re-operate with reference to the 20 4th level and select a trunk N'. The call will be thereupon progressed through the indicated levels of selectors N, M, J and connector K to 25 telephone TB.
- It is thus understood that in case the first inter-office trunk link F' is attained and any succeeding inter-office trunk link in the primary or normal route cannot be linked the call extension will be forthwith destroyed and re-routed over the first preferred alternative trunk route, since the latter said route involves the same trunk group as contains trunk F', which latter group was found to contain idle trunk F' initially. Then, if a busy inter-office trunk group 30 is again encountered an entirely new inter-office routing from the first selector is attempted, which is through the 4th level of the first selector FS2 and selector N as has been set forth. In other 40 inter-office trunk routes to the called telephone exemplified the alternative routes involve completely new inter-office trunk groups. Of course, the second preferred inter-office trunk route may be over the trunk group F', in which case if the said 45 group is primarily encountered as busy the call will be futile. Which method of routing to be employed (by pre-design) to each office from a calling office will be determined by traffic, location and trunk facilities. The group F' may be 50 a very large one, possibly reached through a secondary switch generally similar to SL21, not shown in Fig. 26, making the probability of encountering all trunks thereof busy remote as compared to the available routes which could be 55 employed alternatively.
- It, of course, is understood that when trunk N', for example, is referred to any trunk and corresponding terminating selector of its group is meant and that the said terminating selectors 60 of such trunk group have their bank terminals correspondingly multiplied, unless secondary switches are reached from the said terminals. It will also be understood that the re-routing because of encountering a busy trunk group will 65 concern the inter-office trunk links only, and therefore not the trunk groups local to and within the office terminating the called line. The local selectors in Fig. 26 are the first and second anteceding the connectors C22, K, S, a and g, 70 respectively, with due regard to in-coming selectors having the shown multiplied bank contact connections with the said second anteceding selectors.
- The inter-office trunk selectors and leading-in 75 trunks thereto commonly serve a plurality of
- calling offices, as for example, inter-office trunking selector W may be operated through the office containing selector FS2 or an office calling over trunk X', for example. The inter-office trunks and selectors thus form a universal network of links for connecting calling with called offices wherein a trunk group which is in a normal or primary route for calls between a certain calling and called office may be in a first or in a second preferred alternative route for calls between certain other or even the same calling office. Moreover, a trunk group may be in a normal or primary route from a plurality of calling to a plurality of called offices. 80
- It will be noted that while the exemplified system employs a maximum of four inter-office trunk links (though a greater number may be employed), a lesser number may be employed where the route is possibly more direct, as for example, the trunks from the normal level and the 1st levels of selectors FS2 and FS4, which lead direct to in-coming local selectors d and Y, respectively. Also, the first preferred alternative route to telephone TA involves inter-office selector F only, and therefore requires but two 90 inter-office digit series be sent from the storing device to progress the call from the calling office to the called office, having in mind that in the present assumed call a prefix series corresponding to digit "8" or alternatively a train of three 95 digit series corresponding to "322" may have been sent from the calling telephone to set-up the storing device for the said inter-office routing. In the exemplified call to telephone TA the normal inter-office routing requires a train of four 100 selector FS2, S18, S19 and S20, and lineswitch SL21 to selector S21. 105
- It will appear presently, that if the call cannot be progressed to the office terminating the 110 called line over any of the inter-office trunk routes the first selector FS2 will operate with relation to the seventh level and the call will be progressed over trunk A' through selectors A and B to the attendant's switchboard AS or 115 to the telephone TF, as arranged. Again, if the call involves a prefix which is not pertinent to any of the offices of the system, the call will be automatically forwarded to the attendant's switchboard, BS. So when a call is completed 120 to the switchboard AS or BS, or to telephone TF, the responding party is thus prompted as to the 125 ensuing condition, and may so inform the calling party. 130
- Referring to Fig. 25, it will be noted that line-switch LS (terminating the line from telephone CT in Fig. 1) has access to secondary lineswitch SL. Also, that a telephone CT' leading to lineswitch LS' has access to the said secondary lineswitch SL. The secondary lineswitch SL has access to first selector FS2 and to other first selectors 135 not shown. However, it is preferred that the said other first selectors will each belong to a different group and with reference to the embracing auxiliary selector AS5, but having access to the same main group of out-going trunks as lead from selector FS2. The lineswitch LS3 (terminating the line from telephone T3 in Fig. 130) has access to secondary lineswitch SL3. Also, that a telephone T3' leading to lineswitch LS' has access to the said secondary lineswitch SL3. The secondary lineswitch SL3 has access to first selector FS4 and other first selectors not shown. 140 However, it is preferred that the said other first selectors will each belong to a different group 145
- 150

- and with reference to auxiliary selector AS5, but having access to the same main group of out-going trunks as lead from selector FS4. The relays R2 and R4 (also shown in Figs. 2 and 4) serve to connect the trunks leading to first selectors FS2 and FS4, respectively, to auxiliary selector AS5 consequent upon the seizure of a said first selector. The auxiliary selector AS5 is common to a plurality of embraced first selectors including selectors FS2 and FS4, but it is preferred that not more than one of the said first selectors be accessible from the same secondary lineswitch. For example, each first selector accessible from secondary lineswitch SL will then refer to a different auxiliary selector than the other accessible first selectors. There will thus be as many groups of first selectors and corresponding embracing auxiliary selector therefor as there are selectors accessible to a secondary lineswitch. Thus, a secondary lineswitch will not test more than one first selector with relation to any specific auxiliary selector. There will therefore be as many groups of secondary lineswitches as there are selectors embraced by an auxiliary selector. Of course, in place of actually segregating the secondary lineswitches in groups they may be employed in one large group with the bank connections lapped so any specific secondary lineswitch will not have access to a plurality of selectors embraced by the same auxiliary selector. The carrying out of the referred to segregation is a detail which is not essential to the operation of the system of the present invention.
- 35 The auxiliary selector AS5 upon being seized incident to a first selector being seized, causes any idle selectors of its group to be barred against seizure, until the said auxiliary selector is cut free, as the relays R2 and R4 for example, which correspond to first selectors FS2 and FS4 respectively, actuate upon its respective corresponding first selector becoming seized by a secondary lineswitch to connect the embracing auxiliary selector to the trunk leading to the first selector seized. The relay (R2 or R4, for example), deactuates to disassociate the latter said trunk from the auxiliary selector AS5 upon the requirement of the auxiliary selector terminating. The auxiliary selector AS5 thus serves the first selectors embraced by it positively, without a hunting delay, so when a first selector is seized by a secondary lineswitch (or a primary lineswitch if secondary lineswitches are not employed) the calling party may proceed forthwith to operate his calling dial to cause the directive extension of the call.
- 55 The detailed operation of the exemplified system will become clear, in view of the following specific call descriptions.
- 60 Assume a call from telephone CT to telephone TA, the listed number of which is "FABer-7892", and which will be called by sending prefix digits "322" (equivalent to the prefix letters "FAB") followed by the local digits "7892". It may also be called by alternatively sending the prefix digit "8"; the dial hole "8" being also designated "Faber" as shown in Fig. 23. The three-letter prefix "FAB" will be first assumed as employed.
- 70 Upon removing the receiver of telephone CT the primary lineswitch PL will function in the well known manner to seize the trunk leading to secondary lineswitch SL and the latter said lineswitch will function to seize the trunk leading to first selector FS2 in the well known manner assuming the trunks upon which the wipers are shown resting upon respectively, are idle. If the trunks, or one of them, are not idle the concerned said lineswitch PL or SL will automatically hunt through the agency of the stepping magnet SM and SM', respectively, in the well known manner to seize first selector FS2, having in mind that the selector FS2 (as well as selector FS4) belong to the present invention. The bank contact 101 being ungrounded the secondary lineswitch SL will seize the first selector FS2, so a circuit path can now be traced from grounded battery, upper winding of line relay 501 in auxiliary selector AS5, common conductor 502, slow-releasing series relay R2, make-before-break spring 202, conductor 203, bank contact 102, wiper 103, armature 104, conductor 105, bank contact 106, wiper 107, armature 108, conductor 109, telephone CT, conductor 110, armature 112, wiper 113, bank contact 114, conductor 116, armature 117, wiper 120, bank contact 122, conductor 123, make-before-break spring 205, conductor 207, lower winding of relay 501 to ground, the relays R2 and 501 actuating. Slow-releasing relay 502 is now operatively energized from the grounded armature 503. Armature 505 will ground conductor 507, energizing the polarizing winding of electro-polarized relay 508. The ground on conductor 507 can be traced through armature 408 (in Fig. 4), conductor 409 to bank contact 301 to guard the selector FS4 against seizure, assuming it to be idle. A circuit path can also be traced from grounded conductor 507, armature 208 (in Fig. 2), conductor 209 to bank contact 101 to maintain the secondary lineswitch SL and the primary lineswitch PL seized in the well known manner. The circuits are now in condition for the calling party to start sending the directive control impulses.
- 80 Having in mind the letter equivalent designations on the finger-hole calling dial, the calling party will send first prefix series "F" (corresponding to digit "3"), which will cause armature 503 to retract against its resting contact three times, applying three ground impulses through armatures 510 and 511, winding of slow-releasing series relay 512 to the vertical magnet VM5, causing the shaft to step its set of wipers 513 to 516 (inclusive) into alignment with the 3rd level of bank contacts. Upon the first energization of relay 512 ground from conductor 507 will be applied through armature 518, off-normal springs of set ON5 (which operate consequent to the first off-normal movement of the shaft) to the winding of shunted interrupter relay 519, the latter relay actuating and locking by way of armature 520 on rotary magnet RM5, armature 521 to grounded make contact. Then, upon the retraction of armature 518 following the third impulse to the vertical magnet, ground from conductor 507 will be applied through armatures 518 and 522 to the rotary magnet, causing it to operate to rotate the wipers 513 to 516 into engagement with bank contacts 523 to 526, respectively. Bank contacts 524 to 526 are dead, but bank contact 523 is permanently grounded. When the rotary magnet operated it opened the locking path for relay 519 at armature 520, relay 519 deactuating. However, upon the retraction of armature 520 ground on bank contact 523 is applied over wiper 513, armatures 527, 520, off-normal springs to the winding of relay 519, to cause the latter relay to reactivate, its armature 522 closing ground from conductor 507 to the rotary magnet to step the wipers 513 to 516 into engagement with bank contacts 531 to 534, respectively.
- 85 90 95 100 105 110 115 120 125 130 135 140 145 150

The 3rd, 7th, 8th, 9th and 10th levels of the second bank position refer to the storing device shown in Fig. 6 and interlinked figures. If the said storing device is idle bank contact 531 will not have ground potential thereon, so that the relay 519 will not be reactuated nor will ground potential be maintained on the upper terminal of the winding of switching relay 537. The windings of relays 519 and 537 will energize in series to conductor 507, but due to marginal adjustments, relay 537 only will actuate. Upon the attraction of armature 527 ground is applied from conductor 507, spring of set 540, armature 527, wiper 513, bank contact 531, conductors 541, 601, armature 602 to the winding of relay 603, the latter said relay actuating. Also the ground on conductor 601 will be applied through the winding of slightly slow-releasing relay 901, make-before-break spring 902, conductor 904, armatures 905 to 909 to grounded battery, relay 901 actuating. When armature 910 attracts, the windings of relay 901 and slightly slow-releasing relay 912 will then be operatively energized in series to said grounded conductor 601. The armatures of relay 912 are now grounded from conductor 601, which causes ground to be applied to conductors 614 to 617, and to attached bank contacts 545 to 548, respectively, to busy-guard the multiply attached corresponding bank contacts (not shown) of other auxiliary selectors of the group containing auxiliary selector AS5, so the said seized storing device will be barred against intrusions.

A circuit can be traced from the lower winding of impulse relay 550, armature 551, wiper 515, bank contact 533, conductor 552 to grounded armature 800 in Fig. 8, relay 550 actuating. A circuit path can now be traced from grounded battery, upper winding of relay 212, spring 213 of set CS2 make-before-break spring 214, armatures 215 and 216, common conductor 217, winding of marginal relay 554, operating winding of relay 508, armature 556, common conductor 557, armatures 220, 223, make-before-break spring 225, spring 226, lower winding of relay 212 to ground, relay 212 actuating followed by slow-releasing relay 228. Armature 230 thus applies supplemental ground to conductor 209.

In this connection it will be understood that if the storing device occupying the second bank position in the 3rd level of auxiliary selector AS5 were busy, having been previously seized by an auxiliary selector of the group containing auxiliary selector AS5, through a multiple of the bank contacts shown in Fig. 5, the bank contacts 545 to 548 and 531 would constitute ground potential regardless of from which bank level the seizure occurred, as will appear presently. In that event, the wiper 513 again encountering ground, this time on bank contact 531, the rotary magnet will again operate to advance the wipers an additional step to the third bank contact set (not shown) and there test the said set and seize the corresponding storing device if it is idle and rotate-off to the succeeding set of terminals if it is busy, the operation of rotating-off continuing until an idle storing device is found. The connections made to bank contacts 531 and 522, may if desired, be transferred to bank contacts 523 and 524 and the permanent ground on bank contact 523 removed. The method shown in the drawings reserves the same bank rotary position for a universal storing device, having in mind however, that other storing devices will occupy levels not shown as connected. It will appear presently that a specific storing device may be employed for each

bank position of each level, in lieu of the universal storing device employed which adapts itself to its requirement depending upon what level it is seized from. In that event only the conductors and circuit paths concerned with regard to the level at which the storing device is seized from will be provided. This latter method enables the specific storing devices to be simplified (as compared to the universal storing devices) by reducing relays and contacts occasioned in the drawings due to the convertibility, but a longer number of storing devices in total will be required as the diversity factor of traffic destination cannot be taken advantage of as where the same storing device functions universally, as has been set forth in the applicant's cited pending application for patent.

The storing device seized is now in readiness to operatively receive the second prefix series "A" (corresponding to digit "2") when the calling party next operates the calling dial. Consequent upon the two openings of the traced path including the windings of relay 501, two ground impulses from armature 503 are applied through armatures 510, 511, wiper 514, bank contact 532, conductor 560, series winding of slow-releasing relay 618, wiper 619 of set 619 to 622, bank contact 623, conductor 624, windings of vertical magnets V13, V'13 and V''13 of the routing elements A13, B13 and C13, respectively, in Fig. 13, in multiple, to grounded battery. The shafts 340, 340', 340'' carrying wipers 341 to 345, 342' to 345' and 342'' to 345'', respectively, will be thus stepped into alignment with the second bank level. In a commercial installation there would usually be ten levels of bank contacts accessible from the wipers of the elements A13, B13 and C13; each level having ten rotary positions. Two levels, the second and third, each having three positions, being shown in the drawings Fig. 13.

The relay 618 upon its primary energization attracts its armature to operatively energize the stepping magnet SM6 of the digit distributor element DS6, and upon its deenergization following the second ground impulse the said magnet SM6 will deenergize, causing the wipers 619 to 622 to advance one step so wiper 619 will rest upon bank contact 625. Then upon the calling party sending the third prefix series "B" (corresponding to digit "2"), two ground impulses will be again applied through the winding of relay 618, this time through bank contact 625, conductor 626, windings of rotary magnets R13, R'13 and R''13 in multiple to grounded battery, the shafts 340, 340' and 340'' rotating-in and setting the wipers on the said shafts on the second set of bank contacts of the second level. It will be noted that slow-releasing relay r13 is energized serially with magnet R13, for an object which will appear presently. However, it will become manifest that the relay r13 may be displaced by transferring its armature and connections to relay 618 in Fig. 6, since it is only required that ground be removed from wiper 341 during the process of rotating-in the wipers 341 to 345. Wipers 341 to 345 are set upon bank contacts 347 to 351; wipers 342' to 345' are set upon bank contacts 348' to 351'; wipers 342'' to 345'' are set upon bank contacts 348'' to 351'', respectively. The stepping magnet SM6 will be energized as before and will cause the wipers 619 to 622 to be advanced so wiper 619 is resting upon bank contact 627, following the said setting of the wipers of elements A13, B13 and C13.

At the time grounded wiper 620 engages bank contact 628 a circuit path can be traced from

ground, wiper 620, bank contact 628, bank contact 629, wiper 633 of set 631 to 636 of the numerical order distributor element ND6, armature 637 to the winding of stepping magnet SM'6, the magnet 5 SM'6 attracting its armature 637 to automatically interrupt its energizing path and move the set of wipers from the normal resting position shown in the drawings.

Before proceeding with the description with 10 relation to element ND6 reference will be made to the impulse sending elements A7, B7, C7, D7 and DF8 and associated circuits in Figs. 7 and 8 which lead into Figs. 6, 10, 11, 12, 9 and 13. In Fig. 8 ten digit conductors "1" to "0" lead to bank 15 contacts 801 to 810, respectively. Wipers 814 and 815 of the set 812 to 815 of the element DF8 are tied. The stepping magnet SM8 will operate to successively step the set of wipers 812 to 815 under control of a timed common impulse device ID8, 20 so wiper 815 successively advances from bank contact 816 until a grounded bank contact is encountered. The wipers 812 to 815 will thereupon automatically restore to the normal position shown in the drawings under automatic inter- 25 rupter action of the armature 817 on the stepping magnet SM8, as will appear presently. Suffice it to state at this time that as the wiper 815 progresses from a bank contact to a succeeding one the impulse relay 819 will attract and then 30 retract its armature 800, thereby opening the traced energizing path for relay 550 in Fig. 5, which in turn will correspondingly open and then close the traced path including armature 556 correspondingly to the number of bank contacts 35 801 to 810 are engaged until a grounded one is found. That is to say, if wiper 815 is caused to initiate its advancement under control of the impulse device ID8 and finds ground on bank contact 804, for example, four openings and clos- 40 ings of armature 556 will occur, after which the set of wipers 812 to 815 will rotate back to normal position under automatic interrupter control of the stepping magnet SM8.

Returning to the set wipers of Fig. 13 it will 45 be noted that bank contacts 347 to 351 are disposed as follows: that bank contact 347 is dead, while bank contacts 348 to 351 attach to digit conductors 6, 5, 6 and 7, respectively; that bank contacts 348' to 351' attach to spacing 50 conductors 353 and 354 and digit conductors 5 and 7, respectively; that bank contacts 348" to 351" attach to digit conductors 4, 4, 5 and 8, respectively. It will also be noted that bank contacts 639 to 642 of element ND6 are tied 55 through armatures 101 to 104 of shielded relay 105 in Fig. 10, armatures 101' to 104' of shielded switching relay 105' in Fig. 11 to wipers 342 to 345 in Fig. 13, respectively. So that under the 60 stated set condition, the bank contacts 639 to 642 of element ND6 are tied to digit conductors 6, 5, 6 and 7 leading to bank contacts 806, 805, 806, and 807 in Fig. 8, respectively.

In this connection it will appear that if relay 105' in Fig. 11 actuates and locks the wipers 342 to 345 will have no effective operative relation to the circuits, while wipers 342' to 345' will be connected through resting armatures 108' to 111' of shielded relay 112', attracted armatures 101' to 104' to bank contacts 639 to 642, respectively. So that under the latter assumed condition the bank contacts 639 to 642 are tied to spacing conductors 353 and 354 and digit conductors 5 and 7 leading to bank contacts 643 and 644 in element ND6 and bank contacts 805 and 807 in element DF8, respectively. And it will further appear that

if relay 112' in Fig. 11 now actuates and locks (relay 105' being locked actuated) the wipers 342' to 345' (as well as wipers 342 to 345) will have no effective operative relation to the circuits, while wipers 342" to 345" will be connected through attracted armatures 108' to 111' and attracted armatures 101' to 104' to bank contacts 639 to 642, respectively. So that under the latter assumed condition the bank contacts 639 to 642 are tied to digit conductors 4, 4, 5 and 8, leading to bank contacts 804, 804, 805 and 808 in Fig. 8, respectively.

Returning to the condition ensuing upon the said setting of the wipers in Fig. 13, and wherein wiper 619 is resting upon bank contact 627, wipers 631 to 636 having moved off the normal position so that wiper 636 now rests upon bank contact 639, it will be assumed the calling party forthwith annexes the first local digit "7", though it will appear presently that the storing device will forthwith automatically function to transmit the train of inter-office trunking digit series "6567" interpreted from the sent prefix digits "322" (corresponding to prefix letters "FAB") regardless of annexed digit series being or not being now sent 100 by the calling party.

Upon the calling party annexing first local digit "7", seven ground impulses will be transmitted over conductor 552 in the described manner, the relay 618 actuating to energize the stepping 105 magnet SM6 preparatory to causing the wiper set 619 to 622 to advance one step following the last (7th) ground impulse of the said digit "7" series sent by the calling party. However, the said ground impulses will be conducted through bank 110 contact 627, conductor 645, winding of slow-releasing relay 701 to the stepping magnet 702, the latter said magnet causing the set of wipers 704 to 706 to be advanced seven steps so that wiper 706 will rest upon bank contact 708 attached to digit conductor 7; wiper 705 will rest upon and ground bar 709 and wiper 704 will rest upon restoring bar 710. At the termination of the said first local digit series corresponding to digit "7" the armature of relay 618 will retract, causing 120 wiper 619 to step to bank contact 646. When the second local digit "8" is sent by the calling party, the eight ground impulses will be conducted over bank contact 646, conductor 647, winding of slow-releasing relay 711 to the stepping magnet 712, 125 the latter said magnet causing the set of wipers 714 to 716 to be advanced eight steps so that wiper 716 will rest upon bank contact 718 attached to digit conductor 8; wiper 715 will rest upon and ground bar 719 and wiper 714 will rest upon restoring bar 720. At the termination of the said second local digit series corresponding to digit "8" the armature of relay 618 will retract, causing 130 wiper 619 to step to bank contact 648. When the third local digit "9" is sent by the calling party, the nine ground impulses will be conducted over bank contact 648, conductor 649, winding of slow-releasing relay 721 to the stepping magnet 722, the latter said magnet causing the set of wipers 724 to 726 to be advanced nine steps so that wiper 726 will rest upon bank contact 728 attached to digit conductor 9; wiper 725 will rest upon and ground bar 729 and wiper 724 will rest upon restoring bar 730. At the termination of the said third local digit series corresponding to digit "9" 135 the armature of relay 618 will retract, causing wiper 619 to step to bank contact 650. When the fourth local digit "2" is sent by the calling party, the two ground impulses will be conducted over bank contact 650, conductor 651, winding of 140

145 150

slow-releasing relay 731 to the stepping magnet 732, the latter said magnet causing the set of wipers 734 to 736 to be advanced two steps so that wiper 736 will rest upon bank contact 738 attached to digit conductor 2; wiper 735 will rest upon restoring bar 740. At the termination of the said fourth local digit series corresponding to digit "2" the armature of relay 618 will retract causing wiper 619 to step off bank contact 650 to dead bank contact 652.

Forthwith upon the set of wipers 631 to 636 stepping off-normal wherein wiper 635 rests on permanently grounded bank contact 652, a circuit can be traced from ground, bank contact 652, wiper 635, armatures 653 and 654, conductor 655, winding of relay 825, armature 826 to the winding of relay 827, relays 825 and 827 actuating. It will be noted that at the time conductor 541 became grounded, consequent to the storing device becoming seized, this ground was applied through wiper 812 in element DF8 to operatively energize relay 832.

The cam-wheel 828 of interrupter ID8 is continuously revolving in the clockwise direction indicated at the rate of approximately ten revolutions per second, or the rate per second of sending directive impulses. When the cam projection 829 operates spring set 830 ground on spring 831 is applied over common conductor 833, armatures 834, 835, make-before-break spring 836 to the lower winding of relay 837, the latter said relay actuating, its upper winding locking through armature 838, bank contact 839, wiper 812 to grounded conductor 541. When the projection 829 operates the spring set 840 first thereafter, ground will be applied through armature 841, conductor 842, armature 843, winding of slow-releasing relay 844 to the winding of the stepping magnet SM8 and also from conductor 842, armatures 846, 847 to the winding of relay 819. The stepping magnet SM8 will operate to step the wiper set 812 to 815 in conformance with the rotations of the cam-wheel 828 wherein spring set 840 is operated one time each revolution, the wiper 815 successively resting upon bank contacts cooperative therewith until a grounded contact is encountered, at which time the ground will be applied through the tie to wiper 814, bar 850, make-before-break spring 851 to the lower winding of slow-releasing relay 852, the latter said relay actuating.

In view of bank contact 639 in Fig. 6 being tied through wiper 342 (in Fig. 13) to bank contact 806 in Fig. 8, it will appear that ground through the upper winding of slow-releasing relay 656 will be applied through make-before-break spring 657, wiper 636, bank contact 639 and over the traced path to bank contact 806, wipers 815, 814, bar 850, spring 851 to the lower winding of relay 852 after relay 819 has actuated and deactuated six times incident to the wiper 815 being step-advanced into engagement with bank contact 806. The locking circuit first established for the upper winding of relay 837 is opened when wiper 812 moves off bank contact 839 consequent to the termination of the first ground impulse applied to the magnet SM8, armature 855 of relay 844 sustaining until the second ground impulse is applied to the magnet SM8, so the armature 855 will serve to lock the upper winding of relay 837 to grounded armature 856 until after the last impulse of the ensuing series terminals and relay 827 deactuates, as will appear. The upper winding of relay 656 and the lower winding of relay 852 will then be energized in series, both said relays actuating.

In this connection it will be noted that a resistance r_8 is included in a path between bar 850 and grounded battery. The object of resistance r_8 is to allow for a wider margin of adjustment between relays 852 and 656. That is, if the spring 851 is disengaged from its resting contact before the armature 660 engages spring 657 there would be an opening of the energizing circuit of relay 656, were not the battery path through the resistance r_8 provided. The relay 852 may thus be adjusted to actuate coincident with, slightly in advance of relay 656. Wiper 812 applies ground received from conductor 541 to bar 860, armature 861, spring 851 to lock the lower winding of relay 852 during the existence of ground on conductor 541 and while wiper 812 rests upon bar 860. Grounded armature 862 will ground bar 863 upon which wiper 813 is resting, so that an automatic interrupter action will thus occur to the stepping magnet SM8 to advance the wiper 813 off the bar 863 to its normal position shown in the drawings; also removing the ground derived over wiper 812 from bar 860 to deenergize the lower winding of relay 852.

At the time relay 852 actuates grounded armature 865 applies its ground over conductor 866 to the winding of stepping magnet SM'6, causing it to operatively attract its armatures 637 and 659. Grounded battery on armature 867 will be applied over conductor 869, armature 660, spring 657, upper winding of relay 656 to ground to lock said relay 656. Armature 826 being attracted (as well as armatures 653 and 654) relay 827 will deactuate before the wiper 812 returns to bank contact 839, so that relay 837 will unlock. Due to the slow-releasing characteristic of relay 852, relay 656, magnet SM'6 and slightly slow-releasing relay 661 will be held operatively energized for an appreciable time dependent upon said relay 852 deactuating. Then, after relay 852 deactuates, there will be an additional period over which armature 652 (armature 654 retracting ahead of armature 653) will be sustained attracted in order to interpose a minimum delay in closing the circuit path traced through spring 657 so it will be impossible for the relay 819 to transmit a succeeding series of impulses until sufficient time has elapsed for the switch last directly controlled thereby to automatically complete its hunting or other operation. However, forthwith upon the retraction of armature 865 the armature 637 on the magnet SM'6 will retract to advance the set of wipers 631 to 636 one step so that wiper 636 will rest upon bank contact 640.

Having in mind that bank contact 640 is tied through wiper 343 in Fig. 13 to bank contact 805 in Fig. 8, upon the retraction of armature 653 (armature 654 having previously retracted), ground derived through the upper winding of relay 656 will exist on bank contact 805 in Fig. 8. The impulse sending device of Fig. 8 will function as before described; this time causing relay 852 to actuate upon wiper 815 engaging bank contact 805, followed by the restoring of the wiper 812 to 815. The relay 819 will have transmitted a series of five open ground impulses over conductor 552 while the wiper 815 is advancing from normal position (on bank contact 816) to bank contact 805.

The wiper set 831 to 836 will advance one step, so wiper 636 will rest upon bank contact 641, in the manner before described, in readiness for transmitting the third series of six impulses due to the fact bank contact 641 is tied through wiper 150

- 344 in Fig. 13 to bank contact 806 in Fig. 8. The impulse sending device in Fig. 8 will, (after the delay interval) cause its relay 819 to transmit a series of six open ground impulses to conductor 552 while the wiper 815 is advancing from normal position to bank contact 806. 80
- The wiper set 831 to 836 will advance one step so wiper 636 will rest upon bank contact 642, in the manner before described, in readiness for transmitting the fourth series of seven impulses due to the fact bank contact 642 is tied through wiper 345 in Fig. 13 to bank contact 807 in Fig. 8. The impulse sending device of Fig. 8 will cause its relay 819 to transmit a series of seven open ground impulses to conductor 552 while the wiper 815 is advancing from normal position to bank contact 807. 85
- The wiper set 831 to 836 will advance one step so wiper 636 will rest upon bank contact 662, in the manner before described, in readiness for transmitting the first local series of seven impulses due to the fact bank contact 662 is tied over conductor 663, armature 121, conductor 122, wiper 706, bank contact 708, digit conductor 7 to bank contact 807 in Fig. 8. It will be noted here that while the four inter-office trunking digits "6567" were being transmitted the wiper 635 rested upon one of the permanently grounded bank contacts, but now rests upon bank contact 664 leading over conductor 665 to bar 709, wiper 705, to grounded armature 741. So ground derived through bank contact 664 will be applied to wiper 635 for the object before set forth. The wiper 815 will be caused to advance to bank contact 807, whereupon receiving ground, the relay 852 will actuate in the manner before set forth, the relay 819 having meanwhile transmitted seven open ground impulses to conductor 552 in the manner before set forth. The stepping magnet SM'6 will be energized and deenergized to step the wiper 635 into engagement with bank contact 667 leading over conductor 668, bar 719, wiper 715 to grounded armature 742, in readiness for transmitting the second local series of eight impulses due to the fact bank contact 669 is tied over conductor 670, armature 123, conductor 124, wiper 716, bank contact 718, digit conductor 8 to bank contact 808 in Fig. 8. Ground derived through bank contact 667 will be applied to wiper 635 for the object before set forth. The wiper 815 will be caused to advance to bank contact 808, whereupon receiving ground, the relay 852 will actuate in the manner before set forth, the relay 819 having meanwhile transmitted eight open ground impulses to conductor 552 in the manner before set forth. The stepping magnet SM'6 will be energized and deenergized to step the wiper 635 into engagement with bank contact 671 leading over conductor 672, bar 729, wiper 725 to grounded armature 743, in readiness for transmitting the third local series of nine impulses due to the fact bank contact 673 is tied over conductor 674, armature 125, conductor 126, wiper 726, bank contact 728, digit conductor 9 to bank contact 809, in Fig. 8. Ground derived through bank contact 671 will be applied to wiper 635 for the object before set forth. The wiper 815 will be caused to advance to bank contact 808, whereupon receiving ground, the relay 852 will actuate in the manner before set forth, the relay 819 having meanwhile transmitted nine open ground impulses to conductor 552 in the manner before set forth. The stepping magnet SM'6 will be energized and deenergized to step the wiper 635 into engagement with bank contact 675 leading over conductor 676, bar 739, wiper 735 to grounded armature 744, in readiness for transmitting the fourth local series of two impulses due to the fact bank contact 677 is tied over conductor 678, armature 127, conductor 128, wiper 736, bank contact 738, digit conductor 2 to bank contact 802 in Fig. 8. Ground derived through bank contact 675 will be applied to wiper 635 for the object before set forth. The wiper 815 will be caused to advance to bank contact 802, whereupon receiving ground, the relay 852 will actuate in the manner before set forth, the relay 819 having meanwhile transmitted two open ground impulses to conductor 552 in the manner before set forth. The stepping magnet SM'6 will be energized and deenergized to step the wipers 632 and 633 into engagement with bank contacts 679 and 680, respectively. The permanent ground on bank contact 679 will be conducted to engage wiper 632, tie to wiper 633, bank contact 680, conductor 681, armatures 682, 683, conductor 684, bank contact 534, wiper 516, armatures 563 and 564, conductor 565, armature 232, conductor 233, make-before-break spring 234 to the winding of shielded relay 235, the latter said relay actuating and locking through armature 208 to grounded conductor 209, as will appear. Off-normal spring 236 attached to conductor 233 is free, as will appear. The ground applied to wiper 632 from bank contact 679 will cause the stepping magnet SM'6 to interrupt itself to step the wiper set 631 to 636 to normal position as shown, the set of bank contacts containing 679 being the first set antecedent with reference to the set containing 629. 95
- It will be noted in this connection that if any of wipers 705, 715, 725 and 735 are at normal or if any of the armatures 741, 742, 743 and 744 are in their respective attracted position the cooperative grounding bar will not apply ground to its corresponding bank contact 664, 667, 671 and 675, respectively, so if any element A7, B7, C7 and D7 is not set, the sending of impulses will be arrested until the next setting is made. 100
- The general operation of the storing device in relation to the stated call wherein a train of impulse series constituting digits "6567—7892" was transmitted from the storing device having been described, the detailed operation thereof and the effectiveness thereof with relation to the connecting switch mechanism will now be detailed, reference being had to Fig. 17 for the assembly of additional figures concerned in the stated assumed call. 115
- Assume that the combined sustaining periods of relays 852 and 656 is such that the maximum interval between the impulse series of a train will occur as would be required to hunt over all trunks of a group by a selector or by a selector and a secondary non-numerical switch seized by the selector. The relay 550 will retract its armature 556 responsive to the attractions of armature 800 in sending open ground impulses. Thus, when the first inter-office series of six impulses is sent, relay 212 will vibrate its armature 237 correspondingly and apply six ground impulses through armatures 238, 239, winding of slow-releasing series relay 240 to the vertical magnet VM2, causing the shaft carrying the set of wipers 241 to 243 to raise into alignment with the sixth off-normal bank level. The interrupter relay 245 will function in the well known manner in view of the citation to operate the rotary magnet RM2 to cause the shaft to rotate-in and successively test the busy-test contacts engage- 130
- 135
- 140
- 145
- 150

able by wiper 241, seeking an idle trunk to seize.

It will be assumed that the first trunk tested, terminating on bank contacts 247 to 249, is idle and therefore busy-test contact 247 will not constitute ground potential. This will terminate the ground potential held on the upper winding terminal of switching relay 250 and disable relay 245 from actuating, so that relay 250 will be operatively energized in series with the shunted winding of relay 245, the latter relay not operating due to its marginal adjustment. Armatures 251 and 252 will engage springs 214 and 225, disengaging the respective resting contacts thereof. Relays 212 and 228 deactuate in sequence. A circuit can now be traced from grounded battery, upper winding of line relay 801' in Fig. 18, make-before-break spring 802', armature 803' (which normally short-circuits resistance 804'), bank contact 248, wiper 242, armature 254 (which normally short-circuits resistance 255), armature 252, spring 225, the traced path including armature 556, spring 214, armature 251, wiper 243, bank contact 249, make-before-break spring 805', lower winding of relay 801' to ground, relay 801' actuating. The attracted grounded armature 807' will operatively energize slow-releasing relay 808'. Armature 810' will apply its ground to conductor 811' leading to bank contact 247 before armature 230 in Fig. 2 retracts, so no lapse of ground potential will occur to conductor 209 (and 507) due to the disassociation of relay 212.

Having in mind the general statement regarding the combined release periods of relays 852 and 656, it is clear ample time is allowed for the first selector FS2 to hunt over all the trunk positions of the 6th level (there being perhaps ten or more said positions), before the following impulse series is started were not some means provided for negating the sustaining characteristics or of alternatively closing the circuit paths controlled by the said relays, an idle delay period would occur which is potentially usable for further progressing the call. In the present assumed instance the first set of bank contacts were seized, and therefore, the hunting time provided for testing the successive sets of trunk contacts will be forthwith negated in the following manner. At the time armature 256 attracted and before armature 254 retracted thereafter, an appreciable period occurs during which the normally short-circuited condition of resistance 255 is removed so that the current in the traced path including the winding of relay 554 will be attenuated below its sustaining value due to its marginal adjustment. Under this condition, consequent to the first selector seizing, armature 566 will retract while armature 567 is attracted, so that alternating current from ground-seeking source Ge5 will be applied through armatures 566, 567, wiper 516, bank contact 534, conductor 684, condenser c6 to the lower winding of relay 656 and over conductor 685 to the upper winding of relay 852. The said alternating current will negate the sustaining or slow-releasing properties of the relays 656 and 852 as well as the direct current locked energization thereof, so the said relays will forthwith deactuate. Relay 832 receives its energizing ground from conductor 541, wiper 812, bank contact 839, so that regardless of the fact relays 852 and 656 will deactuate and relays 825 and 827 will again actuate consequent to the said application of alternating current from source Ge5, the initiation of the sending of the second series of impulses to pri-

marily operate the selector S18 will not occur until the spring-set 830 is operated following the return of wiper 812 to apply ground to bank contact 839 to actuate relay 832. It will be noted that dead contacts 890 and 891 are added to the right of bank contact 810 and that the bars 850, 863 and 860 extend correspondingly. Also, that a resistance 892 is interposed in the restoring bar 863 which becomes included after wiper 815 leaves bank contact 810. The purpose of the resistance 892 is to retard the automatic interrupter action of the stepping magnet SM8 so that the relay 852 will be held locked through wiper 812 longer than if the operation of the magnet SM8 were rapid. That is, the resistance 892 serves to retard the return of wiper 812 to bank contact 839 to maintain relay 852 energized until such minimum time as the armature 566 of relay 554 will possibly be retracted in the manner described. The resistance 892 thus permits relay 852 (and also relay 656) to have a shorter sustaining period than would be necessary otherwise in order to provide for the maximum hunting time of a selector, or a selector and a secondary non-numerical switch thereto.

Returning to the condition of the inter-office trunk consequent upon the seizure of its repeater R18. A circuit path can be traced from grounded battery, upper winding of relay 812', spring 813', of cam-spring set CS18, make-before-break spring 814', conductor 815', upper winding of relay 816', armature 817', operating winding of electro-polarized relay 818', conductor 819', make-before-break spring 820', spring 821', lower winding of relay 812' to ground, relay 812' actuating, its grounded armature 823' operatively energizing slow-releasing relay 824'. Conductor 825' will be grounded through armature 826'. Relay 816' will actuate, so that ground from armature 810' is applied through armatures 826' and 827' to operatively energize relay 828' and lock same through its armature 829' to armature 810'. Armature 830' will thus attract preparatory to displace armature 803' for short-circuiting resistance 804' before the attraction of armature 803'.

105

110

115

120

Responsive to the second inter-office series of five impulses being transmitted by relay 819 in Fig. 8, the relay 801' will correspondingly retract and attract its armatures. Relay 808' will sustain and ground will be applied from armature 807', armature 831' to slow-releasing relay 832'. The armatures of relay 832' will thus be attracted during the time the five impulses are being applied by the armature 807' and thus sustained for a brief period following the final closure of the said armature 807'. Grounded armature 836' will operatively energize the lower winding of relay 816' so when armature 817' retracts in repeating the impulses the armatures 827', 830', 803' and 829' will remain attracted over the current lapses in the upper winding of relay 816', the relay 816' being normally sustained actuated by the upper winding thereof (upon the attraction of armature 817'), the lower winding thereof being unenergized. Each time armature 817' retracts the traced path including the windings of relay 812' will be opened, causing armature 823' to correspondingly retract to apply its ground through armatures 840', 841', winding of slow-releasing series relay 842' to the winding of the vertical magnet VM18 to raise the wipers 845' to 847' into alignment with the 5th level of bank contacts. The circuit and operation of the selector S18 (including interrupter relay 848' 140

125

130

135

140

145

and the rotary magnet RM18) is well known, in view of the citation, excepting the introduction of the cam-spring set CS18, armatures 849', 850', and resistance 851' together with a modified arrangement of contacts on switching relay 852' and the cam-spring set CS18; all involved in the present invention. The functioning of the selector S18 wherein it will rotate-in at the 5th level and seize the first idle trunk leading to repeater R19 will now be clear. The discussion of the features of the present invention involved in selector S18 will be taken up presently.

It will be assumed that the wipers 845' to 847' seize the first set of bank contacts 853' to 855', respectively, consequent to relay 852' actuating in the well known manner due to bank contact 853' not presenting ground when tested. Having in mind that consequent upon the actuation of relay 852' the armatures 858' and 859' engage springs 814' and 820', respectively, before the windings of relay 812' are disassociated, it will be clear that the armature 849' will attract before armature 850' retracts. During the time armatures 849' and 850' are coincidentally attracted the resistance 851' is included in the path between armature 859' and wiper 846'. A circuit can be traced from grounded battery, upper winding of line relay 901', make-before-break spring 902', armature 903' (which normally short-circuits resistance 904'), bank contact 854', wiper 846', resistance 851', armature 858, spring 814', conductor 815', upper winding of relay 816', armature 817', operating winding of relay 818', conductor 819', spring 820', armature 859', wiper 847', bank contact 855', make-before-break spring 905', lower winding of relay 901', to ground. relay 901' actuating, its grounded armature 907' operatively energizing slow-releasing relay 908'. Armature 910' will apply its ground over conductor 911', bank contact 853, wiper 845', armature 865' to conductor 825', before armature 826 has had time to retract, so no lapse of ground potential will occur to conductor 825.

Due to the resistance 851' being transiently included in the traced path including the upper winding of relay 816', and that the latter said relay is marginally adjusted to retract its armatures under the condition of a resistance of the value of said resistance 851' being included serially therewith, it will appear that the short-circuit maintained around resistance 804' is transiently removed. This function operates to attenuate the current strength in the circuit path including marginal relay 554 in Fig. 5 to cause its armature 566 to retract so the alternating current source Ge5 will be then applied to deactivate relays 656 (in Fig. 6) and 852 (in Fig. 8) for the object of preparing the storing device for forthwith initiating the sending of the third inter-office series. The armature 826' having remained retracted, relay 828' remains locked, but armatures of relay 816' will re-attract and again short-circuit resistance 804' upon current energizing the upper winding of relay 816' being augmented to the normal value upon the retraction of armature 850'.

Attention is here called that the repeaters R18, R19 and R20 are alike, so that corresponding parts in the repeaters R19 and R20 are numbered as in repeater R18, but employing the index digit "9" in the case of repeater R19 in lieu of "8", and employing the index digit "2" in the case of R20 in lieu of "8". Also, selectors S19, S20, S21 and S22 are like selector S18, with the following exceptions, taking into account that

in selector S19 the index digit "9" is employed in lieu of "8"; that in selector S20 the index digit "2" is employed in lieu of digit "8"; that in selector S21 the index digit "5" is employed in lieu of "8"; that in selector S22 the index digit "6" is employed in lieu of "8". The vertical, rotary and release magnets, off-normal springs and last-rotary cam-springs (which latter operate from a wiper-shaft cam consequent to and before the wipers advance from the last bank contact position at all levels) are similarly designated where employed in the selectors S18, S19, S20, S21 and S22, but using the concerned figure number as the numerical index character. In selector S19 the relay r19 is operated by the cam-spring set CS19. The latter said relay operates armatures to effect the same relative circuit changes as are effectuated by cam-springs CS18, for example. A wiper 980' on the shaft of selector S19 engages a bank contact at each off-normal level position, but disengages same if rotated-in, and an armature 981' is added on relay 942' for disconnecting wiper 980' from the winding of relay r19 while the shaft is being raised. A set of springs 266' in selector S20 is operated by a shaft-cam 267' when the shaft is rotated-in at the seventh level and so maintained at all in positions in the said level to short-circuit the resistance 251', regardless of the positions of armatures 249' and 250'. It is thought that in view of the citations and last foregoing statements and the detailed descriptions in relation to repeater R18 and selector S18, the operation of the repeaters R19 and R20 and selectors S19, S20, S21 and S22 will become clear with the following descriptions.

Upon the third inter-office series of six impulses being sent from armature 800 of relay 819 in Fig. 8, the line relay 812' will correspondingly operate, its armature 817' causing relay 912' to, in turn, operate six times to raise the wipers 945' to 947' into alignment with the 6th level, where the rotary magnet will rotate the wipers until an idle inter-office trunk is found and seized, leading to repeater R20. Upon the fourth inter-office series of seven impulses being sent from armature 800 of relay 819 in Fig. 8, the line relay 812' and 912' will correspondingly operate their respective armatures successively, causing relay 212' to, in turn, operate seven times to raise the wipers 245' to 247' into alignment with the 7th level, where the rotary magnet will rotate the wipers until an idle local trunk is found and seized leading to secondary trunk switch SL21. A circuit can now be traced from grounded battery, winding of slow-releasing line relay 568', armature 569', bank contact 254', wiper 246', spring set 266', armature 258', spring 214', conductor 215', upper winding of relay 216', armature 217' operating winding of relay 218', conductor 219', spring 220', armature 259', wiper 247', bank contact 255', armature 580' to ground resting contact, the relays 568' and 571' actuating in the well known manner in view of the citation to seize the trunk it is shown resting its wipers upon or that relay 568' only will actuate so the wipers will rotate off and hunt. It will be assumed that the inter-office trunk leading to incoming local selector S21 is idle so that switching relay 571' will actuate; energized through the stepping magnet SM21.

In this connection it will be noted that when the relay 252' actuated to effect the seizure of the trunk leading to switch SL21, the resistance 251' was short-circuited by the spring-set 266',

- regardless of the fact an interval occurs in which armatures 249' and 250' are both in their respective attracted positions, so that the current traversing the upper winding of relay 216' will 5 not become transiently attenuated to cause the retraction of armatures 227' and 230'. It will be clear that were it not for the operation of spring set 266' the armatures of relay 216' would be caused to retract because of the attenuation 10 of the current strength traversing the upper winding of said relay 216', armature 203' being sustained attracted. Should the current traversing the upper winding of relay 216' become attenuated the current traversing the operating 15 winding of relay 918' and the upper winding of relay 916' would be attenuated below the sustaining value of said relay 916', so that its armatures would retract, armature 930' removing the short-circuit from resistance 904', armature 903' 20 being sustained attracted. The current traversing the operating winding of relay 818' and the upper winding of relay 816' would be attenuated below the sustaining value of said relay 816' so that its armatures would retract, armature 830' 25 removing the short-circuit from resistance 804', armature 803' being sustained attracted. Under the condition of resistance 804' being included in the path including the winding of relay 554, the storing device would initiate its functioning 30 to transmit the first local series of seven impulses constituted in digit "7", in the manner described. It will thus appear that the purpose of the spring-set 266' is to prevent the storing device initiating the sending of the first local 35 digit series until the switch SL21 has had time to seize an inter-office trunk leading to an incoming selector, which in the present case has been assumed to be the trunk terminating in selector S21. Were the said trunk leading to selector S21 directly accessible from selector S20, without the interposed secondary switch SL21, the spring set 266' would not be required, and if the individual trunks of any other bank levels 40 of selector S20 lead to a secondary lineswitch similar to SL21, the spring-set 266' will be adjusted to operate from an added cam or cams upon the wipers being rotated-in at such level or levels.
- It will be noted that upon the relay 571' actuating a transient interval occurs before armature 572' retracts wherein the resistance 573' is not short-circuited by either armature 572' or 574', so that the resistance 573' is then included in the path traced including the upper winding of relay 216'. This will cause the armatures of relay 216' to retract to cause resistance 204' to be transiently included in the path including the upper winding of relay 916', to in turn cause resistance 904' to be included in the path including the upper winding of relay 816' to in turn cause resistance 804' to be included in the path including the winding of relay 554, effective to forthwith initiate the functioning of the storing device in transmitting the series of seven impulses constituting the first local digit "7".

At the time relay 571' actuates, and before relay 568' deactuates thereafter, to effect the seizure of the trunk to selector S21, a circuit can be traced from grounded battery, upper winding of relay 512', spring 514', conductor 575', winding of slow-releasing shunted relay 576', bank contact 577', wiper 578', resistance 573', armature 569', bank contact 254', wiper 246', armatures 250', 258', spring 214', conductor 215', upper

winding of relay 216', armature 217', operating winding of relay 218', conductor 219', spring 220', armature 259', wiper 247', bank contact 255', armature 580', wiper 581', bank contact 582', conductor 583', spring 520', lower winding of relay 512' to ground. Relays 512' and 524' actuating in sequence, armature 526' grounding conductor 525'. Due to the transient inclusion of the resistance 573' in the last traced path relay 216' will transiently retract its armatures. In view of previous descriptions this will, in turn, cause relays 916' and 816' to correspondingly retract their armatures, and relay 554 to correspondingly retract its armature to cause the storing device to prepare to initiate the sending of the first local digit series. The retraction of armature 572' consistent with the release period of relay 568' will short-circuit the resistance 573' to augment the current strength traversing the last traced path including the upper winding of relay 216' to re-attract the armatures thereof. This will, in turn, cause the attraction of the armatures on relays 916' and 816' and armature 566 on relay 554 to disconnect the alternating current source Ge5. The relay 576' will actuate 100 coincident with the energization of relay 512' and will sustain over any directive impulses sent through its winding from the storing device. Armature 584' will apply ground over conductor 585, bank contact 586', wiper 587', armature 588', 105 bank contact 253', wiper 245', armature 265' to conductor 225' before armature 226' retracts, to maintain the selector S20 in seizure.

The sending of the first local series of seven impulses by armature 800 of relay 819 in Fig. 8 110 will be effective to relay 801' as before described. Relay 801' will, in turn, cause relays 901', 201' and 512' to correspondingly operate to cause the wipers of selector S21 to be raised into alignment with the seventh level of bank contacts and there 115 rotate-in and seize the first idle local trunk leading to local selector S22, the resistance 551' thereupon being transiently included in the path including the upper winding of relay 216' to retract its armatures to prepare to initiate the functioning of the storing device to send the second local digit series constituting digit "8", in the manner described.

The sending of the second local series of digit impulses will be effective to the relays 801', 901' 125 and 201', as before, but due to the attracted state of armature 558' and 559' relay 512' will be disconnected and the line relay 612' in selector S22 will be substituted therefor so that the wipers of selector S22 will be raised into alignment with 130 the eighth level of bank contacts and there rotate-in and seize the first idle local trunk leading to connector C22, the resistance 651' thereupon being transiently included in the path including the upper winding of relay 216' to transiently 135 successively retract the armatures of relays 216', 916', 816' and armature 566 preparatory to initiate the functioning of the storing device to send the third local series constituting digit "9", in the manner described.

The connector C22 being a well known connector, in view of the citation, modified in accordance with the present invention by the introduction of resistance 701', armatures 702' and 703' and off-normal springs 704' of set ON'22, 145 its operation will not require complete detailing to impart a clear understanding of its functioning as contemplated in the present system. It is manifest that the windings of relay 612' have been displaced in the traced path by the wind- 150

ings of line relay 706' in connector C22. The resistance 701' will therefore be included in the traced path including the upper winding of relay 216' upon slow-releasing relay 708' retracting following the sending of the third local series to the vertical magnet VM'22 to raise the wipers 712' to 714' into alignment with the ninth level of bank contacts. The said inclusion of the resistance 701' will cause the attenuation of the current in the upper winding of relay 216' below its sustaining value so it will retract its armatures, effective to prepare for initiating the functioning of the storing device to cause the armature 800 of relay 819 in Fig. 8 to forthwith start the sending of the fourth (last) digit series of two impulses to the rotary magnet RM'22 to rotate the set of wipers 712' to 714' into engagement with bank contacts 715' to 717', respectively, leading to called telephone TA. During the time the impulses are being applied to the latter rotary magnet the slow-releasing relay 720' will maintain its armature 703' attracted to short-circuit resistance 701', the armature 703' retracting to remove the said short-circuit and again include the resistance 701' following the setting of the wipers 712' to 714' upon bank contacts 715' to 717', so that the relays 216', 916', 816' and the relay 554 in Fig. 5 will retract to cause relays 656 and 852 to forthwith deactivate in order to cause the set 30 of wipers 631 to 636 to be returned to normal, incidentally applying ground from bank contact 679, wipers 632, 633, bank contact 680, conductor 681, armatures 632, 683, conductor 684, bank contact 534, wiper 516, armatures 563, 564, conductor 35 565, armature 232, conductor 233, spring 234 to the winding of relay 235. Relay 235 will actuate and lock through armature 208 to conductor 209, which latter conductor receives ground from armature 811' in repeater R18. Relay 235 thus disconnects the common conductor connections extending to auxiliary selector AS5 so that relay R2 in Fig. 2 and relays 501, 502, 537, 550 and 554 in Fig. 5 will deactivate. This will close a circuit from ground, armatures 503, 510, off-normal 40 springs to the release magnet Re5, effective to restore the auxiliary selector AS5. The relay R2 having a slow-releasing characteristic will insure that common conductor 507 will remain grounded from conductor 209, armature 261, long enough after the actuation of relay 235 to permit the release magnet of auxiliary selector AS5 to operate before the ground is removed from conductor 409 in first selector FS4 leading to bank contact 301 of secondary lineswitch SL3, as well as to the 45 conductor corresponding to 409 attached to bank contacts, corresponding to 301, respectively, of other first selectors, not shown, which are embraced by auxiliary selector AS5. The latter function serves to guard all first selectors embraced by auxiliary selector AS5 until the latter said selector is in condition to function in a succeeding call.

Forthwith following the setting of wipers 712' to 714' on the bank contacts 715' to 717', respectively, the signaling current from source Ge22 will be applied over the called line effective to operate the signal bell of the called telephone TA. Before detailing the further operation of the connector C22 attention will be called that the removal of the short-circuit from around resistance 701' will occur upon relay 720' deactuating, regardless of the busy or idle state of the called line leading to telephone TA so that the relay 235 in Fig. 2 will be operated to release the storing device, as will appear, presently.

The resistance 701' will be included in the path including the upper winding of relay 216' at approximately the time the said called line is busy-tested so that if the said called line is busy and busy relay 721' actuates to apply the busy-tone source to the talking conductor 722' the relay 235 in Fig. 2 will have been actuated to connect the talking conductors 123 and 203 to armatures 223 and 215, respectively, and to disconnect the storing device. Under the last stated condition the calling party is in talking relation with the conductors 722' and 723' of the connector C22 over the traced heavy conductors including armatures 215 and 223 and interposed condensers, so will perceive the busy-tone if applied by relay 721'. If the said called line is idle, and therefore becomes seized by connector C22, the relay 235 is caused to actuate and lock in the same manner as if the line were found busy, before the called party has had time to respond and cause the actuation of back-bridge relay 730' which excludes the resistance 701'.

The actuation of relay 730' will also disconnect the signaling current and reciprocate the battery and ground windings of line relay 706' 10C with relation to talking conductors 722' and 723' in the well known manner. This will reverse the direction of current traversing the operating winding of relay 218' in Fig. 20, effective to both windings cumulatively energizing relay 218' to 105 operatively attract armature 226'. This will unlock relay 228' to short-circuit resistance 204' regardless of the position of armature 230'. Ground from armature 210' will be applied through armature 226' to operatively energize 110 relay 289' to reciprocate the battery and ground windings of line relay 201' with relation to springs 202' and 205'. This latter function will, in turn, cause armature 926' to operatively attract, and relay 989' to actuate to, in turn, cause 115 armature 826' to operatively attract and relay 889' to actuate to, in turn, reverse the direction of current flow in the talking path leading to the calling telephone CT to operate a call register or affect supervision devices not shown, for example. 120

The restoration of auxiliary selector FS5 removes ground from bank contact 531, so conductor 541 will cease to constitute ground potential so that relay 603 will deactivate. Ground applied through the winding of low-resistance relay 686 125 to the armatures of relay 603, in common, will be applied to restoring bar 687 in element ND6; restoring bars 710, 720, 730 and 740 in elements A7, B7, C7 and D7, respectively; bar 688 in element DS6; and lower off-normal spring of set 130 ON13 (shown in Fig. 6, operated by shaft 340 shown in Fig. 13), conductor 690 to release magnets Re13, Re'13 and Re''13, in multiple, in Fig. 13. It will thus appear that the grounding of bar 687 will cause no effect in element ND6 because the wiper 633 cooperative therewith is at normal; otherwise it would cause the magnet SM6 to interrupt itself to advance wiper 633 off the said bar 687 so its tied wiper 622 will receive ground from bank contact 680 to continue the wiper 140 movement to normal position shown. Also, the magnets 701, 711, 721 and 731 will interrupt themselves to move the respectively corresponding wipers 705, 715, 725 and 735 off their respective cooperating bars to normal position shown. The 145 wiper 619 of element DS6 is resting upon bank contact 652, so wiper 622 is resting upon the last position of bar 688. The magnet SM6 will thus interrupt itself to move the wipers 619 to 622 to normal position shown. The release magnets 150

Re13, Re'13, and Re''13 will forthwith operate to restore the shafts 340, 340' and 340'' to normal, respectively.

During the time ground is being derived 5 through the winding of relay 686, armature 602 will apply ground to conductor 601 (and attached conductor 541) to maintain guarding potential on bank contact 531 and to maintain relays 901 and 912 locked so that conductors 614 to 617 10 leading to bank contacts 545 to 548, respectively, will be grounded to guard the storing device against seizure at all levels (3rd, 7th, 8th, 9th and 10th) normally accessible from auxiliary selector AS5 and other similar selectors of its group, 15 until all elements of the storing device have been restored to normal in readiness to serve a succeeding call. In view of previous descriptions, any testing auxiliary selector will be barred from the specific said storing device as long as relay 20 686 remains actuated, a hunting auxiliary selector rotating-off to the next set of bank contacts corresponding to a storing device.

It will be noted that when the relay 852 in Fig. 8 actuates and locks it will not sustain locked 25 after alternating current is applied through its upper winding, regardless of the locking ground applied through bar 860 and armature 861. Also, that if the resistance 573' in secondary switch SL21, for example, is permanently short-circuited, when the latter said switch seizes there would be no application of alternating current from source Ge5 to the upper winding of relay 852 (or the lower winding of relay 656) so in that event said relay 852 (and dependent relay 656) 30 will sustain only until its sustaining period expires after being deenergized by reason of wiper 812 advancing off bar 860. The initiation of the operation of the storing device is thus prepared for, thereafter dependent upon the slow-releasing 35 deactuation of relay 656 and the operation of spring set 830. That is, if the relays 852 and 656 are not deenergized by the alternating current from source Ge5, relay 852 will become deenergized when wiper 812 advances off bar 860, to 40 deactuate consistent with its slow-release period, followed by the deactuation of relay 656, consistent with its slow-release period so that the storing device is in condition to automatically annex the next set-up digit series. This condition 45 would manifest itself if a call route does not include means in selectors for causing the attenuating of current in the path including the winding of relay 554.

It will be noted that when the reversal of current takes place due to the operation of cam spring set CS2 in Fig. 2 the spring leading to the upper winding terminal of relay 250 will be freed, thus precluding the actuation of relay 250, which would otherwise occur because of the ungrounding of wiper 241 by rotating-off the last bank contact. This function of relay 250 actuating at this juncture would disconnect the windings of relay 212 during the time the shaft is restoring. Under the latter condition relay 212 would be deenergized, preventing the designed actuation of relay 508.

If switch-arm 893 in Fig. 8 is closed upon its cooperating contact, the relay 852 will be locked directly to conductor 541 and thus solely dependent upon the application of alternating current to its upper winding to deactivate it, having in mind that if the ground is removed from conductor 541 by reason of auxiliary selector AS5 restoring, the locking path of relay 852 will be thereby opened. Under the condition of switch-

arm 893 being closed the relays 852 and 656 will not be required to have the slow-releasing property as their deactuation will then depend upon the said application of the alternating current from source Ge5.

Assume that at the time first selector FS2 rotated-in at the 6th level all trunks leading therefrom were busy and that therefore the set of wipers 241 to 243 will rotate-off the last set of bank contacts and operate the cam-spring set CS2. This will reciprocate the relation of the battery and ground windings of relay 212 with relation to springs 214 and 225, respectively, so that the windings of relay 508 will energize cumulatively to operatively attract its armatures 564, 570 and 572. Armature 570 will thus apply ground over common conductor 571, armatures 262, 263, off-normal spring 265 to the release magnet Re2, effective to restore the selector FS2. Armature 564 will apply ground through armature 563, wiper 516, bank contact 534, conductor 684, armatures 683 and 692', off-normal spring 603', armature 604', conductor 606, upper winding of shielded relay 105', conductor 115', bank contact 607', wiper 634 to 100 grounded battery, relay 105' actuating and locking to lower winding to conductor 116', which latter conductor is permanently attached to conductor 601. Armature 117' will apply ground over conductor 118', armature 609' to the winding of slow-releasing relay 610', the latter said relay actuating. Armature 612' will apply ground received through armature 609' to conductor 613', bar 687, wiper 633, armature 637 to the stepping magnet SM'6, the said stepping magnet automatically interrupting itself to advance the wiper 633 off the bar 687 so wiper 632 will receive ground from bank contact 679 to advance the set of wipers 631 to 636 to the normal position shown in the drawings. Armature 572 will close the alternating current source Ge5 to armature 567 to cause the deactuation of relays 852 and 656 forthwith. Then, upon relay 661 deactuating, following the stated return of the set of wipers 631 to 636 to normal, the circuit path traced including conductor 655 will be closed, the relay 661 being adjusted to sustain over the retracted period of armature 659 during the process of the stepping magnet SM'6 automatically interrupting itself, or when it is held operatively energized.

At the time wipers 632 and 633 engage bank contacts 679 and 680, respectively, applying ground to conductor 681, this ground will be applied through armature 682, winding of relay 620', make-before-break spring 621', bank contact 622', wiper 634 to grounded battery, relay 620' actuating. A locking path for said relay 620' can now be traced from grounded battery, armature and its engaged spring 621', winding of said relay 620', armature 623' to grounded conductor 601. The set of wipers 631 to 636 will have returned to normal position before the deactuation of relay 610' due to the attraction of armature 609', so a circuit path can be traced from grounded conductor 118', armatures 609', 625', conductor 626', bank contact 629, wiper 633, armature 637 to the winding of stepping magnet SM'6 to cause the said magnet to interrupt itself and advance the wipers 631 to 636 to the first off-normal position.

It will be noted that due to the attracted condition of armature 682 when the ground is applied through wiper 633, bank contact 680 to conductor 681, the said ground is prevented from

being applied to conductor 684. This function is to insure that ground will not be applied through armature 564, conductor 565 and over the traced path to energize relay 235, or relay 5 245 if the shaft of selector FS2 is at normal, having in mind that the armature 564 may have retracted after attracting by the time ground is applied from wiper 633 to bank contact 680. Manifestly, the actuation of either or both relays 10 235 and 245 at this juncture would vitiate the call.

Before proceeding with the next effective operation, attention is directed that at the time the alternating current from source Ge5 was applied through wiper 516 to the lower winding of relay 656 and the upper winding of relay 852 the current was also applied through armatures 563 and 564, conductor 565 and over the traced path to the winding of relay 235. The latter said 15 relay, having a shielded core, is non-responsive to the said alternating current. Also, the said alternating current will be applied over conductor 684, armature 683, armature 602' and traced path including the upper winding of relay 105'. 20 The latter said relay having a shielded core, is non-responsive to the said alternating current.

Returning to the condition of the circuits at the time the set of wipers 631 to 636 advanced from normal position responsive to the actuation 30 of relay 620', before relay 610' has had time to deactivate, and remembering that relay 105' is now locked actuated, and the further fact that the element DS6 has not been affected by reason of the attraction of armature 564, it will appear that bank contacts 639 to 642 are now tied to spacing bank contacts 643 and 644, and digit conductors 5 and 7, over paths heretofore traced, in lieu of to digit conductors 6, 5, 6, and 7, respectively, as when wipers in Fig. 13 were originally 35 set. In this connection it will be noted that upon armature 654 retracting, relay 825 will be energized and the element DF8 and co-operating elements will function generally in the manner described to progress the call over the 40 primary inter-office route, to now progress the call over the first preferred alternative inter-office route. However, in the present inter-office trunk routing two digits will be sent to interlink two trunk lines, in lieu of four digits to 45 interlink four trunk lines. The present routing will be over the 5th level of first selector FS2, trunk F', 7th level of selector F, 7th level of selector D to selector S22.

Bank contacts 639 and 640 being tied to bank 50 contacts 643 and 644, respectively, the said bank contacts 643 and 644 will be successively grounded through the upper winding of relay 656 to cause ground to be applied through wiper 632 to energize the stepping magnet SM'6 to cause 55 the wiper 632 to advance off said bank contacts 643 and 644. The relay 656 is preferably marginally adjusted so it will not open the ground path at spring 657, due to the resistance in the winding of the stepping magnet SM'6. The wiper 60 636 is thus advanced to bank contact 641 forthwith upon ground being applied to bank contact 629. This will mean that bank contact 805 will now be grounded to cause five open ground impulses to be sent by relay 819 to cause the shaft 65 of selector FS2 to be raised to and rotate-in at the 5th level and select a trunk F' leading to selector F and then cause bank contact 807 to become grounded to cause seven open ground impulses to be sent by relay 819 to cause the 70 shaft of selector F to be raised to and rotate- 75 in at the seventh level and select a trunk leading to selector D. The first one of the four local digits will then be annexed to operate selector D in a like manner to selector S21 described to extend the connection to selector S22. Selector S22 and connector C22 will be operated as before described to complete the call to telephone TA responsive to the last three of the said four local digits. The repeaters A26 and B26, and selectors F and D correspond in detail to repeaters R18 and R19, and S18 and S19, respectively, the operation of extending the call to telephone TA will be clear.

If it is now assumed that all trunks of 5th level of selector FS2 are busy so that the cam-spring set CS2 will be operated as before in the primary routing wherein the 6th level of first selector FS2 was involved, the relay 508 will again operate to restore the shaft of selector FS2 and to apply ground to conductor 684. 80 However, the armatures of relay 620' (also of relay 105') are locked attracted, so ground applied from bank contact 680, conductor 681, armatures 682, 683, 631' will be conducted over armature 602', spring 603', armature 604', conductor 633', upper winding of shielded relay 112', conductor 115', bank contact 607', wiper 634 to grounded battery, the relay 112' actuating, its lower winding locking to grounded conductor 116'. Armature 120' will apply ground over conductors 121', 635', armature 637' to the winding of slow-releasing relay 638', the latter said relay actuating. Ground from armature 637' will be applied through armature 640' to conductor 613' to ground bar 687 for the object 105 as when before grounded. In the present instance, when ground is applied from wiper 633 to bank contact 680, this ground will be conducted through armatures 682, 683, winding of relay 642', make-before-break spring 643', bank 110 contact 622', wipers 634 to grounded battery, the relay 642' actuating, a locking circuit for relay 642' being traced from grounded battery, armature and engaged spring 643', winding of relay 642', armature 645' to grounded conductor 115 120 601. Before relay 638' has had time to deactivate a circuit path can be traced from grounded conductor 635', armature 637', armature 647', conductor 626' to bank contact 629 for the object before described.

Relays 105' and 112' being locked actuated bank contacts 639 to 642 are now tied to digit conductors 4, 4, 5 and 8, over paths heretofore traced, in lieu of to digit conductors 6, 5, 6 and 7, respectively, as when the wipers in Fig. 13 130 were originally set. Upon armature 654 retracting relay 825 will be energized and the element DF8 and cooperative elements will function generally in the manner described to progress the call over the primary route, to now progress the 135 call over the second preferred alternative route. However, the present inter-office trunk routing will be over the 4th level of first selector FS2, trunk N', 4th level of selector N, 5th level of selector O, 8th level of selector P, 7th level of selector E to selector S22. The repeaters C26, D26 and E26, and selectors N, O, P and E corresponding in detail to repeaters R18, R19, R20 and S18, S19, S20 and S21, respectively, the operation of extending the call to telephone TA will 140 145 be clear.

If it is now assumed that all trunks of the 4th level of selector FS2 are busy so that the cam-spring set CS2 will be operated as before in the primary and also in the first preferred alterna- 150

tive inter-office routing, the relay 508 will again operate to restore the shaft of selector FS2 and apply ground to conductor 684. However, the armatures of relays 620' and 642' (also of relays 5 105' and 112') are locked attracted so the ground applied to conductor 684 will be conducted through armature 631', conductor 646', make-before-break spring 131, winding of shielded relay 105, conductor 115', bank contact 607', 10 wiper 634 to grounded battery, relay 105 actuating and locking through its armature 133 to grounded conductor 116'. It will now appear that the conductors leading from bank contacts 639 to 642 through armatures 101 to 104, armatures 101' to 104', armatures 108' to 111' to wipers 342' to 345', respectively, are opened at armatures 101 to 104, respectively. Armatures 101 and 102 are applied to digit conductors 7 and 6, respectively. Armature 103 is applied through 20 armature 135, switch-arm 137, to digit conductor 3. Armature 104 is applied through switch-arm 140 to digit conductor 4. Thus, bank contacts 639 to 642 are now tied through armatures 101 to 104 to digit conductors 7, 6, 3 and 4, respectively. Also, bank contact 662, tied over conductor 663 to armature 121 is now connected to digit conductor 2 and bank contact 669, tied over conductor 670 to armature 123, is now connected through switch-arm 141 to conductor 25 681. Armature 143 will apply its ground to conductor 145, conductor 626' to bank contact 629. Armature 143 also applies ground through armature 146 to the winding of relay 147, the latter said relay actuating to apply ground from its armature 148, conductor 613' to bar 687 to restore the wipers of element ND6 to normal. When wiper 633 applies ground to bank contact 35 680, conductor 681, armature 149 to the winding of relay 150, the latter said relay will actuate and lock to conductor 116', relay 147 deactuating to remove ground from bar 687. When wiper 633 returns to bank contact 629 the stepping magnet SM'6 will forthwith interrupt itself to 40 advance the wipers 631 to 636 one step from normal position. Then, upon the retraction of armature 654 the relay 819 will be caused to start functioning in the manner described to transmit a digit train consisting of impulse series constituting digits "76342", following which ground will be derived through the upper winding of 45 relay 656, spring 657, wiper 636, bank contact 669, conductor 670, armature 123, switch-arm 141, conductor 681, armatures 682, 683, conductor 684 and over the traced path to the winding of relay 235, the latter said relay actuating and locking to conductor 209, in the manner described. The latter said train of impulse series will progress the call through the seventh level of selector FS2, repeater G26, trunk A', selectors A and B and connector C to telephone TF. The repeater G26, selectors A and B and connector C correspond in detail to repeater R20, selectors S21, S22 and connector C22, respectively, so the detailed operation of the concerned equipments will be understood in view of foregoing descriptions. The attendant, responding to the call extended to telephone TF will inform the calling party over the talking connection established of the condition.

In this connection it will be understood that the reciprocating springs in connector C corresponding to springs operated by the inside armatures on relay 730' in connector C22 will be adjusted to not reciprocate the connections to the windings of line relay therein corresponding to

relay 706', in connector C22, so that meter or toll devices will not register against the calling party.

By changing the switch-arm 137 to the dotted position and also changing switch-arm 140 to the upper dotted position it will be noted that the armature 103 will now extend the connection to digit conductor 5, in lieu of digit conductor 3, and that armature 104 will now extend the connection to conductor 681, in lieu of to digit conductor 4. This will mean, in view of the last foregoing call progression, that an impulse train consisting of digits "7635" will be sent consequent to the relay 105 actuating under the stated condition. This will cause the selector B to complete the call to a trunk of its 5th level leading to operator's jack AS, shown in detail in Fig. 16; response being made by inserting a well known switching cord plug. It will be noted that the "busy trunk tone" will be applied to the ring talking conductor by way of the ring anvil of the jack AS, so that the calling party will forthwith perceive the tone distinctive of the ensuing condition, so the calling party will be apprised as to the ensuing condition forthwith upon the selector B seizing without awaiting for the oral information given by the operator after responding. This tone will be disconnected consequent to the operator inserting the switching plug. The slow-releasing relay R16 will attract its armature to apply ground back over the private conductor 100 to maintain the seizure of selectors A and B upon selector B seizing. It will also cause the lamp L to glow. The operator will know the occasion of the call from the specific lamp signal L corresponding to jack AS attained. The slow-releasing characteristic of relay R16 insures its maintaining actuated if its energizing circuit is opened for a brief interval. The bank terminals shown at the left in Fig. 16 are in the 5th level of selector B, cooperative with the private and line wipers 105 thereof as indicated by the light and heavy conductors respectively, leading to the said bank contacts.

Assume that in lieu of the calling party sending prefix digits "322" he has sent prefix digits 110 "333" of a non-existing office wherein wipers 341 and 342 would have been set upon bank contacts 356 and 357, respectively. Ground from the resting contact of armature of relay r13, wiper 341 will be applied over bank contact 356, conductor 358, right-hand winding of relay 155, conductor 115', bank contact 607', wiper 643 to grounded battery. Relay 155 will actuate and lock its left-hand winding through armature 156 from grounded conductor 116'. Wiper 342 is 115 tied to bank contact 639 over the path traced. Ground through the upper winding of relay 656, spring 657, wiper 636 is applied to bank contact 639 and over the traced path to wiper 342, bank contact 357, conductor 359 to spring 131 of relay 120 105 in Fig. 10. The relay 105 will actuate and lock as before described. However, due to the actuation of relay 155, armature 103 is now applied to digit conductor 7. The switch-arm 140 is in its upper dotted position.

In view of foregoing descriptions the selectors FS2, A and B will function as last described, excepting that selector B will rotate-in at the 7th level and select a trunk like shown in Fig. 16, leading to jack BS. The tone source in the latter instance applied to the ring anvil of jack BS will be distinctive to the condition ensuing.

In foregoing descriptions the re-routing of the call was occasioned by the first selector FS2 ro- 145

150

tating-off the last set of bank contacts after testing all trunks of the level and finding them busy, whereby the cam-spring set CS2 is operated to reverse the direction of current traversing the 5 operating winding of relay 508 to cause it to operatively attract its armatures. It will be clear, in view of previous descriptions, that if the trunk repeater R18 leading to selector S18 is seized and the latter said selector is operated at 10 any level as in the case of the 5th level in the call to telephone TA and all trunks of a level are tested and found busy, the cam-spring set CS18 will be operated to reciprocate the relation of conductors 815' and 819' to the battery and 15 ground windings of relay 812' so that relay 818' will operatively attract its armature 826' to operatively energize relay 889' to in turn reverse the direction of current projected from the battery winding of relay 801' including the operating 20 winding of relay 508 to operatively attract its armatures for the objects set forth. That is to say, if the cam-spring set CS18 is operated the first selector FS2 will be restored, followed by selector S18, and the element ND6 will restore its 25 wipers to normal position and forthwith re-initiate the functioning of the storing device to re-operate the first selector FS2 and succeeding selector F consistent with the said first preferred alternative inter-office trunk route. It follows 30 that if the wipers of the said selector F rotates-off the last set of bank contacts (of the 7th level in the present call) its cam-spring set corresponding to CS18 will operate to cause the relays corresponding to 818' and 889' in repeater A26 35 to operate to in turn, cause relay 508 to operate to cause the first selector FS2 to be restored, followed by selector F, and the element ND6 will restore its wipers to normal position and forthwith re-initiate the functioning of the storing device 40 to re-operate the first selector FS2 and succeeding selectors N, O and P, consistent with the said second preferred alternative inter-office trunk route.

In view of foregoing descriptions relating to 45 Figs. 18, 19 and 20, the operation of any set of cam-springs CS19 and CS20 will cause a like effect upon relay 508 and its dependent equipments. However, in the case of selector S19 the normal functioning is different from that of selector S18, for example. In lieu of the reciprocation taking place in the cam-springs directly a closure of the energizing path including relay r19 is effected to cause the reciprocation of conductors 919' and 915' to the windings of relay 912'. The cam-springs CS19 will only operate in emergency, as will appear.

The wiper 980' will engage the level-test contact 990' when the shaft carrying wipers 945' to 947' is raised so the wipers 945' to 947' are in alignment with the 6th bank level, before the said wipers 945' to 947' are rotated-in thereat, there being a similar contact to contact 990' (as 991' and 992', corresponding to the 7th and 8th levels) at all levels, preferably, so as to anticipate the operation of the cam-spring set CS19 in order to save the delay to the completion of a call extended over an alternative route by reason of the selector S19 rotating-in to operate the cam-spring set CS19 when all trunks of the concerned level are busy at the time the shaft aligns its wipers therewith.

The private conductor of each trunk leading from the 6th level, of selector S19, for example, has a leg through the winding of a relay to a grounded battery; five relays 401'' to 405'' as

shown in Fig. 24 refer to the 6th level accessible from selector S19. There would be as many of the latter said relays as trunk positions in the level; possibly ten or more. Relay 401'' attaches to the conductor 211' which attaches to bank contact 993' and to multiples thereof accessible from other selectors of the group containing selector S19. It is thus clear that if all the trunks accessible from selector S19 at the 6th level are busy, the ground 407'' will be chained to conductor 408'' leading to bank contact 990' and corresponding multiplied bank contacts of other selectors of the group containing selector S19. It will then appear that if the wipers of selector S19 are operated to and stopped in alignment with the 6th bank level wherein all trunks of said level are busy, level-test contact 990' will constitute ground. Under this condition, upon relay 942' deactuating, following the setting of wiper 980' on bank contact 990', preparatory to energize the rotary magnet RM19 to step wiper 980' clear of bank contact 990' and wipers 945' to 947' into engagement with bank contacts 993' to 955', respectively, assuming the latter said bank contacts to be the first accessible set, chain ground 407'' is applied over conductor 408'' (or conductor 408'' may be falsely grounded by switch p in case of an out-of-order trunk condition, for example,) level-test contact 990', wiper 980', armature 981' to the winding of relay r19, the latter said relay actuates to reverse the direction of current in the operating winding of relay 918'. In view of foregoing descriptions this will cause the selectors FS2, S18 and S19 to restore and the call to be routed over the first preferred alternative route involving trunk F' and selector F as has been described. It will be manifest that if the level-test contact 990' does not constitute ground at the time wiper 980' engages it while armature 981' is retracted, the wiper 980' will be caused to forthwith disengage the said contact 990' due to the operation of the rotary magnet. However, if the busy condition of all trunks of the level attains after the hunting operation has started, and the cam-spring set CS19 operates, the relay r19 will cause the re-routing of the call as before set forth.

It will be understood that the present system contemplates the expedient involved in wiper 980' in other selectors terminating inter-office trunks, and also in the first selector (as FS2) local to the originating office though the delay involved in the said first selector idly-rotating-in to the rotary cam-spring set (as CS2) will not be considerable. Where this idle rotating- 120 in occurs in a succeeding selector, the time required to rotate-in accrues objectionably to the delay occasioned by the idle linking of the call extension to the point determining the call as futile over the concerned route. Again, the reversing of current direction is effectively employed only at levels at which the call is being progressed under the automatic control of the storing device, and not at levels of the first selector employed in directly directly progressing the call from the calling device at the calling station; the 1st and the normal level, as will appear. Under the condition of progressing the call over the 1st and the normal levels in the present exampled system the storing device will 130 not, under all conditions, be concerned so that the automatic employment of the alternative route will not hold universally, and moreover the reversing of the direction of current traversing the calling line is objectionable as it may re- 140 145 150

quire special treatment of metering and supervisory devices thereon subject to operation consequent to current reversal. The 1st and the normal levels of the first selector will usually be reserved for local or direct trunks of short length wherein a large number may be provided with low cost and wherein there may be no economic or other object of providing an alternative route.

10 Refer to Fig. 21 wherein the secondary switch SL21 is arranged so in the event all trunks accessible therefrom are busy the leading-in trunk to the said secondary switch will test busy to the antecedent switch (as S20) testing the latter said trunk.

15 Legged to the private conductor of each trunk accessible from switch SL21 is a conductor leading through the winding of a relay to battery; relay 590' being legged from the private conductor 585' attached to bank contact 586' and multiply attached corresponding bank contacts of other switches of the group containing switch SL21. When all accessible trunks are busy, all corresponding relays 590' to 594' will be actuated 20 to close the chain-ground 595' to common conductor 596'. It will thus appear that ground will be applied through armatures 597', 598' to bank contact 253' to guard the idle switch SL21 against seizure. The common conductor 596' being similarly related to all switches of the group 25 containing switch SL21, wherein if the switch is idle armatures corresponding to 597' and 598' will be retracted, will cause all said idle switches to be barred against seizure. The hunting selector 30 S20, for example, will rotate-off bank contact 253', as well as other falsely grounded and busily-grounded private bank contacts, and seize the first one found unbarred. If no unbarred trunk can be found, the selector S20 will rotate-off its 35 last set and operate the cam-springs set CS20, effective to operate relay 508 in the manner and for the object set forth.

40 It will be manifest that the private conductor leading from bank contact 253' of selector S19 and the other private conductors of the 7th level of selector S19, not shown, may be treated as shown in Fig. 24 with relation to the 6th bank level of selector S19. That is to say, Fig. 24 may be assumed to concern selector S20 wherein the 45 cam-spring set CS20 has been displaced by the circuit arrangement shown in selector S19 involving cam-spring set CS19 and relay r19, together with the introduction of a wiper, bank contacts and armature corresponding to wiper 980', bank contacts 990' to 992' and armature 981'. Under this condition, if all the trunks accessible 50 from the secondary switches reached through the 7th level of selector S20 are busy or are falsely guarded due to the common conductor 596' being busy or falsely chain-grounded the extended connection will be destroyed consequent to the relay 242' deactuating following the aligning of the wipers 245' to 247' with the 7th level of bank contacts. There will be a secondary switch as 55 SL21 corresponding to each bank position of the 7th level of selector S20, the employment of secondary switches in relation to antecedent selectors, in general, not being new. However, the present invention contemplates the false busying 60 of the trunk leading-in to the secondary switch; the reversal of the current projected back from the windings of the line relay of the said antecedent selector if all trunks of an attained level are busy or falsely barred; as well as the delaying 65 of the succeeding directive impulse series un-

til the secondary switch has seized, which latter function has been described wherein contact set 266' in selector S20 was concerned.

70 In this connection it will be understood that if the selector succeeding the first selector FS2 is located in the same building, the introduction 80 of a repeater will not be required. For example, bank contacts 247 to 249 would in such case connect direct to conductors 825', 815' and 819', respectively, leading-in to selector S18. This disposition would possibly be employed with relation to the normal level and the 1st off-normal level wherein the trunks are perhaps local to the calling office or extend to a contiguous office, and wherein three-wire trunks are more practical 85 than introducing a repeater to translate to two-wire operation and where energizing the calling telephone from the connector (or from a repeater) is practicable.

90 The call from calling telephone CT to called telephone TA having been described wherein the three-letter prefix "FAB" was sent, followed by the four local digits "7892", the said call will now be described wherein the name prefix "Faber", corresponding to the single digit prefix "8" is 95 alternatively sent.

95 The switches LS, SL, FS2 and AS5 will function as before described consequent upon the receiver of telephone CT being removed from the switch-hook. However, responsive to the sending of the 100 prefix digit "8" the shaft of auxiliary selector AS5 will be raised so its set of wipers 513 to 516 will align with the 8th bank level and there automatically rotate-in in the manner described, wiper 513 engaging permanently busily-grounded 105 bank contact 573, causing the rotary magnet RM5 to advance the wipers an additional step. Wiper 513 is now in engagement with bank contact 547 assumed to be ungrounded due to an idle condition of the concerned storing device, so that the 110 auxiliary selector AS5 will thereupon seize. In view of previous descriptions, wiper 513 will forthwith ground bank contact 547; same being extended over conductor 616, winding of slightly 115 slow-releasing relay 921, make-before-break 120 spring 922, conductor 904, armatures 905 to 909 to grounded battery, relay 921 actuating, wherein battery derived through the winding of relay 912 is applied through spring 922 before the path through spring 909 is opened at armature 906 to 125 sustain relay 921 actuated; relay 912 actuating. The actuation of relay 912 causes conductors 601, 614, 615 and 616 to be mutually tied and grounded from conductor 616 to bar the storing device from seizure from its accessible levels of 130 135 selectors having common access with auxiliary selector AS5.

140 Bank contacts 639 to 642 are now tied through terminals 9a, 9b, 9c and 9d (shown in Figs. 9 and 10), armatures 923 to 926 on relay 921, armatures 927 to 930 on shielded relay 931, digit conductors 6, 5, 6 and 7 to bank contacts 806, 805, 806 and 807 in Fig. 8, respectively. Armature 932 grounds conductor 933 leading to bank contacts 647' and 648' in element DS6 which will 145 cause the said ground to be applied through wiper 621, armature of stepping magnet SM6, armature of relay 618 to the winding of the latter said stepping magnet, its said armature interrupting its energizing path to forthwith automatically step the wipers so that said wipers 619, 620 and 622 will rest upon bank contacts 627, 628 and bar 688, respectively. A circuit path can be traced from armature 510, armature 511, wiper 514 and engaged bank contact, conductor 560, winding of 150

relay 618, wiper 619, bank contact 627, conductor 645, relay 701 to the stepping magnet 702. A circuit can be traced from the lower winding of relay 550, armature 551, wiper 515, bank contact 574, conductor 552 to grounded armature 800, relay 550 actuating. An open circuit path can be traced from the winding of relay 235, spring 234, conductor 233, armature 232, conductor 565, armatures 564, 563, wiper 516, and its 10 engaged bank contact, conductor 684, armatures 683, 682, conductor 681 to bank contact 680. It will be noted here that the winding of relay 245 leads through off-normal spring 236 to conductor 233, so it is in multiple relation with the winding 15 of relay 235.

Upon grounded wiper 620 engaging bank contact 628 the ground will be applied over conductor 626' to bank contact 629 to cause the wipers 631 to 636 to advance one step off-normal in the 20 manner before described. Ground through bank contact 652, wiper 635, armatures 653, 654, conductor 655, winding of relay 825, armature 826 to the winding of relay 827 will cause relays 825 and 827 to actuate in the manner and for the object 25 before described. The storing device will now automatically send inter-office trunking digits "6567" interpreted from the single prefix digit "8" (in lieu of the three-letter prefix "FAB") to operate selectors FS2, S18, S19, S20 and secondary 30 switch SL21 to seize selector S21 in the manner before described, having in mind, of course, that in lieu of the identical said selectors and secondary switch being seized, switches belonging to their respective level groups may have been 35 seized instead.

The calling party will annex the first local digit "7" forthwith following the return of the finger-hole dial in sending the single prefix digit "8", by which time the wipers 619 to 622 will have 40 attained the stated position wherein wiper 619 rests upon bank contact 627, which was its position in the foregoing description following the sending of the third letter of the three-letter prefix "FAE". It is manifest that the relay 921 set-up the same equivalent circuit relation as the wipers 342 to 345 did upon being set upon bank contacts 348 to 351, respectively, and that the 45 positions occupied by wipers 619 to 622 and wipers 631 to 636 forthwith following the sending of the single digit prefix "8" are likewise the same as existed forthwith following the said setting of wipers 342 to 345. The sending device will therefore operate in detail as before described wherein the three-letter prefix "FAB" was sent.

Responsive to the calling party sending the four local digits "7892" the elements A7, B7, C7 and D7 will be set in the manner and in detail as before described when said local digits were annexed to the three-letter prefix "FAB", the 50 wipers 619 to 622 being successively stepped one step following each local digit series sent from the dial as before so that wiper 619 will rest upon bank contact 652 when the last local digit of the called number has been sent from the dial by the calling party. The element ND6 will thus distribute the four numerical orders constituted in the prefix regardless of whether any local digits are sent by the calling party, but the further operation of the element ND6 will, as before, correspondingly depend upon the set-up state of the 55 respective elements A7, B7, C7 and D7. It is thus clear that consistent with the calling party annexing the last local digit "2" the call will be completed to telephone TA in the manner before 60 described, excepting that the armatures 923 to

926 of relay 921 performed the function before performed by the wipers 342 to 345.

Upon the bank contact 680 being grounded by wiper 633 following the re-sending of the last digit series, the relay 235 will be caused to actuate, following by the restoration of the auxiliary selector AS5, in the manner described. This will remove ground, from conductor 616, which will unlock relays 912 and 921, having in mind that relay 686 will remain actuated until all elements (as A7, B7, C7 and D7, for example) restore to normal. Relay 686 will maintain conductor 601 grounded while it is actuated which, in turn, will maintain relays 912 and 921 actuated so that the ground applied to conductor 601 will be effective to grounding the conductors 614 to 617. The relays 912 and 921 being slightly slow-releasing insures that after ground has been received from conductor 616 due to the restoration of the auxiliary selector AS5, they (relays 912 and 921) will sustain until armature 602 has had time to actuate to reenergize it. The storing device is thus guarded against seizure until it is in condition to function normally in a subsequent call as when the elements A13, B13 and C13 100 were employed in the equivalent call to telephone TA.

If it is assumed that at the time the first selector FS2 rotated-in at the 6th level it finds all trunks busy, and therefore operates the cam-spring set CS2, the relay 508 will, in turn, operate to destroy the call extension and apply ground to conductor 684 in the manner before described. However, in the present instance, the shaft 340 (shown in Figs. 6 and 13) is at normal so the 110 off-normal spring set ON13 (shown in Fig. 6) is normal. Under this condition the ground on conductor 684 is applied through armatures 683, 602', off-normal spring 650', armature 651', conductor 652', armature 934, left-hand winding of 115 relay shielded 931, conductor 935, conductor 115', bank contact 607', wiper 634 to grounded battery, relay 931 actuating and locking its right-hand winding to grounded conductor 601. Armature 936 will apply its ground to conductor 118', armatures 120 609' to the winding of relay 610', the latter said relay actuating, armature 612' grounding bar 687 for the object before set forth. When wiper 633 thereafter applied ground to bank contact 680 relay 620' will actuate and lock and relay 610' 125 will deactivate. Wiper 633 will return to bank contact 629 before relay 610' has had time to deactivate so that ground from armature 609' will be applied through armature 625', conductor 626' to bank contact 629 to cause the wiper set 130 631 to 636 to step off-normal wherein wiper 636 will rest upon bank contact 639.

Due to the actuation of relay 931 the ties between bank contacts 639 and 642, attracted armatures 923 to 926 to digit conductors 6, 5, 6 and 135 7, respectively, will be altered to tie bank contacts 639 to 642, armatures 923 to 926, armatures 927 to 930, armatures 938 to 941, spacing conductors 353, 354, digit conductors 5, 7, which lead bank contacts 643 and 644 (in Fig. 6), 805 and 140 807 (in Fig. 8), respectively. Armatures 923 to 926 remaining tied over the traced path to bank contacts 639 to 642, respectively, the equivalent condition now exists as when wipers 342' to 345' were described as set upon bank contacts 348' to 145 351' and relays 105' and 620' were locked actuated. That is to say, bank contacts 639 to 642 are tied to bank contacts 643, 644, 805 and 807, respectively.

When armature 654 retracts following the off- 150

- normal movement of the wiper set 631 to 636, the relays 825 and 827 will energize to initiate the operation of sending the inter-office digit train "57" in the manner before described; to be followed by the sending of the four local digits "7892" under the conditions before described. It will be noted, in this connection, that if the calling party has not annexed the first local digit at the time the relay 620' actuated wiper 7, 6, 3 and 4, and armatures 121 and 123 will tie bank contacts 662 and 669 to digit conductor 2 and conductor 681, armatures 682, 683, conductor 684 and over the traced path to the winding of relay 235 in Fig. 2, to first divert the call to telephone TF and then forthwith disconnect the storing device and the auxiliary selector AS5, in the manner before described wherein the three-letter prefix "FAB" was employed and wherein selector FS2 failed to find an idle trunk in the 6th, 5th, and 4th levels involved in the three inter-office routes provided for calls to the office containing the telephone TA. 80
- 10 620 will be resting on bank contact 628, so that the wiper 633 will encounter ground on bank contact 629 upon its return to normal, independent of the ground applied from conductor 118' by way of armatures 609' and 625'. 85
- 15 If the selector FS2 fails to find an idle trunk in the fifth level and operates the cam-spring set CS2 the relay 508 will be caused to operate effective to restore the selector FS2; deactivate relays 852 and 656; and apply ground over conductor 684 in the manner before described. 90
- 20 The ground applied to conductor 684 may be traced through armatures 631', 602', off-normal spring 650', attracted armature 651', conductor 655', armature 943, left-hand winding of shielded relay 944, conductor 935, bank contact 607', wiper 634 to grounded battery, relay 944 actuating and locking its right-hand winding to conductor 601. Armature 945 will apply its ground to conductor 635', armature 637', to the winding of relay 638', the latter said relay actuating, armature 640' grounding bar 687 for the object before set forth. 95
- 25 When wiper 633 thereafter applies ground to bank contact 680 relay 642' will actuate and lock and relay 638' will deactivate. Wiper 633 will return to bank contact 629 before relay 610' has had time to deactivate, so that ground from armature 637' will be applied through armature 647', conductor 626' to bank contact 629 to cause the wiper set 631 to step off-normal wherein wiper 30 636 will rest upon bank contact 639. Due to the actuation of relay 944 the ties between bank contact 639 to 642, armatures 938 to 941, bank contacts 643, 644, 805 and 807, respectively, will be altered to tie armatures 938 to 941 to digit conductors 4, 4, 5 and 8 leading to bank contacts 804, 804, 805 and 808, in Fig. 8, respectively, the equivalent condition now exists as when wipers 342" to 345" were described as set upon bank contacts 348" to 351" and relays 105', 112', 620' and 642' were locked actuated. That is to say, 105 bank contacts 639 to 642 are tied to bank contacts 804, 804, 805 and 808, respectively. 110
- 35 When armature 654 retracts following the off-normal movement of the wiper set 631 to 636, the relays 825 and 827 will energize to initiate the operation of sending the inter-office digit train 4458 in the manner before described, to be followed by the sending of the four local digits "7892" under the conditions before described. 115
- 40 If the selector FS2 fails to find an idle trunk in the fourth level and operates the cam-spring set CS2 the relay 508 will be caused to operate effective to restore the selector FS2, deactivate relays 852 and 656; and apply ground over conductor 684 in the manner before described. Due to relays 620' and 642' being locked actuated, the ground applied to conductor 684 may be traced through armature 631', conductor 646, spring 131, winding of relay 105, conductor 115', bank contact 607', wiper 634 to grounded battery, relay 105 actuating and locking in the manner before described. The terminals 9a to 9d are now disconnected from bank contacts 639 to 642, respectively, and the armatures 101 to 104 apply 120 the bank contacts 639 to 642 to digit conductors 125
- 45 In foregoing descriptions wherein the selector FS2 operated its cam-spring set CS2 the wiper 634 was then described as resting upon bank contact 607'. It will be clear in view of foregoing statements that if the selector FS2 seized a trunk and that a succeeding inter-office selector of a connection rotated to operate its cam-spring set CS18, CS19 or CS20, as the case may be, due to encountering a busy trunk group, the wiper 634 will be resting upon one of the following four contacts respectively, which are tied to conductor 115', so regardless of any one of the said positions of wiper 634 when a selector of the progressed extension causes the relay 508 to actuate, the selector FS2 and the storing device will function as has been described wherein it was assumed the busy trunk condition was encountered 130 by selector FS2. 135
- 50 Assume that in lieu of the described call from telephone CT to telephone TA the call is now made to telephone TB, the telephone number of which is "DAIry 6789". The present three-letter prefix "DAI" is equivalent to digits "321". It will thus be manifest that the wipers 341 to 345; 342' to 345'; 342" to 345" of elements A13, B13 and C13 will be set upon bank contacts 361 to 365; 362' to 365'; 362" to 365", respectively, responsive 140 to the calling party transmitting the three-letter prefix "DAI". 145
- 55 The stated setting of the elements A13, B13 and C13 will mean that bank contacts 639 to 642 in Fig. 6 are tied to bank contacts 805, 803, 804 and 140 805 in Fig. 8, respectively. Switch-arm 367 will be closed upon its cooperative contact, so that bank contact 361 will be tied over conductor 368 to armature 661' in Fig. 6. Upon relay 105' actuating and locking as will appear presently, the 145 bank contacts 639 to 642 will become alternatively tied to bank contacts 805, 802, 807 and 808, respectively. Upon relay 112' actuating and locking (relay 105' remaining locked), as will appear presently, the bank contacts 639 to 642 will be- 150

come alternatively tied to bank contacts 643 and 644 in Fig. 6, 804 and 802 in Fig. 8, respectively.

In view of foregoing descriptions, the storing device is now set to progress the call over a primary inter-office trunk route involving the 5th, 3rd, 4th and 5th levels of selectors FS2, F, G and H, respectively, to selector I, or over a first preferred alternative inter-office trunk route involving the 5th, 2nd, 7th and 8th levels of selectors FS2, F, V and W to selector L, in case one of the selectors F, G or H fails to find an idle trunk at the level concerned. However, it will appear presently, that if the selector FS2 fails to find an idle trunk in the 5th level when primarily operating the call will be forthwith attempted over a second preferred alternative inter-office trunk route (ignoring the first alternative trunk route), involving the 4th level of selector FS2 and the 2nd level of selector N to selector M; selectors I, L and M having their 6th levels commonly connected to the trunks of the group of which local selector J terminates one thereof. That is to say, if the selector FS2 fails to find an idle trunk F' when operating primarily, the first preferred alternative route which also involves the 5th level of selector FS2 will be ignored and the progression of the call forthwith attempted over the 4th level of selector FS2, trunk N' and 2nd level of selector N to selector M. But if the trunk F' is seized in the primary attempt and the completion of the call over the primary inter-office trunk route is rendered futile by reason of a busy trunk condition beyond, the first preferred alternative trunk route will be next attempted which in the present instance involves the said trunk F' (also concerned in the primary route) as the first link, and a different route beyond. Thus, a wholly new inter-office trunk route will not be involved. In the second attempt, if the first trunk link F' was attained primarily, but if the selector F failed to seize in the primary attempt, or if any succeeding inter-office selector fails to seize in the second attempt, the second preferred alternative inter-office trunk route will be taken. The second preferred alternative inter-office trunk route involves trunk N' in lieu of trunk F' used in the primary and the first preferred inter-office trunk routes. It will be manifest that the bank contacts 362'' to 365'' may be attached otherwise than shown. For example, to digit conductors 5, 6, 3 and 2, respectively to cause the second preferred alternative inter-office trunk route to concern the 5th level of selector FS2 as in the case of the primary and the first preferred alternative routes, but otherwise contemplating an inter-office trunk route not shown in Fig. 26.

It will be noted that while first selector FS2 is rotating-in the wiper 631 is resting upon bank contact 662'. When cam-spring set CS2 operates, causing relay 508 to operate, relay 105' will actuate and lock as before described; followed by the actuation of relay 610' and the application of ground to bar 687. Thus, if relay 610' is caused to actuate before the wiper 631 advances from bank contact 662', a circuit path will be closed from grounded armature on relay 113, wiper 341, bank contact 361, switch-arm 367, conductor 363, armature 661', bank contact 662', wiper 631, off-normal spring 663', conductor 633', upper winding of relay 112', conductor 115', bank contact 607', wiper 634 to grounded battery, relay 112' actuating and locking to conductor 116'. When relay 112' actuates and applies ground over conductor 121', relay 638' will actuate. At this juncture relays 105' and 112' are locked actuated, and

relays 610' and 638' are actuated and the wiper set 631 to 636 is advancing by way of restoring to normal due to the ground on bar 687. When wiper 633 applies ground to bank contact 680, conductor 681, armature 682 to the winding of relay 620' in the manner before described this ground is conducted through armature 664' on relay 638', armature 683 to the winding of relay 642', relay 620' and 642' actuating coincidentally and locking, relays 610' and 638' deactuating thereafter. It will be noted that though both relays 620' and 638' actuated coincidentally responsive to a single grounding of bank contact 680 the effective circuits of the storing device are as if relays 620' and 638' actuated due to separate groundings of bank contact 680 before described wherein the storing device was placed in condition to transmit a prefix train corresponding with the second alternative inter-office trunk route. That is, in the present instance, the first preferred alternative inter-office trunk route will not be attempted, but that the second preferred alternative inter-office trunk route will be next attempted. If a selector in the second preferred alternative inter-office trunk route encounters a busy trunk group whereby relay 508 will actuate to cause ground to be applied from wiper 633 to bank contact 680 the said ground will be applied through armatures 682, 683, 631', conductors 646' to actuate relay 105 for the object set forth. 105

If it is assumed that the first selector FS2 seized trunk F' in the said call to telephone TB, but that one of selectors F, G or H failed to seize and therefore operated its cam-spring set corresponding to CS18, CS19 or CS20, respectively, the wiper 631 will have advanced from bank contact 662'. Under this condition the circuit path including armature 661' and conductor 633' to the upper winding of relay 112' will not be closed so relay 105' only will actuate and lock, followed by the actuation of relay 610' and the restoration of the wipers 631 to 636 because of the grounding of bar 687. When wiper 634 grounds bank contact 680 the relay 620' will actuate and relay 610' will deactuate preparatory to causing relays 112' and 638' to actuate in the event any selector FS2, F, V or W encounters all trunks as busy whereby relay 508 will actuate and apply ground over conductor 684, armatures 631', 602', off-normal spring 603', armature 604', conductor 633' to the winding of relay 112'. The latter said relay will actuate and lock, followed by the actuation of relay 642' consequent to wiper 633 applying ground to bank contact 680, in the manner now clear. The call will now be progressed over the said second preferred alternative inter-office trunk route. If any of the linking selectors concerned in the latter said route fail to find and seize an idle trunk, so that relay 508 will be caused to actuate because thereof, the wiper set 631 to 636 will be caused to restore and relay 105 will operate for the object set forth. 120 125 130 135

The descriptions relating to the call to telephone TB have specifically concerned the inter-office trunk routes, but in view of previous descriptions it will be understood that the calling party will annex the local digits forthwith following the transmitting of the prefix letters, the storing device then transmitting the said local digits effective to selectors I, L or M and J and connector K to complete the call only after an inter-office connection to a said selector I, L or M has been completed, the sending and storing of the local digits being independent of the func- 140 145 150

tioning of the storing device in completing the connection to an incoming selector I, L or M.

The call from calling telephone CT to called telephone TB having been described wherein the 5 three-letter prefix "DAI" was sent, followed by the four local digits "6789", the said call will now be described wherein the name prefix "Dairy", corresponding to the single digit prefix "7", is alternatively sent. Under this condition the auxiliary selector AS5 will rotate-in at the 7th bank level in lieu of the 3rd, wiper 513 encountering permanently grounded bank contact 575. This will cause the set of wipers 513 to 516 to advance an additional step. Wiper 513 10 is now in engagement with bank contact 548 as assumed to be ungrounded due to an idle condition of the concerned storing device, so that the auxiliary selector AS5 will seize. In view of previous descriptions, wiper 513 will forthwith 15 ground bank contact 548; same being extended over conductor 617, winding of slightly slow-releasing relay 948, make-before-break spring 949, conductor 904, armatures 905 to 909 to grounded battery, relay 948 actuating wherein 20 battery derived through the winding of relay 912 is applied through spring 949 before the path through spring 909 is opened at armature 905, to sustain relay 948 actuated, relay 912 actuating. The actuation of relay 912 causes the guarding 25 of the storing device as before set forth.

Bank contacts 639 to 642 are now tied through terminals 9a, 9b, 9c and 9d, armatures 952 to 955 on relay 948, armatures 956 to 959 on shielded relay 960, digit conductors 5, 3, 4 and 5 to 30 bank contacts 805, 803, 804 and 805, respectively. Armature 961 grounds conductor 933 for the object set forth, so that wipers 619, 620 and 622 will now rest upon bank contacts 627, 628 and bar 688, respectively. A circuit path can be 35 traced from armature 510, armature 511, wiper 514 and engaged bank contact, conductor 560, winding of relay 618, wiper 619, bank contact 627, conductor 645, relay 701 to the stepping magnet 702. A circuit can be traced from the 40 lower winding of relay 550, armature 551, wiper 515, bank contact 574, conductor 552 to grounded armature 800, relay 550 actuating. An open circuit traced path leading from the winding of 45 relay 235 can be traced through wiper 516 and 50 its engaged bank contact, to bank contact 680.

Upon grounded wiper 620 engaging bank contact 628 the initiation of the sending of the primary inter-office digit train "5345" will occur. If relay 508 actuates while wiper 631 is resting 55 upon a bank contact successive to 662' (not shown) ground from conductor 684 will be applied through armatures 683, 602', off-normal spring 650', armature 651', conductor 652', armature 963, left-hand winding of relay 960, conductor 935, one of the bank contacts successive to 607' engaged by wiper 634 to grounded battery; relay 960 actuating and locking to right-hand winding to conductor 601. Armature 964 will apply its ground over conductor 118', armature 609' to the winding of relay 610' and through 65 armature 612' to bar 687, the relay 610' actuating and the element ND6 operating to restore its wipers.

Due to the attracted state of armatures 956 to 70 959, bank contacts 639 to 642 are now tied through armatures 952 to 955, 956 to 959, 966 to 969 of shielded relay 970 to digit conductors 5, 2, 7 and 8, leading to bank contacts 805, 802, 807 and 808, in lieu of to bank contacts 805, 803, 804 75 and 805, respectively. The set-up condition now

existing concerns the first preferred alternative inter-office trunk route, the storing device operating as when a similar setting was effected by the actuation of relay 105', whereby an attempt is now automatically made to progress the call over the latter said route. If a busy trunk condition is found whereby relay 508 will actuate, regardless of which contact 607', or any successive one, the wiper 634 is then resting upon, ground applied over conductor 684 will be conveyed through armatures 631', 602', off-normal spring 650', armature 651', conductor 655', armature 971, left-hand winding of relay 970, conductors 935, 115', wiper 634 to grounded battery, relay 970 actuating, its right-hand winding locking to conductor 601. Armature 972 applies its ground to conductor 635', armature 637' to the winding of relay 638' the latter said relay actuating and the element ND6 operating to restore its wipers as described. When wiper 633 grounds bank contact 680 this ground will be conducted over conductor 681, armatures 682, 683 to the winding of relay 642', the latter said relay actuating and locking. 85 90 95

Due to the attracted state of armatures 966 to 969 bank contacts 639 to 642 are now tied to spacing conductors 353, 354, digit conductors 4 and 2 leading to bank contacts 643, 644, 804 and 802, in lieu of bank contacts 805, 802, 807 and 808, respectively. The set-up condition now existing concerns the second preferred alternative inter-office trunk route, the storing device operating as when a similar setting was effected by the actuation of relay 112', whereby an attempt is now made to progress the call over the latter 105 said route. If a busy trunk condition is found whereby relay 508 will actuate, regardless of which contact 607', or any successive one the wiper 634 is then resting upon, ground applied over conductor 684 will be conveyed through 110 armature 631', conductor 646', to actuate and lock relay 105 for the object set forth. 115

In this connection it will be noted, that if first selector FS2 operates the cam spring set CS2 when attempting to extend the call over the primary route, at which time wiper 631 is resting upon bank contact 662', the ground applied over conductor 684 will be applied through armatures 683, 602', off-normal spring 650', armature 651', conductor 652', armature 963, left-hand winding of relay 960, conductors 935, 115', bank contact 607', wiper 634 to grounded battery, relay 960 actuating and locking. Armature 973 applies its ground to terminal 9e on conductor 368 shown in Figs. 9 and 10. Ground from armature 964 is applied over conductor 118', armature 609' to the winding of relay 610', the latter said relay actuating. Ground on terminal 9e will traverse armature 625', bank contact 662', wiper 631, off-normal spring 672', armature 971, left-hand winding of relay 970, conductors 935, 115', bank contact 607', wiper 634 to grounded battery, relay 970 actuating and locking. Armature 972 will apply its ground over conductor 635', armature 637' to the winding of relay 638', the latter 130 135 140 said relay actuating. Relays 610' and 638' are actuated while relays 620' and 642' are normal. However, as bar 687 is grounded, the wipers of element ND6 will restore, wiper 633 incidentally applying ground to bank contact 680, conductor 681, armature 682 to the winding of relay 620' and armatures 664', 683 to the winding of relay 642', the relays 620' and 642' actuating and locking, the relays 610' and 638' thereafter deactuating. It is thus clear that the storing 145 150

device is now set in accordance with forthwith progressing the call over the second preferred alternative inter-office trunk route wherein the first preferred alternative trunk route has been 5 ignored for the reasons set forth. If, when the call is again progressed in accordance with the ensuing setting, and encounters a busy trunk group ground applied over conductor 684 will be conducted through armature 631', conductor 646' 10 to operate relay 105 for the object set forth. In view of foregoing descriptions, it is thought that the operation of the system wherein a call is made from telephone CT to TC, the telephone number of which is "FADist—4567", will be manifest. Suffice it to state that responsive to the calling party sending the three-letter prefix "FAD", corresponding to digits "323", the elements A13, B13 and C13 will have their wipers 15 341 to 345, 342' to 345' and 342'' to 345'' set 20 upon the respective bank positions designated 323, 323' and 323'' in Fig. 13. It will follow that bank contacts 639 to 642 are tied to bank contacts 804, 804, 805 and 806 so that the primary inter-office trunk route will be over the 4th level 25 of first selector FS2, repeater C26, trunk N', 4th level of selector N, repeater D26, 5th level of selector O, repeater E26, selector P, repeater N26 to selector Q. If any trunk group is encountered busy whereby relay 105' will actuate and 30 lock, and in view of the functioning of the element ND6 responsive thereto, the call will now be progressed over the first preferred inter-office trunk route determined by the setting of element B13. Bank contacts 639 to 642 are now tied to 35 bank contacts 806, 805, 806 and 805, respectively, in lieu of as ensued before the actuation of relay 105', so that the first preferred alternative said route will be over the 6th level of first selector FS2, repeater R18, trunk S18', 5th level of selector S18, repeater R19, 6th level of selector S19, 40 repeater R20, 5th level of selector S20, repeater O26 to selector T. If any trunk group is encountered busy whereby relay 112' will actuate and lock, and in view of the functioning of the element ND6 responsive thereto, the call will 45 now be progressed over the second preferred inter-office trunk route determined by the setting of element C13. Bank contacts 639 to 642 are now tied to bank contacts 805, 803, 804 and 50 804, respectively, in lieu of as ensued before the actuation of relay 112', so that the second preferred alternative said trunk route will be over the 5th level of first selector FS2, repeater A26, trunk F', 3rd level of selector F, repeater H26, 55 4th level of selector G, repeater I26, 4th level of selector H, repeater P26 to selector U. If any trunk group is encountered busy whereby relay 105 will actuate the call will be routed through the 7th level of first selector FS2, repeater G26, 60 trunk A' to selector A and to the attendant's station or one of the switchboard jacks, depending upon the setting of switch-arms 137, 140 and 141. Assume a call from telephone CT to telephone 65 TD, the telephone number of which is "FEDeral—2345". Responsive to sending the three-letter prefix "FED", corresponding to digits "332", the elements A13, B13 and C13 will have their wipers 341 to 345, 342' to 345' and 342'' to 345'' set 70 upon the respective bank positions designated 332, 332' and 332'' in Fig. 13. It will follow that bank contacts 639 to 642 are tied to bank contacts 643, 644, 675' and 803 wherein bank contact 370 in Fig. 13 is tied over spacing conductor 75 371 to bank contact 675'. The primary inter-office trunk route will thus be over the 3rd level of first selector FS2, repeater Q26, trunk Y' to selector Y. If the trunk group represented by trunk Y' is encountered as busy whereby relay 105' will actuate and lock, and in view of the functioning of the element ND6 and the destroying of the futile connection responsive thereto, the call will now be progressed over the first preferred alternative inter-office trunk route determined by the setting of element B13. Bank contacts 639 to 642 are now tied to bank contacts 643, 806, 805 and 804, respectively, in lieu of as ensued before the actuation of relay 105', so that the first preferred said alternative route will be over the 6th level of first selector FS2, repeater R18, trunk S18', 5th level of selector S18, repeater R19, 4th level of selector S19, repeater R26 to selector b. If any trunk group is encountered busy whereby relay 112' will actuate and lock, and in view of the functioning of the element ND6 and the destroying of the futile connection, responsive thereto, the call will now be progressed over the second preferred inter-office trunk route determined by the setting of element C13. Bank contacts 639 to 642 are now tied to bank contacts 805, 803, 804 and 802, respectively, in lieu of as ensued before the actuation of relay 112', so that the second preferred alternative said trunk route will be over the 5th level of first selector FS2, repeater A26, trunk F', 3rd level of selector F, repeater H26, 4th level of selector G, repeater I26, 2nd level of selector H, repeater S26 to selector c. If any trunk group is encountered busy, whereby relay 105 will actuate, the call will be routed as before set forth. In case no busy trunk group is encountered in any of the inter-office trunk routes attempted, the local digits will be re-sent from the storing device in the manner now clear to complete the connection.

Before proceeding with the descriptions relating to the employment of the alternative calling single digit prefix "O", used in lieu of the three-letter prefix "FED", attention is called to Fig. 14 wherein relays 401' to 405' and 411' to 415' are shown legged from the private conductors of the "1" level and the "normal" level of first selector FS2, respectively. The said private conductors are multiplied into bank contacts accessible to first selector FS4 and other first selectors of the group containing said FS2 and FS4. The "1" and "normal" levels of the said selectors may contain more or less than the five indicated trunks shown in Fig. 14; ten or more possibly. It will be noted that if all the trunks of the "1" level are busy-grounded, ground 421' will be chained to common conductor 422', and if all the trunks of the "normal" level are busy-grounded, ground 425' will be chained to common conductor 426'. Common conductors 422' and 426' attached to bank contacts 578 and 579 accessible to wiper 513 of auxiliary selector AS5 at the first off-normal position at the "0" and "normal" levels, respectively. It is thus clear that if all the trunks of the "1" level accessible from first selector FS2 are busy, the ground 421' will be chained to conductor 422' leading to bank contact 578 and multiples correspondingly accessible from other auxiliary selectors of the group containing selector AS5. Also, if all the trunks of the "normal" level accessible from first selector FS2 are busy, the ground 425' will be chained to conductor 426' leading to bank contact 579. That is to say, if all trunks of the "1" level accessible from selectors FS2, FS4 and other selectors of its group are

busy, the selector AS5 will be caused to advance wiper 513 from bank contact 578 and test the succeeding contact 545 if operated with respect to the "0" level. Also, if all trunks of the "normal" level accessible from first selectors FS2, FS4 and other selectors of their group are busy, the auxiliary selector AS5 will be caused to advance wiper 513 from bank contact 579 and test the succeeding contact 546 if operated with respect to the "9" level.

It will appear presently, that if the wiper 513 does not find a barred condition when testing bank contact 578 or 579, there will be no storing device concerned and the call will be automatically extended over the "1" or "normal" level of first selector FS2, respectively, the successive links of the connection being seized responsive to direct directive control from the finger-hole dial of the calling device. However, if a said barred condition is encountered by wiper 513, a storing device will be selected which will automatically progress the call over a first preferred alternative inter-office trunk route, and if a busy trunk condition is encountered to then re-progress the call over a second preferred inter-office trunk route, and if a busy trunk condition is again encountered to then re-progress the call to an attendant's switchboard or station.

It will be assumed the calling party sent the prefix digit "O" in lieu of the three-letter prefix "FED". The shaft 581 of the auxiliary selector AS5 will be raised into alignment with the "0" level and there rotate-in. Incidental to the shaft attaining the 9th level spring set 582 will operate from the shaft cam 583 closing a path from ground, armature 584, said spring set 582 to the upper winding of relay 550, the latter said relay being maintained energized dependent upon the retracted state of armature 584 or the restoration of the shaft 581. When the last ground impulse of the "0" series is imparted to the vertical magnet VM5, this ground will be also applied through armature 585, conductor 586, armature 281, winding of relay 240 to the vertical magnet VM2, effective to raise the shaft of first selector FS2 so its wipers align with the first off-normal level and there rotate-in following the retraction of armature 283, the latter said armature having previously applied ground through off-normal springs to the winding of relay 245 to actuate and lock the said relay 245 coincident with energizing the vertical magnet VM2. The first idle trunk Y' leading to selector Y will be seized.

The armature 518 retracts following the aligning of the wipers 513 to 516 with the "0" level, the rotary magnet RM5 operating as set forth to cause the first set of bank contacts to be engaged. That is, the wipers of first selector FS2 align with the "1" level of bank contacts coincident with the wipers of auxiliary selector AS5 aligning with the "0" level of bank contacts. It follows that the respective said wiper sets will coincidently rotate-in. If it is assumed that bank contact 578 does not constitute ground potential the auxiliary selector will seize thereat, whereupon a circuit can be traced from grounded bank contact 587, wiper 516, armatures 563, 564, conductor 565, armature 232, conductor 233, spring 234 to the winding of relay 235, the latter said relay actuating and locking to conductor 209. Relay 212 is thus energized in series with the calling line without deactuating said relay 212, which actuated responsive to the actuation of relay 550. Relay 501 will deenergize to cause the restoration of auxiliary selector AS5 and the

deactuation of relay R2, which latter function unbars the other first selectors embraced by auxiliary selector AS5.

The first selector FS2 will seize the first idle trunk Y' in the "1" level leading to selector Y, in the manner before described. However, in the present instance, the relay 235 is actuated so that upon the calling party annexing the four local digits "2345", the selectors Y and Z, and the connector a will operate under direct directive control of the finger-hole dial on the calling telephone, completing the call to called telephone TD, while the auxiliary selector AS5 is subject to use in another call.

Having in mind that the "1" level of first selector FS2 concerns the primary inter-office trunk route, and assuming the trunks of the said level (and its commoned 3rd level) are all busy, under which condition bank contact 578 (as well as the corresponding bank contact of all auxiliary selectors embracing first selectors having access to the trunk group represented by Y') constitutes ground, the wiper 513 will automatically rotate-off bank contact 578 and similarly test bank contact 545. It will be assumed the storing device is idle and therefore bank contact 545 is ungrounded. The auxiliary selector AS5 will thus seize the storing device.

In this connection it will be remembered that the shaft cam 588 operates the spring set 540 at the first rotary off-normal step at the "9" and "0" levels. Thus, when the bank contact 578 was seized wherein armature 527 attracted, ground cannot be falsely applied from conductor 507 to wiper 513 to ground conductor 422' and attached bank contacts corresponding to 578. Also, when the bank contact 578 is encountered grounded and wherein relay 519 will re-actuate to cause the wiper 513 to advance to select a storing device to progress the call over a level (6 or 5) other than the "1" level of first selector FS2, a circuit will be closed from ground, armature 589, spring of set 540, conductor 571, armatures 262, 263, off-normal spring 265 to the release magnet Re2, to restore the shaft of first selector FS2 in readiness to be re-operated under the automatic control of the selected storing device.

Returning to the condition which ensues upon bank contact 545 being seized, ground from conductor 507 will be applied through spring of set 540, armature 527, wiper 513, bank contact 545, conductor 614, winding of slightly slow-releasing relay 974, make-before-break spring 975, conductor 904, armatures 905 to 909 to grounded battery, the relay 974 actuating, wherein battery derived through the winding of relay 912 is applied through spring 975 before the path through spring 909 is opened at armature 908 to sustain relay 974 actuated; relay 912 actuating. The actuation of relay 912 causes the guarding of the storing device as before set forth.

Bank contacts 639 to 642 are now tied through terminals 9a, 9b, 9c and 9d, armatures 976 to 979 on shielded relay 974, armatures 980 to 983 on shielded relay 984, spacing conductor 653 and digit conductors 6, 5 and 4 to bank contacts 643, 806, 805 and 804, respectively. Armature 985 grounds conductor 933 for the object set forth, so that wipers 619, 620 and 622 will now rest upon bank contacts 627, 628 and bar 688, respectively. A circuit path can now be traced from armature 510, armature 511, wiper 514 and engaged bank contact, conductor 560, winding of relay 618, wiper 619, bank contact 627, conductor 645, relay 701 to the stepping magnet 702. A circuit

can be traced from the lower winding of relay 550, armature 551, wiper 515, bank contact 590, conductor 552 to grounded armature 800, relay 550 remaining actuated. An open circuit path 5 leading from the winding of relay 235 can be traced through wiper 516 and its engaged bank contact, to bank contact 680. Due to bank contact 639 being tied to bank contact 643 the wipers will automatically advance to the second 10 off-normal position.

Upon grounded wiper 620 engaging bank contact 628 the initiation of the sending of the first preferred alternative inter-office digit train "654" will occur. If relay 508 actuates while wiper 634 15 is resting upon bank contact 657' or any successive one, ground from conductor 684 will be applied through armatures 683, 602', off-normal spring 650', armature 651', conductor 652', armature 986, left-hand winding of relay 984, conductor 935, the bank contact engaged by wiper 634 to grounded battery; relay 984 actuating and locking its right-hand winding to conductor 601. Armature 987 will apply its ground over conductor 118', armature 609' to the winding of relay 25 610' and through armature 612' to the winding of relay 610' and through armature 612' to bar 687, the relay 610' actuating and the element ND6 operating to restore its wipers.

Due to the attracted state of armatures 980 30 to 983, bank contacts 639 to 642 are now tied to digit conductors 5, 3, 4 and 2, leading to bank contacts 805, 803, 804 and 802, in lieu of bank contacts 643, 806, 805 and 804, respectively. The set-up condition now existing concerns the second 35 preferred alternative inter-office trunk route, the storing device operating as when a setting for progressing a call over a first preferred alternative inter-office trunk route was effected by the actuation of relay 105', whereby an attempt 40 is now automatically made to progress the call over the second said route. It will be noted that due to armature 988 being attracted, terminals 9h and 9i (shown in Figs. 9 and 6) are tied. Thus, if a busy trunk condition is found whereby relay 45 508 will actuate, regardless of which bank contact the wiper 634 is then resting upon, ground applied over conductor 684 will be conveyed through armature 683, armature 988 in Fig. 9, conductor 646' to actuate and lock relay 105 for 50 the object set forth, relay 638' and 642' remaining normal.

In this connection it will be noted that when the three-letter prefix "FED" was sent, the primary route involved the 3rd level of first selector 55 FS2 and when the single digit prefix "O" was sent, the primary route involved the 1st (off-normal) level, the said 3rd and 1st levels being common to the same group of trunks Y'. The object of this arrangement is in view of the cam-spring set CS2 not being operated from the normal or 1st off-normal level wherein the storing device is not concerned after the first selector FS2 rotates-in. Under this condition if a busy trunk condition should occur after the testing of 60 the level (normal or 1st) starts no reversal of the current in the calling line will take place if the selector fails to find an idle trunk so a false operation of a call register or supervisory device on the calling line cannot occur. The relays 65 401' to 405' and 411' to 415' thus, in fact, concern the privates of the 1st and 3rd, and the normal and 2nd levels commonly respectively.

Assume a call from telephone CT to telephone TE, the telephone number of which is "EDIor—75 2346". Responsive to sending the three-letter

prefix "EDI" corresponding to digits "331" the elements A13, B13 and C13 will have their wipers 341 to 345, 342' to 345' and 342'' to 345'' set upon the respective bank positions 331, 331' and 331'' in Fig. 13. Assuming that switch-arm 372 is closed, a circuit path can be traced from grounded wiper 341, bank contact 373, switch-arm 372, conductor 681, armatures 682, 683, conductor 684, bank contact 534, engaged wiper 516, armatures 563, 564, and over the traced path to the windings of relays 235 and 245, the latter said relays actuating. Relay 212 will thus become energized in series with the calling line and the rotary magnet RM2 will energize from conductor 209, armatures 283 and 284, the shaft of first selector FS2 forthwith rotating-in on the normal level and select the first idle trunk d' leading to selector d. The inter-office trunk route will thus be over the "normal" level of first selector FS2, repeater T26, trunk d' to selector d. In view of relay 235 having actuated the auxiliary selector AS5 will restore to disengage the storing device. The first selector FS2 will seize a trunk before the calling party will have released the finger-hole dial to send the first local digit "2", so the selector d will be directly directly operated from the said dial. The selector e and the connector g will then be operated responsive to the last three local digits, completing the connection. Under the condition last described, if the selector FS2 fails to find an idle trunk, due to a busy trunk condition there will be no alternative inter-office trunk route alternatively taken, it being remembered that the normal and 1st levels will preferably reserve for short trunk lengths where ample margin of idle trunks will exist.

Having in mind that the group of trunks d' are accessible from the 2nd and "normal" levels, commonly, if it is desired to have the alternative inter-office trunk routes available when sending the three-letter prefix "EDI", the switch-arm 372 will be opened. Bank contacts 639 to 642 are tied through wipers 342 to 345 to bank contacts 643, 644, 675', and 802. The primary inter-office trunk route will thus now be over the 115 2nd level of first selector FS2, repeater T26, trunk d' to selector d. If the trunk group represented by d' is encountered as busy by first selector FS2 and cam-spring set CS2 is operated, whereby relay 105' will actuate and lock, and in view of the functioning of the element ND6 and the restoration of first selector FS2 responsive thereto, the call will now be progressed over the first preferred alternative inter-office trunk route determined by the setting of element B13. 130 Bank contacts 639 to 642 are now tied to bank contacts 806, 805, 806 and 806, respectively, so that the first preferred said alternative route will be over the 6th level of first selector FS2, repeater R18, trunk S18', 5th level of selector S18, repeater R19, 6th level of selector S19, repeater R20, 6th level of selector S20, repeater U26 to selector h. If any trunk group is encountered busy whereby relay 112' will actuate and lock, and in view of the functioning of the element ND6 140 and the restoration of first selector FS2 responsive thereto, the call will now be progressed over the second preferred alternative inter-office trunk route determined by the setting of element C13. Bank contacts 639 to 642 are now tied to bank contacts 804, 804, 805 and 805, respectively, in lieu of as ensued before the actuation of relay 112', so that the second preferred alternative said trunk route will be over the 4th level of first selector FS2, repeater C26, trunk N', 4th 150

- level of selector N, repeater D26, 5th level of selector O, repeater E26, 5th level of selector P, repeater V26 to selector i. If any trunk group is encountered busy whereby relay 105 will actuate, the call will be routed as before set forth. In case no busy inter-office trunk group is encountered in any of the inter-office trunk routes attempted the local digits will be re-sent from the storing device in the manner now clear.
- 10 It will be assumed the calling party sent the single prefix "9" in lieu of the three-letter prefix "EDI". The shaft 581 of the auxiliary selector AS5 will be raised so its wipers align with the "9" level and there rotate-in. If it is assumed that bank contact 579 does not constitute ground the latter said selector will seize thereat, ground being applied from bank contact 591, wiper 516, armatures 563, 564, conductor 565 and over the traced path to the windings of relays 235 and 245, the latter said relays actuating, causing the first selector FS2 to rotate-in at its normal level the auxiliary selector FS3 to restore as before described, subject to use in another call. Relay 212 is energized in series with the calling line without deactuating said relay 212 which actuated responsive to the actuation of relay 550 when the spring set 582 operated consequent to the wipers on shaft 581 aligning with the 9th level.
- 15 The first selector FS2 will seize the first idle trunk d' in the normal level leading to selector d, in the manner before described. However, in the present instance, the relay 235 is actuated so that upon the calling party annexing the four local digits "2346" the selectors d and e and the connector g will operate under direct directive control of the finger-hole dial on the calling telephone, completing the call to called telephone TE.
- 20 Having in mind that the normal level of first selector FS2 concerns the primary inter-office trunk route, and assuming the trunks of the said level (and its commoned 2nd level) are all busy, under which condition bank contact 579 constitutes ground, the wiper 513 will automatically rotate-off bank contact 579 and similarly test bank contact 546. It will be assumed the storing device is idle and therefore bank contact 546 is ungrounded. The auxiliary selector will thus seize the storing device. Ground from conductor 597 will be applied to through wiper 513 to bank contact 546, conductor 615, winding of relay 989, make-before-break spring 990, conductor 904, armatures 905 to 909 to grounded battery, the relay 989 actuating, wherein battery derived through the winding of relay 912 is applied through spring 990 before the path through spring 909 is opened at armature 907 to sustain relay 989 actuated; relay 912 actuating. The actuation of relay 912 causes the guarding of the storing device as before set forth.
- 25 Bank contacts 639 to 642 are now tied through terminals 9a, 9b, 9c and 9d, armatures 991 to 994 on shielded relay 989, armatures 995 to 998 on shielded relay 999, digit conductors 6, 5, 6 and 6 to bank contacts 806, 805, 806 and 806, respectively. Armature 900 grounds conductor 933 for the object set forth, so that wipers 619, 620 and 622 will now rest upon bank contacts 627, 628 and bar 688, respectively. A circuit path can now be traced from armature 510, armature 511, wiper 514 and engaged bank contact, conductor 560, winding of relay 618, wiper 619, bank contact 627, conductor 645, relay 701 to the stepping magnet 702. A circuit can be traced from the lower winding of relay 550, armature 551, wiper 515, bank contact 590, conductor 552 to grounded armature 800, relay 550 remaining actuated. An open circuit path leading from the winding of relay 235 can be traced through wiper 516 and its engaged bank contact, to bank contact 680.
- 30 Upon grounded wiper 620 engaging bank contact 628 the initiation of the sending of the first preferred alternative inter-office digit train "6566" will occur. If relay 508 actuates while wiper 634 is resting upon bank contact 607' or any successive one, ground from conductor 684 will be applied through armatures 683, 602', off-normal spring 650', armature 651', conductor 652', armature 901'', left-hand winding of shielded relay 999, conductor 935, the bank contact engaged by wiper 634 to grounded battery; relay 999 actuating and locking its right-hand winding to conductor 601. Armature 902'' will apply its ground over conductor 118', armature 609' to the winding of relay 610' and through armature 612' to bar 687, the relay 610' actuating and the element ND6 operating to restore its wipers.
- 35 Due to the attracted state of armatures 995 to 998, bank contacts 639 to 642 are now tied to digit conductors 4, 4, 5 and 5 leading to bank contacts 804, 804, 805 and 805, respectively. The set-up condition now existing concerns the second preferred alternative inter-office trunk route, the storing device operating as when a setting for progressing a call over a first preferred alternative inter-office trunk route was effected by the actuation of relay 105', whereby an attempt is now automatically made to progress the call over the second alternative route. It will be noted that due to armature 903'' being attracted, terminals 9h and 9i are tied. Thus, if a busy trunk condition is found whereby relay 508 will actuate, regardless of which contact the wiper 634 is then resting upon, ground applied over conductor 684 will be conveyed through armature 683, armature 903'' in Fig. 9, conductor 646' to actuate and lock relay 105 for the object set forth, relays 638' and 642' remaining normal.
- 40 In this connection it will be noted that when the three-letter prefix "EDI" was sent, the primary route involved the 2nd level of first selector FS2 and when the single digit prefix "9" was sent the primary route involved the normal level, the said 2nd and normal levels being common to the same trunks d'.
- 45 It has been stated that the 3rd and 1st levels, and the 2nd and normal levels of first selector FS2 are common to the same trunks represented by Y' and d', respectively. However, it will be understood that while the trunks of the said commoned trunks may belong to the same major group, each level of a pair of said commoned levels may contain a sub-group so that the identical trunks may not be accessible from two different levels, though the two sub-groups of trunks will extend to the same group of incoming selectors in the originating office or a remotely located office. This is the preferred method of connecting the trunks in the normal, 1st, 2nd and 3rd levels.
- 50 It will be noted that if the trunks of the normal or the 1st level accessible from selector FS2 are out-of-order, example, the corresponding switch n or m may be closed to falsely bar the corresponding trunk group, and the auxiliary selector, such as AS5 will then select a storing device which will cause a different group of trunks to be selected over than contained in the normal and 1st levels when operated with 150

relation to the "9" or the "0" level, as the case may be.

In the foregoing descriptions the calling telephone CT and the first selector FS2 was concerned. A call from telephone T3 through line-switch PL3, secondary lineswitch SL3 and first selector FS4 will be clear in view of the descriptions, having in mind that corresponding elements concerned in the latter call have index 10 characters which correspond to the elements shown in Figs. 1 and 2, but with numerical reference to Figs. 3 and 4. If a call has been initiated from telephone CT or T3 and the relay 235 or 435, as the case may be, has not operated, a secondary lineswitch seized thereafter will itself seize a first selector not embraced by auxiliary selector AS3. It will seize one commonly accessible with auxiliary selector AS3 to a group of storing devices.

Attention is called to the fact that the conductor leading from the make contact of armature 567 can be preferably attached to a wiper not shown in lieu of to the conductor leading to wiper 516. The first said wiper (not shown) will cooperate with bank contacts (not shown) which are companion to the bank contacts engageable from wiper 516. The conductor 685 will then lead to the bank contact engaged by the said added wiper coincident with wiper 516 engaging a bank contact attached to conductor 684. The condenser c6 will be removed. Under this arrangement alternating current from source Ge5 through armature 567 will be applied to the lower winding of relay 35 656 and the upper winding of relay 852 without other attachments, such as the various shielded relays when locked actuated. Under this preferred arrangement the said shielded relays may be non-shielded. The shielded relays 40 in Fig. 9 are shown slugged, but it will be understood that the shield alone will render the said relays slow-releasing.

In the exemplified system, three trunk routes between a calling and called line have been assumed. It will, of course, be understood that a less number or that a greater number of routes may be employed for all calls or a portion of them only, depending upon the location, and other conditions attending. For example, if the 45 prefix "EDI" (corresponding to "331") refers to a call in which but one alternative route is provided, the bank contact of set "331" in element C13 adapted to be engaged by wiper 342' will be attached to conductor 359. Then, if the 50 first alternative route appertaining to the said prefix is found busy, the relay 105 will be caused to actuate to divert the call to an attendant or an operator, in the manner described, in place of making a third attempt to complete the 55 call over the second alternative route as described wherein the bank contacts of set "331" refer to digit conductors. In the same manner, if no alternative route were provided, the bank contact of set "331" adapted to be engaged by wiper 342' will be attached to conductor 359. Then, if the 60 primary route appertaining to the said prefix is found busy, the relay 105 will be caused to actuate to divert the call to an attendant or an operator, in the manner described, in place of making a second attempt to complete the 65 call over the first alternative route as described wherein the bank contacts of set "331" refer to digit conductors. In this connection, if but one alternative route is 70 described, in place of making a second attempt to complete the call over the first alternative route as described wherein the bank contacts of set "331" refer to digit conductors. In this connection, if but one alternative route is 75 provided the make contact of armature 995 in Fig.

9 will be attached to conductor 359, and if no alternative route were provided the make contact of armature 991 will be attached to conductor 359. Of course, in the latter case, relay 999 would not be installed.

In the exemplified system primary and secondary line-switches have been shown for automatically extending an initiated call to a trunk line embraced by an auxiliary selector AS5. It will be manifest that the primary lineswitches may have direct access to the said trunk lines, obviating the employment of the secondary lineswitches. Also, in lieu of seizing the said trunks through the agency of lineswitches, so-called finderswitches may be provided individual to each said trunk line and the finderswitches of the respective trunks then adapted to hunt in predetermined order to seize a calling line.

In Fig. 13 three independent shafts and corresponding sets of operating magnets are provided. It will be manifest that a single shaft operated by one set of magnets and carrying the three sets of wipers may be alternatively employed.

In the exemplified calls the first letter of the 100 three-letter prefixes all referred to the "3" finger-hole, but it will be manifest that any of the finger-holes 1 to 6 may correspond to the first pull to select a respective storing device corresponding to the 1st to the 6th level accessible 105 from the auxiliary selector AS5. Under the assumed condition fingerholes 1 to 6 involve a total 16 letters, so that any number of offices beginning with any of said 16 indicated letters may be employed so long as the second and also the third 110 letters of the prefixes for any two offices do not correspond to the same finger-hole. It will be manifest that other holes than have been may be converted to the alternative named finger-hole calling.

Adaptations of the system of the present invention exemplified may be made in applying principles thereof to various forms of systems of the general type to which it belongs, regardless of other operative features of the system being different from those of the exemplified system, without departing from the scope of the invention as defined by the broadest interpretation of the subjoined claims.

I claim:—

1. In an automatic telephone system, a calling and a called line, a trunk route between the calling and called lines, the route made up of a plurality of trunk links having terminating switches respectively, the trunks belonging to a corresponding plurality of trunk groups, a storing device, a dial on the calling line, means for initiating a call and for selecting the storing device, means whereby thereafter operating the dial will set-up a condition in the storing device for automatically directing the extension of a connection from the calling line towards the called line over one of said plurality of trunk links, means for then operating the terminating switch on the trunk link with selective relation to a said group of trunks, automatically applied means then made operative to test for and seize the first idle trunk tested of the group, means for arresting the directive operation of the storing device for only a predetermined period before again directly operating to further advance the call to permit the said operated switch to selectively seize a succeeding trunk of the latter said group, and means controlled over the call extension for initiating the directive operation of the storing device be- 150

- fore the termination of said predetermined period to further progress the connection consequent to the switch selecting an idle trunk link. 80
5. 2. In an automatic telephone system, a calling and a called line, a trunk route between the calling and called lines, the route made up of a plurality of trunk links having terminating switches respectively, the trunks belonging to a corresponding plurality of trunk groups, a storing device, a dial on the calling line, means for initiating a call and for selecting the storing device, means whereby thereafter operating the dial will set-up a condition in the storing device for automatically directing the extension of a connection from the calling to the called line over one of said plurality of trunk links, means for operating the terminating switch on the trunk link with relation to a group of trunks and for 85 arresting the directive operation of the storing device for a predetermined period before again directly operating to further advance the call to permit the said operated switch to selectively seize a succeeding trunk of the latter said group, and means including a resistance for marginally affecting a relay controlled over the call extension for initiating the operation of the storing device within the predetermined period to further progress the connection consequent to the 90 switch seizing a trunk link. 95
3. In an automatic telephone system, a calling and a called line, a trunk route between the calling and called lines, the route made up of a plurality of trunk links having terminating switches respectively, the trunks belonging to a corresponding plurality of trunk groups, a storing device, a dial on the calling line, means for initiating a call and for selecting the storing device, means whereby thereafter operating the dial will 100 set-up a condition in the storing device for automatically directing the extension of a connection from the calling to the called line over one of said plurality of routes involving one or more links from respective said trunk groups, means for operating the terminating switch of a said link over the link to set the switch with relation to a group of trunks and for permanently arresting the directive operation of the storing device to permit the last operated said switch to selectively seize a successive trunk of the latter said group, means controlled over the call extension for initiating the operation of the storing device to further progress the connection consequent to the switch seizing a trunk link, and means controlled over the call extension to efface the extension if the switch finds a busy group and for automatically initiating the operation of the storing device to 105 110 115 120 125 130 135 140 145 150
4. In an automatic telephone system, a calling line, a called line, a plurality of trunk routes between the calling and called lines, the routes made up of one or more trunk links having terminating switches respectively, the trunks belonging to a corresponding plurality of trunk groups, a storing device, a dial on the calling line, means for initiating a call and for selecting the storing device, means whereby thereafter operating the dial will set-up a condition in the storing device for automatically directing the extension of a connection from the calling to the called line over one of said plurality of routes involving one or more links from respective said trunk groups, means for operating the terminating switch of a said link over the link by the storing device to set the switch with selective relation to a said group of trunks, means for then arresting the directive operation of the storing device for only a predetermined period before again directly operating to further advance the call to permit the last operated said switch to selectively seize a successive trunk of the latter said group, means controlled over a link of the call extension for initiating the operation of the storing device before the termination of said predetermined period to further progress the connection consequent to the switch seizing a trunk link, and means controlled over a link of the call extension to efface the extension consequent upon said switch finding a busy said group and for then automatically initiating the operation of the storing device to re-progress the call over another of the said routes in the direction of the called line. 80 85 90 95 100 105 110 115 120 125 130 135 140 145 150
5. In an automatic telephone system, a calling line, a called line, a plurality of trunk routes between the calling and called lines, the routes made up of one or more trunk links having terminating switches respectively, the trunks belonging to a corresponding plurality of trunk groups, a storing device, a dial on the calling line, means for initiating a call and for selecting the storing device, means whereby thereafter operating the dial will set-up a condition in the storing device for automatically directing the extension of a connection from the calling to the called line over one of said plurality of routes involving one or more links from respective said trunk groups, means for operating the terminating switch of a said link over the link to set the switch with relation to a group of trunks and for permanently arresting the directive operation of the storing device to permit the last operated said switch to selectively seize a successive trunk of the latter said group, means controlled over the call extension for initiating the operation of the storing device to further progress the connection consequent to the switch seizing a trunk link, and means controlled over the call extension to efface the extension if the switch finds a busy group and for automatically initiating the operation of the storing device to 100 105 110 115 120 125 130 135 140 145 150

- progress the call over another of the said routes in the direction of the called line, and means whereby a further progression will be effaced and the call thereafter progressed over a new 5 route in the direction of the called line under conditions as before caused the said effacement and the said reprogression of the call extension.
7. In an automatic telephone system, subscriber lines, lineswitches for said lines respectively, trunk lines and corresponding linking switches therefor for extending connections from the respective trunks, an auxiliary switch multiply connected with the trunk lines operated for 10 extending connections in branch relation to the possible extensions from a said trunk, means for extending a connection from a said subscriber line through a lineswitch to the auxiliary switch over any idle one of said trunk lines, means effective consequent to effecting a connection to 15 the auxiliary switch to bar extending a connection to the auxiliary switch over any other of said trunk lines, and automatic means controlled over the subscriber line for then operating only the auxiliary switch.
- 20 8. In an automatic telephone system, lines, trunk lines and corresponding linking switches therefor for extending connections from the respective trunk lines, an auxiliary linking switch which will be directly seized coincident with connecting a first said line and any one of said 25 trunk lines, the auxiliary switch for extending connections in branch relation to the trunk line extensions made thereafter, and relay means in the auxiliary switch and in the switch of the 30 trunk line connected with by a first said line independently controlled over the connected first said line for directly operating the switch on the connected trunk line and the auxiliary switch coincidently to effect respective extensions from 35 the connected first said line by said operated switches.
9. In an automatic telephone system, lines, trunk lines and corresponding linking switches therefor for extending connections from the respective trunk lines, an auxiliary linking switch normally multiply connected with the trunk lines which will be directly seized coincident with connecting a first said line with any one of said trunk lines, the auxiliary switch for extending connections 40 in branch relation to the trunk line extensions made thereafter, means directly controlled over the first said line connected with the trunk line and also over a connection established through the auxiliary switch for disconnecting 45 the auxiliary switch from the trunk line to which the first said line is connected, and means for thereafter selectively operating the switch on the connected trunk line to extend a connection from the trunk line.
- 50 10. In an automatic telephone system, calling stations, trunk lines and corresponding linking switches therefor, an auxiliary selector normally multiply connected with the trunk lines, means for connecting a calling station with a trunk line, means for directly operating the corresponding linking switch from the calling station connected with the trunk, means effective consequent to the operation of the linking switch to disconnect the auxiliary selector from the trunk leading 55 to the linking switch, leaving the auxiliary selector multiply connected to the remaining trunk lines, means for selectively operating the linking switch after said disconnection of the auxiliary switch, means for successively seizing the remaining trunk lines from the calling stations re- 60 spectively, and means for thereafter successively disconnecting the auxiliary selector from the trunks seized, leaving the auxiliary selector disconnected from all the trunk lines and the trunk lines free from each other.
- 65 11. In an automatic telephone system, lines, switches for said lines respectively, trunk lines and corresponding switches therefor, an auxiliary link switch companion to the trunk lines which will be directly seized coincident with seizing any one of said trunk lines from a first said switch, means for barring all the trunk lines against seizure consequent to the said seizing, means controlled from the first said line for directly operating the auxiliary switch from its position when first seized independent of any other said switch, means for disconnecting the auxiliary link switch from the said trunk line while the said seizure is maintained, means effective consequent to the said disconnection for unbarring the said barred trunk lines with the exception of the said seized trunk line now maintained barred independent of the auxiliary link switch, and means whereby the unbarred said trunk lines and the auxiliary link switch are rendered subject to seizure in a new call.
- 70 12. In an automatic telephone system, calling and called lines, trunk lines leading to linking switches respectively, an auxiliary switch normally commonly connected to the trunk lines, a storing device accessible from the auxiliary switch, other trunk lines each terminating in a respective linking switch, a calling dial on the calling line, means for initiating a call on the calling line and to link a connection to an idle one of first said trunk lines and the auxiliary switch, means whereby the said auxiliary switch may be directly operated from the dial to select a storing device, means for thereafter setting-up a condition in the storing device for automatically causing the switch on the seized said trunk line to link a connection over one of said other trunk lines in the direction of the called line, and means controlled from the storing device for disassociating the auxiliary switch from the first said trunk line seized.
- 75 13. In an automatic telephone system, calling and called lines, trunk lines leading to linking switches respectively, an auxiliary switch normally commonly connected to the trunk lines, a storing device accessible from the auxiliary switch, other trunk lines each terminating in a respective linking switch, a calling dial on the calling line, means for initiating a call on the calling line and to link a connection to an idle one of first said trunk lines and the auxiliary switch, means whereby the auxiliary switch may be directly operated from the dial to select a storing device, means for thereafter setting-up a condition in the storing device under control of the dial for automatically causing the switch on the seized said trunk line to link a connection over one of said other trunk lines in the direction of the called line, and means controlled from the storing device for disassociating the auxiliary switch from the first said trunk line seized.
- 80 14. In an automatic telephone system, calling and called lines, trunk lines leading to linking switches respectively, an auxiliary switch normally commonly connected to the trunk lines, a storing device accessible from the auxiliary switch, other trunk lines each terminating in a respective linking switch, a calling dial on the calling line, means for initiating a call on the calling line and to link a connection to an idle one of

- first said trunk lines and the auxiliary switch, means whereby the auxiliary switch may be directly operated from the dial to select a storing device, means for setting-up a condition in 5 the storing device for automatically causing the operation of the switch on the seized said trunk line and also switches on one or more said other trunk lines to extend a connection from the calling line to the called line, and means operative 10 incidental to setting a said switch upon the called line for disassociating and restoring the auxiliary switch from the connection and rendering it subject to use in a new call. 15. In an automatic telephone system, a calling line, a called line, a plurality of trunk links each terminating in a linking switch, means for directly operating certain ones of the switches successively to extend a tandem connection from the calling to the called line, means for operating 20 one of said switches with step-by-step selective reference to a group of said trunk links and thereafter with testing relation to the individual trunks of the group to seize an idle one of said trunk links by way of extending the connection 25 toward the called line, and means effective consequent to operating the switch with said selective relation to a group of trunks but not in individual testing relation thereto, effective if all the said trunks are busy for effacing the extended 30 connection. 16. In an automatic telephone system, a calling line, a called line, a plurality of trunk links each terminating in a linking switch, means for directly operating certain ones of the switches 35 successively to extend a tandem connection from the calling to the called line, means for operating one of said switches with step-by-step selective relation to a group of said trunk links and thereafter with testing relation to the individual 40 trunks of the group to seize an idle one of said trunk links of the group by way of extending the connection toward the called line, means effective consequent to operating the switch with said selective relation to a group of trunks but not in 45 individual testing relation to the trunks thereof, effective if all the said trunks of the group are busy for effacing the extended connection, and means automatically effective to forthwith re-extend the connection in the direction of the 50 called line. 17. In an automatic telephone system, a calling line, a called line, a plurality of trunk links each terminating in a linking switch, means for directly operating certain ones of the switches 55 successively to extend a tandem connection from the calling to the called line, means for operating one of said switches with selective relation to a group of said trunk links and thereafter with testing 60 relation to the individual trunks of the group to seize an idle one of said trunk links of the group by way of extending the connection toward the called line, means effective consequent to operating the switch with selective relation to a group of trunks but not in individual testing relation to the 65 trunks thereof, effective if all the said trunks of the group are busy for effacing the extended connection, and means automatically effective to forthwith re-extend the connection in the direction of the called line wherein there will be no 70 possibility of seizing any said trunk link adapted to be seized in the first said extension of the call. 18. In an automatic telephone system, a calling line, a called line, a dial on the calling line for directly controlling the progression of a call 75 from the calling to the called line, a plurality of trunk routes between the calling and called lines, each said route made up of a plurality of trunk links, means for progressing a call over a pre-determined route towards the called line responsive to the operation of the dial, means for automatically effacing the progressed extension of the call consequent to encountering a barred trunk condition, and means responsive to the said encountering of the said barred condition for automatically re-progressing the call in the direction of the called line employing a different trunk route than the predetermined route but using the first link involved in the antecedent dial progression of the call over the predetermined trunk route. 19. In an automatic telephone system, a calling line, a called line, a dial on the calling line for directly controlling the progression of a call from the calling to the called line, a plurality of trunk routes between the calling and called lines, each said route made up of a plurality of trunk links, means for progressing a call over a pre-determined route towards the called line responsive to the operation of the dial, means for automatically effacing the progressed extension of the call consequent to encountering a barred trunk condition, means responsive to the said encountering of the said barred condition for automatically re-progressing the call in the direction of the called line employing a different trunk route than the predetermined route, and means dependent upon the call being progressed to the first trunk link of the route for automatically progressing the call over the said first link as a part of the said different trunk route. 20. In an automatic telephone system, a calling line, a called line, a dial on the calling line for directly controlling the progression of a call from the calling to the called line, a plurality of trunk routes between the calling and the called line, each said route made up of a plurality of trunk links, means for progressing a call over a predetermined route towards the called line responsive to the operation of the dial, means for automatically effacing the progressed extension of the call consequent to encountering a barred trunk condition, means responsive to the said encountering of the said barred condition for automatically re-progressing the call in the direction of the called line employing a different trunk route than the predetermined trunk route from only beyond the first link used in the antecedent progression, and means dependent upon the call being barred from the first link of the said predetermined trunk route for automatically re-progressing the call over a different trunk route not involving the said first link. 21. In an automatic telephone system, a calling line, a called line, a dial on the calling line for directly controlling the progression of a call from the calling to the called line, a plurality of trunk routes between the calling and the called line, each said route made up of one or more trunk links, a storing device, means for setting-up a stored condition in the storing device responsive to effecting a portion of the calling number of the calling line from the dial whereby the call will be extended from the calling line over a predetermined route in the direction of the called line under automatic self-control of the storing device, means for automatically effacing the progressed extension of the call consequent to encountering a barred trunk condition, means in the storing device responsive to the said encountering of the said barred condition to automatically self- 130 135 140 145 150

- control the reprogression of the call over a specific one of a plurality of alternative routes in the direction of the called line, which alternative route the call will be re-progressed over being dependent upon the number of trunk links inter-linked before the barred trunk condition is encountered. 5
22. In an automatic telephone system, a calling line, a called line, a dial on the calling line for 10 directly controlling the progression of a call from the calling to the called line, a plurality of trunk routes between the calling and the called line, each said route made up of one or more trunk links, a storing device, means for 15 setting-up a stored condition in the storing device responsive to effecting a portion of the calling number of the calling line from the dial whereby the call will be extended from the calling line over a predetermined route in the direction of the 20 called line under automatic self-control of the storing device, means to automatically efface the progressed extension of the call consequent to encountering a barred trunk condition, and means in the storing device responsive to the said 25 encountering of the said barred condition to automatically self-control the re-progressing of the call over a specific one of a plurality of alternative routes in the direction of the called line, which alternative route the call will be progressed over 30 in the second progression being dependent upon if the first link of the predetermined route is busy or not when encountered. 35
23. In an automatic telephone system, a calling and a called line, three or more trunk routes between the said calling and the called line, a dial on the calling line, a storing device, means for initiating a call from the calling line and for 40 directly operating the dial to select the storing device, means whereby consequent to selecting the storing device the storing device will set-up a condition therein for potentially progressing the call under automatic control of the storing device in the direction of the called line over a normal route involving two or more links and a first and 45 a second preferred alternative route, the said first preferred alternative route involving the first link of the normal route as its first link, means whereby if the normal route is idle the call will be completed thereover to the called line, means whereby 50 consequent to a busy link being encountered in the normal route after the first link is seized the progressed extension of the call will be automatically effaced and the call then progressed over the said first alternative route under automatic control of the storing device, and means whereby if a busy first link is encountered in the normal route the call will be effaced and the call then progressed over the said second alternative route under automatic control of the 55 storing device. 60
24. In an automatic telephone system, a calling and a called line, three or more trunk routes between the said calling and the called line, a dial on the calling line, a storing device, means for initiating a call from the calling line and for 65 directly operating the dial to select the storing device, means for then operating the dial to set-up a stored condition in the storing device for potentially progressing the call under automatic control of the storing device in the direction of the called line over a normal route involving two or more links and a first and a second preferred alternative route, the said first preferred alternative route involving the first link 70 of the normal route as its first link, means where- 75
- by if the normal route is idle the call will be completed thereover to the called line, means whereby consequent to a busy link being encountered in the normal route after the first link is seized the progressed extension of the call will be automatically effaced and the call then progressed over the said first alternative route under automatic control of the storing device. 80
25. In an automatic telephone system, a calling line, a called line, a dial on the calling line for 85 directly controlling the progression of a call from the calling to the called line, a plurality of trunk routes between the calling and the called line, each said route made up of one or more trunk links, a storing device, an attendant's station, means for setting-up a stored condition in the storing device responsive to effecting a portion of the calling number of the called line from the dial whereby the call will be extended from the calling line over a predetermined route in 90 the direction of the called line under automatic self-control of the storing device, means to automatically efface the progressed extension of the call consequent to encountering a barred trunk condition, means in the storing device responsive to the said 95 encountering of the said barred condition to automatically self-control the progression of the call over a specific one of a plurality of alternative routes in the direction of the called line, which alternative route the call will be re- 100 progressed over being dependent upon the number of trunk links inter-linked before the barred trunk condition is encountered, and means whereby if the call cannot be completed due to all routes being barred the progressed extension 105 last made will be effaced and the call then progressed to the attendant's station. 110
26. In an automatic telephone system, a calling and a called line, a plurality of trunk routes between the said calling and called lines, a dial 115 on the calling line, a storing device, means for initiating a call from the calling line and for directly operating the dial to select the storing device, means whereby consequent to selecting the storing device the storing device will set-up a condition therein for potentially progressing the call under automatic directive control of the storing device in the direction of the called line over a normal route involving a plurality of links and a first and a second preferred alternative 120 route, the said first preferred alternative route involving a portion of the normal route as a portion of the first alternative route, means whereby if the normal route is idle the call will be completed thereover to the called line, means where- 125
- by if a busy link is encountered in the normal route after the call has been completed over the said portion of the normal route the progressed extension of the call will be effaced and the call then progressed over the said first alternative route under automatic control of the storing device, and means whereby if a busy trunk condition is encountered before completing the call over the said portion of the normal route the progressed extension of the call will be effaced and 130 the call then progressed over the said second alternative route under the automatic control of the storing device. 135
27. In an automatic telephone system, a calling and a called line, a plurality of trunk routes 140

- between the said calling and called lines, a dial on the calling line, a storing device, means for initiating a call from the calling line and for directly operating the dial to select the storing device, means for then operating the dial to set-up a stored condition in the storing device for potentially progressing the call under automatic directive control of the storing device in the direction of the called line over a normal route involving a plurality of links and a first and a second preferred alternative route, the said first preferred alternative route involving a portion of the normal route as a portion thereof, means whereby if the normal route is idle the call will be completed therover to the called line, means whereby if a busy link is encountered in the normal route after the call has been completed over the said portion of the normal route the progressed extension of the call will be effaced and the call then progressed over the said first alternative route under automatic control of the storing device, and means whereby if a busy trunk condition is encountered before completing the call over the said portion of the normal route the progressed extension of the call will be effaced and the call then progressed over the said second alternative route under the automatic control of the storing device. 28. In an automatic telephone system, a calling and a called line, a plurality of trunk routes between the said calling and called lines, a dial on the calling line, a storing device, means for initiating a call from the calling line and for directly operating the dial to extend a call from the calling line to the called line, means whereby if the dial is operated to extend the call in the direction of the called line under direct directive control of the dial and a busy trunk condition is encountered, a set-up condition will occur in the storing device consequent to the said busy condition being encountered whereby the progressed extension of the call will be effaced and a new progression of the call will be automatically made over another of said plurality of routes in the direction of the called line under self-directive control of the storing device in correspondence with said set-up condition. 29. In an automatic telephone system, a calling and a called line, a plurality of trunk routes between the said calling and called lines, a dial on the calling line, a storing device, means for initiating a call from the calling line and for directly operating the dial to extend a call from the calling line to the called line, means whereby if the dial is operated to extend the call in the direction of the called line under direct directive control of the dial and a busy trunk condition is encountered, a set-up condition will occur in the storing device consequent to the said busy condition being encountered whereby the progressed extension of the call will be effaced and a new progression of the call will be automatically made over another of said plurality of routes in the direction of the called line, and means whereby if the said new progression of the call encounters a busy trunk condition the progressed extension of the call will be again effaced and a second new progression of the call will be made over another of said plurality of routes in the direction of the called line. 30. In an automatic telephone system, a calling and a called line, a plurality of trunk routes between the said calling and called lines, a dial on the calling line, a first switch, a storing device, means for initiating a call from the calling line to extend the calling line to the switch and for operating the dial to directly directly operate the switch to progress the call in the direction of the called line, means effective if the switch encounters a barred condition to set-up a condition in the storing device consequent thereto whereby the switch will be restored and a new operation thereof will be made to progress the call over a different one of said routes in the direction of the called line. 31. In an automatic telephone system, a calling and a called line, a plurality of trunk routes between the said calling and called lines, a dial on the calling line, a first switch, a storing device, means for initiating a call from the calling line to extend the calling line to the switch and for operating the dial to directly directly operate the switch to progress the call in the direction of the called line, means effective if the switch encounters a barred condition to set-up a condition in the storing device consequent thereto whereby the switch will be restored and a new operation thereof will be made to progress the call over a different one of said routes in the direction of the called line, and means whereby if the said new progression of the call encounters a barred condition the progressed extension of the call will be again effaced and a second new progression of the call made over another of said plurality of routes in the direction of the called line. 32. In an automatic telephone system, lines, trunk lines, switches for the respective trunk lines, a shaft switch connected in multiple with the trunk lines, means for simultaneously connecting a random first said line with a random said trunk line and the shaft switch, means for barring the unconnected trunk lines against connection with random other first said lines consequent to a first said line becoming connected with a said trunk line, automatic means for operating the shaft of the shaft switch from its position when connected with controlled over the said connected first said line and trunk line without affecting the switch of the connected trunk line, and means for then operating the switch of the connected trunk line over the connected first said line while maintaining the said connection. 33. In an automatic telephone system, lines, trunk lines, switches for the respective trunk lines, a shaft switch connected in multiple with the trunk lines, means for simultaneously connecting a random first said line with a random said trunk line and the shaft switch, means for barring the unconnected trunk lines against connection with random other first said lines consequent to a first said line becoming connected with a said trunk line, automatic means for operating the shaft of the shaft switch from its position when connected with controlled over the said connected first said line and trunk line without affecting the switch of the connected trunk line, and means dependent upon the operation of the shaft switch for then operating the switch of the connected trunk line over the connected first said line while maintaining the said connection. 34. In an automatic telephone system, lines, trunk lines, switches for the respective trunk lines, a shaft switch connected in multiple with the trunk lines, means for simultaneously connecting a random first said line with a random said trunk line and the shaft switch, means for barring the unconnected trunk lines against connection with random other first said lines consequent to a first said line becoming connected with a said trunk line, automatic means for operating the shaft of the shaft switch from its position when connected with controlled over the said connected first said line and trunk line without affecting the switch of the connected trunk line, and means for initiating a call from the calling line to extend the calling line to the switch and for operating the dial to directly directly operate the switch to progress the call in the direction of the called line, means effective if the switch encounters a barred condition to set-up a condition in the storing device consequent thereto whereby the switch will be restored and a new operation thereof will be made to progress the call over a different one of said routes in the direction of the called line.

- nection with random other first said lines consequent to a first said line becoming connected with a said trunk line, automatic means for operating the shaft of the shaft switch from its position when connected with controlled over the said connected first said line and trunk line without affecting the switch of the connected trunk line, means for then operating the switch of the connected trunk line over the connected first said line while maintaining the said connection, means for disconnecting the shaft switch from the said trunk line while thereafter maintaining the connection from the connected first said line with the trunk line, and means whereby the switch of the trunk line will continue an initiated selective operation after the shaft switch has been disconnected. 80
35. In an automatic telephone system, first lines, second lines, a switch for each of the second lines, a common switch connected in multiple operative relation with all of said second lines coincidentally, means controlled over a first said line for connecting with a random one of said second lines and the common switch simultaneously, automatic means for operating the common switch only from the connected first line, means dependent upon an operation of the common switch for rendering the switch on the connected second line responsive to the automatic means from the connected first line, means for then disconnecting the common switch from the connected second line, and means for thereafter operating the switch on the connected second line. 90
36. In an automatic telephone system, first lines, second lines, a switch for each of the second lines, a common switch connected in multiple operative relation with all of said second lines coincidentally, means controlled over a first said line for connecting with a random one of said second lines and the common switch simultaneously, automatic means for operating the common switch only from the connected first line, means dependent upon the operation of the common switch for rendering the switch on the connected second line responsive to the automatic means from the connected first line, means for then disconnecting the common switch from the connected second line, means for thereafter operating the switch on the connected second line, and means for operating the disconnected common switch from another said first lines before the last said operation of the switch on the said second line terminates. 100
37. In an automatic telephone system, lines, a switch for each of said lines, a common switch connected in multiple operative relation to all of the said lines coincidentally, means for seizing a random one of said lines, means for then automatically operating only the common switch over the connected line, means made operative responsive to only specific operative movement of a plurality of possible operative movements of the common switch for causing the operation of the switch on the connected line, means for then disconnecting the common switch, and means for thereafter operating the switch on the connected line. 110
38. In an automatic telephone system, lines, a switch for each of said lines, a common switch connected in multiple operative relation to all of the said lines coincidentally, means for seizing a random one of said lines, means for then automatically operating only the common switch over the connected line, means made operative re- 120
- sponsive to only specific operative movement of a plurality of possible operative movements of the common switch for enabling the operation of the switch on the connected line, means for then disconnecting the common switch, and means for thereafter operating the switch on the connected line. 130
39. In an automatic telephone system, a calling and a called line, a trunk route between the calling and called lines, the route made up of a plurality of trunk lines having terminating switches respectively, the trunks belonging to a corresponding plurality of trunk groups, a storing device, a dial on the calling line, means for initiating a call and for selecting the storing device, means whereby thereafter operating the dial will set-up a condition in the storing device for automatically directing the extension of a connection from the calling to the called line over one of said plurality of trunk links, means for operating the terminating switch on the trunk with selective relation to a group of trunks, automatically applied means then made operative to test for seize the first idle trunk tested, means for arresting the directive operation of the storing device for only a predetermined period before again directly operating to further advance the call to permit the said operated switch to selectively seize a succeeding trunk of the latter said group, and means including a resistance for marginally affecting a relay controlled over the call extension for initiating the directive operation of the storing device before the termination of said predetermined period to further progress the connection consequent to the switch seizing a trunk link. 140
40. In an automatic telephone system, a calling and a called line, a trunk route between the calling and the called lines, the route made up of a plurality of trunk links having terminating switches respectively, the trunks belonging to a corresponding plurality of trunk groups, a storing device, a dial on the calling line, means for initiating a call and for selecting the storing device, means whereby thereafter operating the dial will set-up a condition in the storing device for automatically directing the extension of a connection from the calling to the called line over one of the said plurality of trunk links, means for operating the terminating switch on the trunk link with selective relation to a group of trunks, automatically applied means then made operative to test for and seize the first idle trunk tested, means for arresting the directive operation of the storing device for only a predetermined period before again directly operating to further advance the call to permit the said operated switch to selectively seize a succeeding trunk of the latter said group, and means including a source of current to which a condenser is transparent effective to a relay controlled over the call extension for initiating the directive operation of the storing device before the termination of said predetermined period to further progress the connection consequent to the switch seizing a trunk link. 150
41. In an automatic telephone system, a calling line, a called line, a dial on the calling line for directly controlling the progression of a call from the calling to the called line, a plurality of trunk routes between the calling and called lines, each said route made up of a plurality of trunk links, means for progressing a call over a predetermined route towards the called line responsive to the operation of the dial, means to automatically efface the progressed extension of the 160

- call consequent to encountering a barred trunk condition after the first linking operation has been effected, and means responsive to the said encountering of the said barred condition for automatically re-progressing the call in the direction of the called line employing a different trunk route than the predetermined route but using the first link involved in the antecedent dial progression of the call over the predetermined trunk route. 5 10 15 20 25 30 35 40 45 50 55 60 65 70 75
42. In an automatic telephone system, a calling line, a called line, a dial on the calling line for directly controlling the progression of a call from the calling to the called line, a plurality of trunk routes between the calling and called lines, each said route made up of a plurality of trunk links, means for progressing a call over a predetermined route towards the called line responsive to the operation of the dial, means for automatically effacing the progressed extension of the call consequent to encountering a barred trunk condition after the first linking operation has been effected, means responsive to the said encountering of the said barred condition for automatically re-progressing the call in the direction of the called line employing a different trunk route than the predetermined trunk route, and means dependent upon the call being progressed to the first trunk link of the route for automatically progressing the call over the said first link as a part of the said different trunk route. 10 15 20 25 30 35 40 45 50 55 60 65 70 75
43. In an automatic telephone system, a calling line, a called line, a dial on the calling line for directly controlling the progression of a call from the calling to the called line, a plurality of trunk routes between the calling and the called line, each said route made up of one or more trunk links, a storing device, an attendant's station, means for setting up a stored condition in the storing device responsive to effecting a portion of the calling number of the called line from the dial whereby the call will be extended from the calling line over a predetermined route in the direction of the called line under automatic self-control of the storing device, means for thereupon automatically effacing the progressed extension of the call consequent to encountering a barred trunk condition intermediate of said predetermined route regardless of any condition of the calling line, and means responsive to said effacement for then extending the call from the calling line to the attendant's station. 10 15 20 25 30 35 40 45 50 55 60 65 70 75
44. In an automatic telephone system, a calling line, a called line, a dial on the calling line for directly controlling the progression of a call from the calling to the called line, an attendant's station, a storing device, means for setting up a stored condition in the storing device responsive to effecting a portion of the calling number of the called line from the dial whereby the call will be thereby extended from the calling line over a predetermined route in the direction of the called line under automatic self-control of the storing device, and automatically applied means whereby if the call cannot be completed over the route due to the route being barred the progressed extension will be thereupon effaced regardless of any condition of the calling line and the call then progressed to the attendant's station. 10 15 20 25 30 35 40 45 50 55 60 65 70 75
45. In an automatic telephone system, a calling and a called line, a plurality of trunk routes between the said calling and called lines, a dial on the calling line, a first switch, a storing device, means for initiating a call from the calling line to extend the calling line to the switch and for operating the dial to directly directly operate the switch from its restored position to progress the call in the direction of the called line, automatically applied means effective if the switch encounters a barred trunk condition to set-up a condition in the storing device consequent thereto whereby the switch will be returned to its restored position and a new operation thereof made to progress the call over a different one of said routes in the direction of the called line. 5 10 15 20 25 30 35 40 45 50 55 60 65 70 75
46. In an automatic telephone system, a calling and a called line, a plurality of trunk routes between the said calling and called lines, a common link of said routes intermediate of the first and last links of said routes, a dial on the calling line, a first switch, a storing device, means for initiating a call from the calling line to extend the calling line to the switch and for operating the dial to directly directly operate the switch from its restored position to progress the call over a first trunk link in the direction of the called line, automatically applied means effective if the switch encounters a barred trunk condition to set-up a condition in the storing device consequent thereto whereby the switch will be returned to its restored position and a new operation thereof made to progress the call over a different one of said routes in the direction of the called line. 10 15 20 25 30 35 40 45 50 55 60 65 70 75
47. In an automatic telephone system, a calling and a called line, a plurality of trunk routes between the said calling and called lines, a dial on the calling line, a first switch, a storing device, means for initiating a call from the calling line to extend the calling line to the switch and for operating the dial to directly directly operate the switch from its restored position to progress the call in the direction of the called line, automatically applied means effective if the switch encounters a barred trunk condition to set-up a condition in the storing device consequent thereto whereby the switch will be returned to its restored position and a new operation thereof made to progress the call over a different one of said routes in the direction of the called line, and automatically applied means effective if the said new progression of the call encounters a barred trunk condition the progressed extension of the call will be again effaced responsive to again returning the switch to its restored position and a second new progression of the call made over another of said plurality of routes in the direction of the called line. 10 15 20 25 30 35 40 45 50 55 60 65 70 75
48. In an automatic telephone system, a calling and a called line, a plurality of trunk routes between the said calling and called lines, a common link of said routes intermediate of the first and last links of said routes, a dial on the calling line, a first switch, a storing device, means for initiating a call from the calling line to extend the calling line to the switch and for operating the dial to directly directly operate the switch from its restored position to progress the call over the first trunk link in the direction of the called line, automatically applied means effective if the switch encounters a barred trunk condition to set-up a condition in the storing device consequent thereto whereby the switch will be returned to its restored position and a new operation thereof made to progress the call over a different one of said routes in the direction of the called line, and automatically applied means effective if the said new progression of the call encounters a barred trunk condition the progressed extension 10 15 20 25 30 35 40 45 50 55 60 65 70 75

- of the call will be again effaced responsive to again returning the switch to its restored position in the manner as before and a second new progression of the call made over another of said plurality of routes in the direction of the called line to said common link. 80
49. In a telephone system, an automatic selective switch, a leading-in conductor for said switch, a resistor, relay mechanism, and means responsive to the switch effecting a specific selective operation for operating said relay mechanism to momentarily include the resistor in series with the leading-in conductor. 85
50. In a telephone system, an automatic selective switch, a leading-in conductor for said switch, a resistor, relay mechanism, means for directly operating the switch over the leading-in conductor, and means responsive to the switch affecting a specific selective operation directly controlled over the leading-in conductor for operating said relay mechanism to momentarily include the resistor in series with the leading-in conductor. 90
51. In a telephone system, an automatic selective switch, a pair of leading-in conductors for said switch, a resistor, relay mechanism, and means responsive to the switch effecting a specific selective operation for operating said relay mechanism to momentarily include the resistor in series with the leading-in conductors. 100
52. In a telephone system, an automatic selective switch, a pair of leading-in conductors for said switch, a resistor, relay mechanism, means for directly operating the switch over the leading-in conductors, and means responsive to the switch effecting a specific selective operation step-by-step directly controlled over the leading-in conductors for operating said relay mechanism to momentarily include the resistor in series with the leading-in conductors. 105
53. In a telephone system, an automatic selective switch, a first and a second relay, a resistor, a leading-in line for the switch, means for seizing the switch over the line to thereby operate the first relay from normal, means for selectively operating the switch over the line to thereby operate the second relay and to restore the first relay to normal, and means responsive to the said relay operation for momentarily including the resistor serially in the line. 110
54. In a telephone system, an automatic selective switch, a group of lines selectively accessible from the switch, relay mechanism, a resistor, a leading-in line of the switch, means for directly operating the switch over the leading-in line to select the group of lines, automatically applied means for then operating the switch to successively test lines of the group to select the first idle line of the group tested, and automatically applied means rendered operative responsive to the last said selection for causing the operation of the relay mechanism to momentarily include the resistor in series with the leading-in line. 115
55. In a telephone system, a talking and operating trunk line having not to exceed two conductors, the trunk line divided into near and remote sections, a resistor for each said section, a reverser for interchanging the said conductors of the respective sections specific to the respective sections, means responsive to introducing a said resistor in series in a conductor of one said section will thereby cause the introduction of the other said resistor in series with the other said section, and means responsive to operating the reverser to interchange the said conductors of one said section will thereby cause the reverser of the other said section to interchange the conductors of the other said section. 120
56. In a telephone system, a talking and operating trunk line having not to exceed two conductors, the trunk line divided into near and remote sections, a resistor for each said section, and means responsive to introducing a said resistor in series with a conductor of one of said sections will thereby cause the introduction of the other said resistor in series with the other said section. 125
57. In a telephone system, a talking and operating trunk line, the trunk line divided into near and remote sections, a marginally adjusted relay of the near section, a source of current included with said relay and the talking conductors of the near section, a polarized relay of the near section included with said source of current, a resistor for serial inclusion with the winding of the marginal relay, a reverser on the near section for interchanging the connections of the said source with respect to the polarized relay, a source of current serially included with the talking conductors of the remote section, a resistor for inclusion with last said source, a reverser on the remote section for interchanging the talking conductors of the remote section with respect to the source of current thereof, means responsive to including the resistor of the remote section to include first said resistor in a series path with the winding of the marginal relay to operatively affect the marginal relay, and means responsive to operating the reverser of the remote section to operate the reverser on the near section to operatively affect the polarized relay. 130
58. In a telephone system, a talking and operating trunk line, the trunk line divided into near and remote sections, a marginally adjusted relay for the near section, a source of current included with said relay and a conductor of the near section, a resistor for the marginal relay, a resistor for the remote section, and means responsive to introducing the resistor of the remote section serially with a said conductor thereof to introduce first said resistor in a series path with the winding of the marginal relay to operatively affect the marginal relay. 135
59. In a telephone system, a talking and operating trunk line, the trunk line divided into near and remote sections, a resistor for each said section, a reverser specific for each section for interchanging the talking conductors of the respective sections, means responsive to introducing a said resistor in series in a talking conductor of one of said sections will thereby cause the introduction of the other said resistor in series with a talking conductor of the other said section, and means responsive to operating the reverser to interchange the talking conductors of one said section will thereby cause the reverser of the other said section to interchange the talking conductors of the said other section. 140
60. In a telephone system, a talking and operating trunk line, the trunk line divided into near and remote sections, a resistor for each said section, and means responsive to introducing a said resistor in series with a talking conductor of one of said sections will thereby cause the introduction of the other said resistor in series with a talking conductor of the other of said section. 145
61. In a telephone system, a talking and operating trunk line, the trunk line divided into near 150

- and remote sections, a relay winding and source of current serially included with conductors of the remote section, a resistor for series inclusion with the winding of the relay and conductors 5 of the remote section, a reverser for interchanging the connection of the conductors of the remote section with respect to said source of current, a winding of a polarized relay and a winding of a marginal relay included in a series path 10 with conductors of the near section, a source of current for energizing the windings of the marginal and polarized relays, a resistor for series inclusion with the windings of the latter said relays to operatively affect only the marginal relay, a reverser for interchanging the connection of the conductors of the near section with respect to the latter said source of current to operatively affect only the polarized relay, a circuit closer for the near section for closing said 15 20 energized path, means responsive to the said closure for operatively energizing the relay on the remote section, a switch under control of said relay of the remote section, means including the resistor on the near section responsive to said inclusion of the resistor of the remote section to operatively affect only the marginal relay, means including the reverser on the near section responsive to operating the reverser on the remote section to operatively affect only the 25 30 polarized relay, and means controlled by alternative predetermined specific operation of the switch for correspondingly operating only the marginal relay or only the polarized relay.
62. In a telephone system, a talking and operating trunk line, the trunk line divided into near and remote sections, a relay winding a source of current serially included with conductors of the remote section, a resistor for series inclusion with the relay and said conductors of 35 40 the remote section, a winding of a marginal relay included in a series path with conductors of the near section, a source of current in series with conductors of the near section to form an energized path with the winding of the marginal relay, a resistor for series inclusion with the winding of the marginal relay effective to operatively affect it, a circuit closer for the near section for closing said energizing path, means responsive to the said closure for operatively energizing the 45 50 55 relay on the remote section, a switch under control of said relay of the remote section, means including the resistor on the near section responsive to said inclusion of the resistor of the remote section to operatively affect the marginal relay, and means controlled by specific predetermined operation of the switch for causing said inclusion of the resistor of the remote section.
63. In a telephone system, a selective switch, a plurality of groups of lines accessible from the switch, a leading-in line for the switch, means for seizing the switch and for then directly operating the switch from its position when seized controlled over the leading-in line to select 60 65 70 75 a random said group of said lines, automatically applied means for thereupon causing the switch to selectively test individual lines of the selected group and to connect with the first idle line of the group tested, and automatically applied means responsive to directly selecting the group to restore the switch to its position when seized if all the lines of the group selected are busy without testing any of the individual lines of the group.
- 75 64. In a telephone system, a selective switch, a group of lines accessible from the switch, a leading-in line for the switch, means for seizing the switch and for then directly operating the switch from its position when seized controlled over the leading-in line to select said group of lines, automatically applied means for thereupon causing the switch to selectively test individual lines of the selected group to connect with the first idle line of the group tested, and automatically applied means responsive to testing all the lines of the group when busy to restore the switch to its position when seized.
65. In a telephone system, a selective switch, a group of lines accessible from the switch, a leading-in line for the switch, a group busy terminal for said group which will manifest a guarding condition only when all the trunks of the group are busy, means for seizing the switch and for then directly operating the switch from its position when seized controlled over the leading-in line to select said group of lines, automatically applied means for thereupon causing the switch to selectively test individual lines of the selected group to connect with the first idle line of the group tested, and automatically applied means responsive to directly selecting the group to thereupon restore the switch to its position when seized if all the lines of the group selected are busy without testing any of the individual lines of the group.
66. In a telephone system, a calling line, a first switch, groups of trunks accessible from the switch, a switch for terminating each of said trunks, a directive device, a storing device, means controlled over the calling line responsive to the directive device for setting up a condition in the storing device to cause it to self-direct the operation of first said switch to select a said group with predetermined correspondence with the operation of said directive device, automatically applied means for then causing the switch to hunt for and seize the first idle line hunted over in the selected group, a secondary selective switch on trunks of a certain said group for selecting a second said switch responsive to its corresponding trunk being seized by said first switch, automatically applied means for disabling the self-directive operation of the storing device responsive to selecting only the group, automatically applied means for initiating the directive operation of the storing device at the termination of a predetermined period after only the group is selected, automatically applied means for initiating the self-directive operation of the storing device responsive to the first idle line of the group being seized, means for operating the switch for the trunk seized responsive to the re-initiating of the self-directive operation of the storing device, and means dependent upon the group of trunks selected for determining if the re-initiated, operation of the storing device will occur responsive to the seizure of the trunk or will be delayed until said predetermined period elapses to allow time for selective operation of said secondary switch.
67. In a telephone system, a selective switch, a group of lines accessible from the switch, a leading-in line for the switch, a group busy terminal for said group which will manifest a guarding condition only when all the trunks of the group are busy, means for seizing the switch and for causing the switch to operate from its position when seized to select said group of lines, automatically applied means for thereupon causing the switch to selectively test individual lines of the selected group to connect with the first idle line of the group tested.

- line of the group tested, and automatically applied means including the group busy test terminal responsive to said selection of the group to thereupon restore the switch to its position when seized if all the lines of the group selected are busy without testing any of the individual lines of the group.
68. In a telephone system, a calling line, a trunk line, a two-dimension connective switch terminating the trunk line, a called line accessible from the switch, a directive device, a storing device, means controlled over the calling line responsive to the directive device for setting up a condition in the storing device to cause it to self-direct the operation of the first switch controlled over the trunk line in said two dimensions, means for initiating the operation of the storing device for self-directively operating the switch in only one dimension in the selection of the called line, automatically applied means for then disabling the self-directive operation of the storing device for only a predetermined period responsive to effecting its said directive operation, and automatically applied means operated over the trunk line by the switch for again initiating the self-directive operation of the storing device before the termination of the said period consequent to the switch completing its said operation for thereupon operating the switch in its other said dimension to select the called line.
69. In a telephone system, a calling line, a trunk line, a selective switch terminating the trunk line having a directed group selection operation and an automatically applied operation to hunt over lines of the group to select an idle line of the group, a two-dimension connective switch accessible from the first said switch over a line of said group, a called line accessible from the last said switch, a directive device, a storing device, means controlled over the calling line responsive to the directive device for setting-up a condition in the storing device to cause it to self-direct the operation of said switches to complete a connection from the calling line to the called line controlled over the trunk line, means whereby when the first said switch is operated with selective relation to a group containing the line leading to second said switch the storing device will be disabled for only a predetermined time in order to allow time for first said switch to hunt for the line of the second said switch, means for then reinitiating the operation of the storing device to operate second said switch in a first dimension in the selection of the called line, automatically applied means operative to then disable the operation of the storing device for only a predetermined time, and means automatically applied by second said switch consequent to the completion of its operation in said first dimension to thereupon reinitiate the operation of the storing device before the termination of said predetermined time in order to forthwith operate second said switch to select the called line and avoid the predetermined time delay of operation following the normal operation of the storing device.
70. In a telephone system, a calling line, a called line, automatic switch mechanism, a manually operated sending device, means whereby responsive to operating the sending device the switch mechanism will be thereby directly step-by-step directly operated to extend a connection from the calling line towards the called line, and means whereby responsive to a barred condition being encountered in said extension thereby preventing the completion of the extension to the called line
- the extension will be disestablished and a new extension thereupon reestablished from the calling line without specific operation of the sending device for the new extension.
71. In a telephone system, a calling line, a 80 called line, automatic switch mechanism, a manually operated sending device, means whereby responsive to operating the sending device the switch mechanism will be thereby directly step-by-step directly operated to extend a connection from the calling line towards the called line, means whereby responsive to a barred condition being encountered in said extension thereby preventing the completion of the extension to the called line the extension will be disestablished and a new extension thereupon reestablished from the calling line without specific operation of the sending device for the new extension, and means whereby the new extension will be extended to said called line after said effacement wherein the operation of the sending device is the same as when the connection is completed to said called line wherein no effacement occurs.
72. In a telephone system, a calling line, lines, a manually operated sending device on the calling line, automatic switches for linking extensions over a plurality of random trunk routes from the calling line in response to operation of the sending device specific to a random one of said lines, means whereby the extension will first be 100 made over a predetermined one of said routes indexed by said specific operation of the sending device, means made operative responsive to a barred condition being encountered in said specific route thereby preventing the completion 110 of the extension the extension will be disestablished and a new extension will be thereupon reestablished to the calling line over a different said route, means whereby depending upon at what stage of the extension the barred condition 115 is encountered will determine over which said route the new extension from the calling line will be progressed over, and means whereby regardless of what said trunk route is used to complete the extension from the calling line the said 120 calling line will be connected to the specific one of said lines indexed by the said operation of the sending device.
73. In a telephone system, a calling line, a called line, automatic switches for linking trunk 125 extensions from the calling line to the called line, trunk links for a plurality of alternative trunk routes between the calling line and the called line, means responsive to encountering a barred trunk condition in linking a said extension thereby preventing the completion of the extension to the called line the trunk extension will be disestablished and a new extension reestablished from the calling line over another one of said 130 trunk routes, and means depending upon at what stage of the extension the barred condition is encountered will determine over which said route the new extension will be progressed over.
74. In telephone system, a calling line, a manually operated sending device, automatic switches 140 for linking trunk extensions over random trunk routes from the calling line in response to the operation of the sending device specific to a single said route, means made operative responsive to a barred condition being encountered in said 145 specific route thereby preventing the completion of the extension the extension will be disestablished and the call then reestablished over a different said trunk route, and means depending upon at what stage of the extension the barred 150

condition is encountered will determine over which said route the second extension from the calling line will be progressed over.

75. In a telephone system, a calling line, a called line, a plurality of trunk routes between said calling and called lines, automatic switch mechanism, a manually operated sending device for directively operating the switch mechanism for extending a trunk connection from the calling line over one of said routes to the called line, means whereby if a barred condition occurs to prevent the completion of said extension to the called line the trunk extension will be thereby disestablished and a re-extension made over another said trunk route from the calling line to the called line, means depending upon at what stage of the trunk extension the barred condition is encountered will determine over which said trunk route the re-extension from the calling line will be progressed over, and means whereby the sending device will be operated in only one specific manner to effect the connection from the calling line to the called line whether or not said effacement and re-extension is made.

76. In a telephone system, a calling line, a called line, a plurality of trunk routes between said calling and called lines, automatic switch mechanism, a manually operated sending device for directively operating the switch mechanism for extending a trunk connection from the calling line over one of said routes to the called line, means whereby if a barred condition occurs to prevent the completion of said extension to the called line the trunk extension will be thereby disestablished and a re-extension made over another said trunk route from the calling line to the called line, means depending upon at what stage of the trunk extension the barred condition is encountered will determine over which said trunk route the re-extension from the calling line will be progressed over, and means whereby the party operating the sending device will not be apprised as to which said route the connection from the calling line to the called line has been extended over.

77. In a telephone system, a subscriber's calling line, a called line, an operator's station, automatic switch mechanism, a calling device, means for the subscriber to initiate a call on the calling line, means whereby responsive to the operation of the calling device only after initiation of the call the switch mechanism will operate to extend a connection from the calling line to the called line, means responsive to a barred condition being encountered in the extension of the call thereby preventing the completion of the call extension to the called line the extension will be effaced and a re-extension of the effaced call made from the calling line to the operator's station, and means whereby the effacement will occur responsive only to said barred condition being encountered regardless of any condition occurring on the calling line while the initiated call is maintained non-abandoned by the subscriber.

78. In a telephone system, a subscriber's calling line, a called line, an operator's station, automatic switch mechanism, a calling device, means for the subscriber to initiate a call on the calling line, means whereby responsive to the operation of the calling device only after initiation of the call the switch mechanism will operate to extend a connection from the calling line to the called line, means responsive to a barred condition being encountered in the extension of the call

thereby preventing the completion of the call extension to the called line the extension will be effaced and a re-extension of the effaced call made from the calling line to the operator's station, and means whereby the effacement and re-extension will occur responsive only to said barred condition being encountered regardless of any condition occurring on the calling line while the initiated call is maintained non-abandoned by the subscriber.

79. In a telephone system, a subscriber's calling line, a called line, an operator's station, automatic switch mechanism, a calling device, means for the subscriber to initiate a call on the calling line, means whereby responsive to the operation of the calling device only after initiation of the call the switch mechanism will operate to extend a connection from the calling line to the called line, means responsive to a barred condition being encountered in the extension of the call thereby preventing the completion of the call extension to the called line the extension will be effaced and a re-extension of the effaced call made from the calling line to the operator's station, and means whereby the effacement will occur responsive to said barred condition being encountered regardless of how soon after encountering said barred condition the initiated call is abandoned by the subscriber.

80. In a telephone system, a calling line, a called line, an operator's station, automatic switch mechanism, a manually operated calling device, means whereby responsive to the operation of said calling device the switch mechanism will be directively operated to extend a connection from the calling line towards the called line, and means revertively controlled over said call extension towards the calling line responsive to a barred condition being encountered preventing the extension being further extended towards the called line the extended portion over which said control was effected will be effaced and a new extension made to connect the calling line to the operator's station without specific operation of the calling device for said new extension.

81. In a telephone system, a calling line, a called line, an operator's station, automatic switch mechanism, a manually operated calling device, means whereby responsive to the operation of said calling device the switch mechanism will be operated to extend a connection from the calling line towards the called line, and means revertively controlled over said call extension towards the calling line from a remote portion of the extension whereby responsive to a barred condition being encountered preventing the extension being extended to the called line the extension from the calling line will then be diverted from the called line as its objective to the operator's station as its objective without specific operation of the calling device because of said diversion of the call.

82. In a telephone exchange system, calling lines, called lines, selective switches for extending a calling line to one of said called lines, a register sender for recording the complete designation of wanted lines, a mechanism accessible in common to a plurality of selective switches for controlling the operation thereof, means in said mechanism for receiving a portion of a recorded designation, means in said mechanism for translating said portion of said recorded designation, means operable in accordance with said translated record for causing a plurality of said switches to operate to extend the calling line, means effective prior

- to the operation of said switches for nullifying said translated record and for automatically setting up a new translation to cause one of said switches to extend the calling line towards the 5 called line independently of the designation of said called line, and means for completing the extension of said calling line to said called line in accordance with said complete designation. 80
83. In a telephone exchange system, a calling 10 office, a called office, trunks extending between said calling and said called offices, a register sender for recording the designation of wanted lines in said called office, a mechanism accessible in common to a number of lines in said calling 15 office for controlling the selection of one of said trunks and for receiving and translating a portion of said recorded designation, means effective upon the translation of said portion of the recorded designation for transmitting to said sender an 20 indication of the class of service, and means rendered effective when all of said trunks are busy for automatically changing the class of service 25 indication in the sender. 85
84. In a telephone exchange system, a calling office, a called office, an intermediate office, trunks for completing a connection between said calling and said called offices, trunks for completing a connection between said calling and said intermediate office, a register sender for recording 30 the designations of wanted lines in said called office, means for indicating to the sender different classes of service required, means under control of a subscriber in the calling office for directively selecting one of said first mentioned trunks 35 and for indicating to the sender a corresponding class of service, and means effective when all of said first mentioned trunks are busy for automatically selecting an idle one of said second trunks and for automatically indicating to the 40 sender a new class of service required. 90
85. In a telephone exchange system, a calling office, a called office, an intermediate office, trunks for completing a connection between said calling and said called offices, trunks for completing a connection between said calling and said intermediate offices, a register sender for recording 45 the designations of wanted lines in said called office, a common controlling mechanism in said calling office for controlling the selection of one 50 of said first mentioned trunks, means effective upon the selection of said one of said trunks and under control of said mechanism for transmitting a class of service indication to said sender, and means rendered effective when all of said first 55 mentioned trunks are busy for automatically selecting an idle one of said second trunks and for changing the class of service indication in the sender. 95
86. In a telephone system, a group of selective 60 switches, a group of lines accessible from said switches, a trunk line including a bar conductor for each said switch, switch mechanism for seizing said trunks only when unbarred, a common bar conductor for said group of switches connected through a normally closed contact on each said switch to the bar conductor of the corresponding trunk only when the corresponding 65 trunk is idle, a relay for each of said lines, a chain circuit from ground to said common bar conductor closed by said relays only when all 70 100
- said lines are busy whereby when all said lines are busy ground will be applied over said common conductor to the bar conductor of each of the idle ones of said trunks to bar them from seizure by the switch mechanism. 105
87. In a telephone system, a group of selective switches, a group of lines accessible from said switches, a trunk line having not to exceed three conductors including a bar conductor for each said switch, switch mechanism for seizing said trunks only when unbarred, a common bar conductor for said group of switches connected through a normally closed contact on each said switch to the bar conductor of the corresponding trunk only when the corresponding trunk is idle, a relay for each of said lines, a chain circuit from ground to said common bar conductor closed by said relays only when all said lines are busy whereby when all said lines are busy ground will be applied over said common conductor to the bar conductor of each of the idle ones of said trunks to bar them from seizure by the switch mechanism. 110
88. In a telephone system, a calling line, called subscriber lines, a call directing device on the calling line, trunk lines and terminating selective switches therefor, means responsive to operating the directive device in accordance with the designation of a desired one of said subscriber lines for successively operating a train of said switches to link a trunk connection from the calling line to the desired subscriber line, a signal transmitting device, and means whereby responsive to the extension being barred from being completed to the last switch of the required train for disestablishing the extension and thereupon establishing a new extension from the calling line to the signal transmitting device to thereby apply a signal over the calling line to indicate the barred condition. 115
89. In a telephone system, an automatic switch, groups of lines accessible to said switch, an impulse sending apparatus for sending a particular series of impulses to said switch to effect the operation of the switch to associate it with the corresponding one of said groups of lines, and circuit arrangements controlled from the lines of said last mentioned group and responsive to a predetermined condition of said lines to alter the digit transmitted to said switch so that it will be brought into operative relation to a different one of said groups of lines. 120
90. In a telephone system, an automatic switch, groups of lines accessible to said switch, an impulse sending apparatus for sending a particular series of impulses to said switch to effect the operation of the switch to associate it with the corresponding one of said groups of lines, circuit arrangements controlled from the lines of said last mentioned group and responsive to a predetermined condition of said lines to alter the digit transmitted to said switch so that it will be brought into operative relation to a different one of said groups of lines, and means operative responsive to all of said lines in said last group being busy to alter the digit transmitted to said switch so that it will be brought into operative relation to another one of said groups of lines. 125

HERBERT M. FRIENDLY. 145
